UNITED STATES PATENT OFFICE

2,379,169

MULTIPLYING MACHINE

Ernest Charles McClure, Wahroonga, New South Wales, Australia, assignor to Powers Accounting Machines Limited, London, England, a company of Great Britain

Application June 26, 1939, Serial No. 281,180
In Great Britain July 2, 1938

9 Claims. (Cl. 235—61.6)

This invention relates to multiplying machines and has for its object to provide a machine capable of effecting multiplication of two factors, of which the multiplier may be a whole number and/or a fraction while the multiplicand may be a number expressed in the decimal notation or in a non-uniform, e. g. sterling, notation.

According to the present invention a machine for multiplying a number by a whole number and/or a fraction comprises means for entering a multiplicand into the machine, means for entering a predetermined fraction of said multiplicand into the machine, multiplying means, means for causing said multiplying means to effect multiplication of the multiplicand by the whole number portion of the multiplier and means for causing said multiplying means to effect multiplication of the predetermined fraction of the multiplicand by a whole number multiplier which, when divided by the denominator of the predetermined fraction of the multiplicand yields the fraction which occurs in the multiplier.

The invention also includes a machine for multiplying a number by a whole number and/or a fraction comprising means for entering a multiplicand into the machine, means operative under the control of said entering means to enter into the machine a predetermined fraction of said multiplicand, means for entering into the machine a multiplier comprising a whole number and a fraction, means operative under the control of said multiplier entering means for converting the fractional portion of the multiplier into the numerator of a fraction a whole number which, when divided by the denominator of the predetermined fraction of the multiplicand, is equivalent to the fractional portion of the multiplier, multiplying means, means for causing said multiplying means to effect multiplication of the multiplicand by the whole number portion of the multiplier and means for causing said multiplying means to effect multiplication of the predetermined fraction of the multiplicand by the whole number multiplier into which the fractional portion of the multiplier has been converted.

Preferably the machine according to the invention comprises means operative under the control of multiplier entering means for making a set-up representative of the whole number portion of the multiplier and of the whole number multiplier which represents the fractional portion of the multiplier, means operative under the control of the multiplicand entering means for

making a set-up representative of the multiplicand, means also operative under the control of the multiplicand entering means for making a set-up representative of the predetermined fraction of the multiplicand, means for reading the set-up of the whole number multiplier which represents the fractional portion of the multiplier, means for contemporaneously reading the set-up of the fractional multiplicand, means for effecting the multiplication of the readings of these two set-ups under the joint control of their two said reading means, means for reading the set-up of the whole number portion of the multiplier, means for reading the set-up of the multiplicand, means for effecting the multiplication of the readings of these two last named set-ups under the joint control of their reading means, and means for adding the two products thereby obtained.

20 The means for entering the predetermined fraction of the multiplicand may comprise means for making a series of set-ups, one for each multiplicand digit, and each representing the predetermined fraction of the corresponding digit, 25 means for accumulating the resulting partial quotients and means operative under the control of said accumulating means for making a set-up representing the sum of said partial quotients.

According to a further feature of the invention the machine may comprise four set-up devices, means for entering a multiplicand into one of said set-up devices, means for entering a predetermined fraction of said multiplicand into another of said set-up devices, means for entering into the third set-up device the whole number portion of the multiplier and also a whole number multiplier which, when divided by the denominator of the predetermined fraction of the multiplicand yields the fractional portion of the multiplier, means for multiplying a multiplicand by a single digit multiplier, means for causing the multiplying means to perform a number of successive multiplying operations equal to the number of digits in the whole number portion of the multiplier and the whole number multiplier representing the fractional portion of the multiplier, means operative at each multiplying operation to set up in the fourth set-up device a predetermined multiple of the contemporaneous multiplicand, means whereby during the first of a series of successive multiplying operations the multiplying means is placed under the control of the set-up device which contains the fractional multiplicand, while during

subsequent multiplying operations said multiplying means is placed under the control of the set-up device in which the predetermined multiples are set up, until multiplication of the fractional multiplicand by all the digits of the fractional multiplier has been completed, means for then erasing the predetermined multiple set-up, means for then placing the multiplying means under the control of the set-up device containing the whole multiplicand during one multiplying operation only, and means for thereafter placing said multiplying means again under the control of the predetermined multiple set-up device until multiplication of the whole multiplicand by the whole number portion of the multiplicand has been completed.

Preferably the machine is controlled by perforated records and means is provided for recording the product, e. g. by punching it in the same record, e. g. a card, as that containing the factors from which the product was calculated. The product, however, may be printed on a sheet, whether or not it is punched in a card, and whether or not the machine is record-controlled.

In applying the invention to a machine for multiplying a sterling amount by a decimal number, a fraction or a multiplier containing both a whole decimal number and a fraction, the predetermined fraction of the multiplicand which is set up may be $\frac{1}{960}$ in which case the fractional portion of the multiplier will be set up as a whole number which, with 960 as a denominator, constitutes the numerator of a fraction equivalent to the fractional portion of the multiplier. For example $\frac{1}{3}$ would be set up in the machine as 320 since $320/960 = \frac{1}{3}$.

In order to handle fractions which cannot be exactly expressed with 960 as a denominator, the predetermined fraction of the multiplier may be $\frac{1}{9600}$ or even $\frac{1}{96000}$ if greater accuracy is required.

The invention will now be described with reference to the accompanying diagrammatic drawings which show the invention as applied to a record card controlled multiplying machine of the kind described in British specification No. 490,358.

In the drawings:

Fig. 1 and Fig. 1A together form an outside elevation of the machine looking at the left hand side;

Fig. 2 is a front elevation of the machine;

Figs. 3 and 3A are longitudinal sections of the machine on the line III-III of Figs. 4A, 4B, 4C, and 4D;

Figs. 4A, 4B, 4C, and 4D together form a sectional plan on the line IV-IV of Fig. 1; Figs. 4C and 4D being to a larger scale than Figs. 4A and 4B;

Fig. 52 is a timing diagram of the punch shaft.

The machine illustrated in the accompanying drawings is similar in form to the machine described in British specification No. 490,358, and those parts which also appear in British specification No. 490,358 will be given the same reference numerals as in that prior specification. Those parts which are not described in the aforesaid British specification will be given reference numerals commencing with the number 600.

Base

The machine comprises a base portion within which is mounted the mechanism for reading the factors from the card, and the mechanism for punching the products therein as well as the card feeding mechanism. Above the base portion is mounted the multiplying mechanism.

Mounted in the base portion (Fig. 5) is the driving shaft 1 which is rotated from an electric motor (not shown) by means of a belt and pulley 2. The shaft 1 drives through worm gearing 3, the driving member of a clutch mounted freely on a transverse shaft 4 which controls the card feeding mechanism and the sensing pin box

and will hereinafter be termed the selection shaft.

The clutch, through which the drive is transmitted from the shaft 1 to the selection shaft 4 will be described later.

Driven from the selection shaft 4 by means of sprocket wheels and a chain is another transverse shaft 5 which controls the total taking operations including the punching of the product on the card and will hereinafter be referred to as the punch shaft.

The cards, in each of which two factors have been punched are stored in a magazine 6 from which they are delivered by a reciprocating picker 7 to feed rolls 8 which feed them to the sensing pin box 9. The picker 7 (Fig. 47A) is reciprocated by means of arms 10 (Figs. 2 and 47A) secured to a shaft 11 carrying another arm 12 driven through a connecting rod 13 from an eccentric 14 (Figs. 10D and 47A) on the selection shaft 4.

After the card has been sensed, further feed rolls 8a transport the card from the pin box 9 to the punching unit, of which the side plates are indicated at 15 in Figs. 1, 6, 10C, 10D and 50C. Thence further feed rolls 8b deliver the card to a receiver 16 (Fig. 1) after the product has been punched therein. The feed rolls 8, 8a, and 8b are driven through sets of gearing 17, 17a, 17b from the driving shaft 1 (Fig. 5) the gears 17b being secured to a shaft 18 which is driven from the shaft 1 through gearing 19.

Card sensing pin box

The pin box 9 is of the form described in British specification No. 401,012 but the timing thereof differs from that of the pin box described in the aforesaid prior specification in that in the construction according to the invention the pin box remains down for the greater part of the revolution of the selection shaft 4 and is only up for a relatively short part of the revolution during which period the card which is in the pin box is released by withdrawal of the card stop 600, and is fed to the punching unit 15 by the feed rolls 8a while at the same time the next card is fed to the pin box by means of the picker knife 7 and the feed rolls 8.

The moving portion 21 of the pin box is reciprocated by a pair of cams 22 (Fig. 7) on the selection shaft 4. Each cam 22 is in the form of a track formed in a disc 22a and engaging with each cam track is a roller 23 on an arm 24 pivoted to the machine frame at 25 and connected at its other end by a link 26 to the moving portion 21 of the pin box (Figs. 1, 7, 10C and 10D).

The reciprocating plate or shutter of the pin box (member 26 in specification No. 401,012) is operated by means of a cam 28 on the selection shaft 4 (Fig. 7), this cam serving to rock a lever 29 pivoted to the machine frame at 30 and at its upper end to an arm 31 on a spindle 32 (Fig. 7) carrying a short arm which pivotally engages a block secured to the shutter.

In the present construction the card stop 600 (Figs. 10C, 10D and 47A) is driven independently of the pin box 9 by the following mechanism. The card stop 600 passes at its upper end through a guide 601 and has at its lower end a downwardly extending rod 602 passing through a bar 603 mounted transversely between the side plates 604 of the base, and a spring 605 urges the card stop upwards. Passing through a slot in the card stop is an arm 606 secured to a transverse shaft 608, and projecting from the card

stop is a bracket 610 carrying a pin 611 bearing on the end of the arm 608. Also secured to the shaft 609 is another arm 612 carrying a roller 613 engaging with a cam 614 secured to the selection shaft 4. Each time the shaft 4 rotates, the cam 614 rocks the arm 608 clockwise (Fig. 47A) thereby withdrawing the card stop at the appropriate time to permit release of the card from the pin plates 606 and allowing the card stop 600 to rise under the action of the spring 605 at the proper time to arrest the card for sensing.

Selection, multiplication, and punch shafts and clutch mechanism controlling them

The mechanism for controlling the selection shaft so that it makes one revolution only when started up, will now be described (Figs. 8 and 9).

Freely mounted on the selection shaft 4 is a driving member 36 (Figs. 9 and 10D) carrying a sprocket wheel 37 (Fig. 2) connected by a chain 38 to a sprocket wheel 39 (Figs. 2 and 10B) carried by a driving clutch member 36a freely mounted on a transverse shaft 41. This transverse shaft carries cams which control the multiplication operations and will hereinafter be referred to as the multiplication shaft Figs. 10A, 10B, 22, 48A and 48B).

The driving clutch member 36 on the shaft 4 is rotated from the driving shaft 1 through the worm gearing 3 (Figs. 2 and 10B) and thus when the motor is started the shaft 1 rotates continuously and the driving clutch members 36 and 36a also rotate continuously.

Fixed to the shaft 4 is a driven clutch disk 44 and secured to the multiplication shaft 41 is a driven clutch disk 44a.

Mechanism is provided for controlling the two clutches in such a way that the clutch for the selection shaft 4 remains in engagement for only one revolution, whereas the clutch for the multiplication shaft 41 remains in engagement for a number of revolutions depending upon the number of digits in the multiplier. The mechanism for starting the machine and for controlling the clutch of the selection shaft 4 will now be described.

In order to start the machine a button 46 is pushed to the right in Figure 8. This button is pivoted to a lever 47 which is pivoted to the machine frame at its lower end 48 and carries a pin 49 which can engage with a recess formed in a link 50 pivoted to a lever 51 which in turn is pivoted to the machine frame at 52. Pivoted at the upper end of the lever 51 is an arm 53 which engages with a pin 54 secured to the upper end of an arm 55 secured to a shaft 56. When the button 46 is pushed to the right the lever 47 is rocked clockwise about its pivot 48 and the pin 49 engaging with the recess in the link 50 rocks the lever 51 clockwise about its pivot 52 thereby moving the arm 53 to the right and rocking the shaft 56 clockwise. Secured to the shaft 56 is a control bell crank 57 carrying two rollers 58, 59 (Fig. 9).

Mounted in radial slots 60 in the driven disc 44 which is secured to the selection shaft 4 are two dogs 61 each carrying a roller 62 engaging with a cam slot 63 in a disc 64 free on the shaft 4. Also mounted on the shaft 4 is a keep plate 65 which is attached to the driven disc 44 and is connected by a spring 66 to the disc 64, the spring 66 tending to pull the disc 64 clockwise with relation to the keep plate 65.

Normally one of the dogs 61 engages with a 75 later.

detent 61a and the disc 64 is held stationary by a lug 68 thereon engaging with the end of a stop lever 69 pivoted to the machine frame by means of a pin and slot at 70. This lever 69 is also provided with a spring 71 tending to pull it to the left in Figure 9. The spring 71 is stronger than the spring 66 and acting through the lug 68 maintains the lever 69 over to the left.

As already explained when the button 46 is pushed to the right the shaft 56 is rocked clockwise and accordingly the control bell crank 57 is also rocked clockwise. The stop lever 69 is also provided with a pivoted latch 72 connected by a spring 73 to the control bell crank 57, this spring 15 tending to pull the lever 69 clockwise about the pivot 70. This movement of the lever 69 is, however, normally prevented by engagement of the latch 72 with a banking plate 74.

When the control bell crank 57 is rocked clockwise as described above the lower roller 59 rocks the latch 72 clear of the banking plate 74 whereupon the spring 73 rocks the lever 69 clockwise out of the path of the lug 68.

The spring 66 then pulls the disc 64 clockwise about the shaft 4 whereby the cam slots 63 force the dogs 61 into engagement with the periphery of the driving disc 36.

As the driving disc 36 rotates slots 75 formed therein come into register with the clutch dogs 61 whereupon the spring 66 pulls the plate 64 still further clockwise relatively to the keep plate 65 and driven disc 44 whereby the cam slots 63 force the dogs 61 into the slots 75. The rotation of the driving disc 36 then takes the driven disc 44 with it through the medium of the dogs 61, the disc 64 rotating with the other members.

As these members rotate a roller 76 on the keep plate 65 strikes a block 77 on the end of an arm 78 secured to the shaft 56 carrying the control bell crank 57 whereby the latter is rocked counter-clockwise and the lower roller 59 thereon rocks the stop lever 69 also counter-clockwise about its pivot 70 thereby moving the left hand end of the stop lever into the path of the lug 68 on the plate 64. At the same time the latch 72 engages the banking plate 74 and prevents the lever 69 from rocking back again in the clockwise direction.

Then as the discs 36, 44, 64 and 65 rotate the lug 68 strikes the left hand end of the stop lever 69 whereby the stop lever is pushed towards the right to the end of its slot 70 thereby extending the spring 71. The plate 64 is then arrested but the driven plate 44 is carried round still further 55 whereby the cam slots 63 force the dogs 61 radially outwards disengaging them from the slots 75 in the driving disc 36. The spring 71 then contracts and pushes the stop lever 69 slightly to the left whereby the plate 64 is turned slightly counter-clockwise and the cam slots 63 move the dogs 61 clear of the periphery of the driving plate 36, the detent 61a engaging one of the dogs 61 in this position and preventing further movement of the driven disc 44 and of the selection shaft 4.

65 The latter has therefore been arrested after making one revolution.

While the machine is running the action of the clutch control mechanism in disengaging the selection shaft clutch causes the clutch for the multiplication shaft 41 to engage, whereupon the shaft 41 commences to rotate and is permitted to rotate for a number of revolutions corresponding to the number of digits of the multiplier, under the control of mechanism which will be described later.

During the revolution of the shaft 4 in which the pin box 9 is sensing the last card of a series the last card but one is fed to the punch unit 15 and at the end of this revolution the last card remains in the pin box and the last card but one in the punch unit.

The multiplication shaft then operates and the product of the factors read from the last card but one is calculated, after which the shaft 4 makes another revolution. During this revolution the last card is fed from the pin box to the punch unit and the product of the factors read from the last card but one (during the preceding revolution but one of the shaft 4) is punched in the last card but one and this card is ejected. During the same revolution of the selection shaft the last card is fed into the punch unit.

Also during this revolution of the shaft 4 the pin box performs a sensing operation, but as no card is present, the "no card" mechanism, which will be described later, is set to stop the machine.

The multiplication shaft then starts again and the product of the factors read from the last card (during the preceding revolution but one of the shaft 4) is punched in the last card and the last card is ejected.

Since during the preceding revolution of shaft 4 the "no card" mechanism was set to stop the machine the machine will stop at the end of the revolution during which the last card is punched.

During the last revolution of the selection shaft "no card" was again sensed and accordingly the "no card" mechanism is again set to stop the machine, and consequently does stop the machine as soon as the selection shaft 4 has made one revolution on being started up again.

As described in British specification No. 401,012, there is provided in the pin box a so-called "no card" pin which is shown at 40 in Fig. 2 of the aforesaid prior specification. Referring still to the prior specification, when there is a card in the pin box the pin 40 is prevented from descending to the fullest extent and accordingly an arm 47 is held in an upper position. In the present description the arm 79 in Fig. 7 corresponds to the arm 47 described in British specification No. 401,012.

When there is a card within the pin box and the arm 79 is therefore held up the left end of this arm is clear of a block 31a on the arm 31 through which the shaft 32 of the pin box shutter 27 is rocked and consequently the shutter is operated.

When there is no card in the pin box the arm 79 is permitted to drop and engages the block 31a thereby preventing the arm 31 from moving under the action of the cam 28 on the selection shaft 4. Secured to the shaft 32 (Fig. 8) is an arm 80 pivoted by a pin and slot connection 81 to a latch 82 pivoted to the machine frame at 83. This latch co-operates with a pin 84 on the upper end of a lever 85 pivoted to the machine frame at 86 and carrying a roller 87 cooperating with a cam 88 on the shaft 4. When there is no card in the pin box the shaft 32 is held by the arm 79 in a position in which the latch 82 is held up clear of the pin 84, consequently as the shaft 4 rotates the roller 87 drops into the recess in the cam 88 under the action of a spring 85a and the lower end of the lever 85 switches off the motor by engaging a pin 92 on a link 90 connected to the operating knob of the motor switch 91.

It may here be pointed out that when the button 46 is pushed to the right the lower end of the lever 81, engages the pin 92 on the link 90,

and moves the latter to the left to close the motor switch 91.

From the foregoing it will be seen that when the machine is started the shaft 4 makes one revolution after which the motor is switched off.

In order to cause the machine to continue to operate it is necessary to push the button 46 to the right again whereupon the motor is switched on and the lower clutch causes the selection shaft 10 4 to make another revolution. Since during the first revolution there was a card in the pin box consequently the shaft 32 was able to rock clockwise in Figures 7 and 8 whereby during the second revolution the latch 82 is engaged with the pin 84 and prevents the roller 87 from dropping into the recess in the cam 88 so that the motor switch 91 remains closed.

The clutch for driving the multiplication shaft 41 is constructed in a similar manner to that of the selection shaft 4 and the plate 64a (Fig. 9) thereof is provided with a lug 68a which normally engages with the right end of a stop lever 69a pivoted to the machine frame by a pin and slot 70a and having a spring 71a similar to the spring 71. This stop lever 69a is provided with a pivoted latch 72a which normally engages with the banking plate 74. When the roller 76 on the plate 65 rocks the control bell crank 57 counter-clockwise at the end of the one revolution of the shaft 4 the upper roller 58 on the bell crank swings the latch 72a clear of the plate 74 whereupon a spring 73a pulls the stop lever 69a clockwise about its pivot 70a thereby withdrawing its right hand end from the lug 68a so that the clutch for the multiplication shaft 41 engages in a manner similar to that in which the engagement of the clutch for the selection shaft 4 is effected.

Normally therefore when the selection shaft 4 stops the multiplication shaft 41 starts. As already mentioned, however, during the first revolution of the selection shaft 4 the "no card" mechanism is set to stop the machine and it is therefore necessary to prevent the multiplication shaft 41 from starting until button 46 has been pressed again. To this end when the roller 87 (Fig. 8) drops into the recess of the cam 88 and the lever 85 is thereby swung counter-clockwise by the spring 85a a lug 93 on the upper end of the lever 85 moves over a lug 94 on the left hand end of the stop lever 69a and therefore prevents the latter from rocking out of the path of the lug 68a. The lug 94 has an inclined upper surface 94a (Fig. 9) so that as the lug 93 passes over the lug 94 the lever 69a is rocked slightly counter-clockwise thereby lifting the latch 72a just clear of the plate 74. This clearance permits the latch 72a to return into engagement with the plate 74 when the roller 58 is moved from engagement therewith. At the same time the bell crank 57 is returned to its mid-position by the action of spring 73a assisted by spring 95 attached to the tail 57a of the bell crank.

When the machine is started up again the shaft 4 makes one revolution during which the card which was sensed during the first revolution is fed from the pin box 9 into the punch unit 15. The multiplication shaft 41 then starts because the lever 85 is prevented from rocking counter-clockwise by the latch 82 and its upper lug 93 does not engage the lug 94 on the stop lever 69a so that the latter can move clear of the lug 68a.

Before describing the mechanism actuated by the multiplication shaft 41 the mechanism for retaining the factors read from the card will be described.

The factors read from the card by the pin box 9 are set up in two stop baskets located in the upper portion of the machine, there being a stop basket 620 for the multiplier and a stop basket 621 for the multiplicand (Figs. 2, 4B, 10A and 10B).

Multiplier stop basket

The multiplier stops 622 are mounted in upper and lower plates 623, 624 (Fig. 11) of the basket 620 and each stop has an enlarged portion 625, the lower end of which rests on the lower plate 624 while a spring 626 is disposed between the upper plate 623 and the upper end of the enlarged portion 625.

Running longitudinally of each column of stops is a latching slide 627 carrying a series of cam projections 628 one for each stop. Each stop has a cam projection 629 and when any stop is raised (see the extreme right hand stop in Fig. 11) its cam projection 629 by engagement with the associated cam projection 628 on the slide 627 pushes the latter to the left (Fig. 11) against the action of a spring 630 until the projection 629 is above the projection 628, when the spring 630 pulls the slide 627 back to the right thereby bringing the projection 628 below the projection 629 so that the stop is prevented from descending.

Mechanism, which will be described later, is provided for pushing the slides 627 to the left when it is desired to release the stops 622 which have been set.

Multiplicand stop basket

In the machine according to the invention, when the multiplicand is read from a card the complete multiplicand is set up in certain columns of the multiplicand stop basket 621 and also $\frac{1}{160}$ of this multiplicand is set up in certain other columns of the same stop basket 621.

For convenience of reference the value $\frac{1}{660}$ of the multiplicand will hereinafter be referred to as the fractional multiplicand. In the drawings the stops which receive the fractional multiplicand are shown at **631** and the stops which receive the complete multiplicand are shown at **632** (Figs. 4B, 10A and 10B).

In the multiplicand stop basket 621 there are eleven denominational columns of stops 632 for receiving the complete multiplicand and, reading from top to bottom of Fig. 4B the denominations associated with these columns are: ten thousandths of one penny (0.0001d.), thousandths of one penny (0.001d.), hundredths of one penny (0.01d.), tenths of one penny (0.1d.), pence, units of shillings, tens of shillings, units of pounds, tens of pounds, hundreds of pounds and thousands of pounds.

The columns of stops 631 which receive the fractional multiplicand are interdigitated with the columns of stops 632 and there are nine columns of stops 631 of which the denominations, reading from top to bottom of Fig. 4B, are as follows: ten thousandths of one penny (0.0001d.) thousandths of one penny (0.001d.), hundredths of one penny (0.01d.), tenths of one penny (0.1d.), pence, units of shillings, tens of shillings, units of pounds and tens of pounds.

There are thus two columns of stops for each denomination up to tens of pounds, one column 632 for the associated denominational digit of the complete multiplicand, and one column 631 for the associated denominational digit of the fractional multiplicand, each column 631 being to the right of the associated column 632 (looking at the front of the machine).

Each column of stops **631** and **632** except the two pence columns, the two tens of shillings columns, and the tens of pounds column **631** has ten stops representing the digits 0 to 9. Each of the two pence columns has twelve stops representing the digits 0 to 11 and the two tens of shillings columns have only two stops representing the digits 0 and 1. The tens of pounds column **631** which receives the tens of pounds digit of $\frac{1}{960}$ of the multiplicand also has only two stops representing the digits 0 and 1, because the maximum multiplicand which can be set up in the columns **632** is £9999-19-11.9999d. and $\frac{1}{960}$ of this value can never give rise to a digit greater than one in the tens of pounds denomination.

18 one in the tens or pounds denomination.

The construction of the stops 631 and 632 in the multiplicant stop basket 621 is the same as that of the stops 622 in the multiplier stop basket 620 and each column of multiplicant stops has a latching slide similar to the latching slides 621 in the multiplier stop basket. The latching slides for the fractional multiplicant stops 631 are shown at 633 and those for the complete multiplicant stops 632 are shown at 634. (Figs. 4B, 10A and 10B).

Fraction stop basket and connection box therefor

The stops 632 for the complete multiplicand are set from the pin box 9 through wires 635 in a connection box 636 (Figs. 10A, 10B and 15), a small intermediate connection box 637 having rods 638 being disposed between the upper ends of the wires 635 and the lower ends of the stops 632.

35 Adjacent to the connection box 636 is another connection box 639 of which the wires 640 serve to set stops 641 in another stop basket 642. The wires 635 in the connection box 636 are so connected to the wires 640 in the connection box 639 that the raising of a wire 635 of a particular value sets stop 641 in the basket 642 to represent $\frac{1}{600}$ of that value. For the sake of clarity the connection box 639 and the stop basket 642 will be referred to as the fraction connection box and the fraction stop basket respectively.

For example if the wire 635 in the connection box 636 representing £1000 is raised, then stops 641 in the fraction stop basket 642 representing

50 are raised. At the same time the wire 635 acting through the associated rod 638 in the intermediate connection box 637 directly sets the No. 1 stop in the thousands of pounds column of the complete multiplicand series of stops 632 in the 55 multiplicand stop basket 621.

It may here be pointed out that although there is a wire 635 for the value zero in each denomination in the connection box 636 and a corresponding zero stop in the multiplicand stop basket 621, there are no settable zero stops in the fraction stop basket 642. Hence in the example quoted above viz:

$$\frac{\text{£}1000}{960} = \text{£}1\ 0.\ 10d.$$

only two stops would be set in the basket 642, i. e. one representing one pound and one representing ten pence.

70 It will thus be seen that the raising of one wire 635 in the connection box 636 may involve the setting of stops in several denominations of the fraction stop basket 642.

Moreover since the multiplicand as read from the card will usually contain a plurality of digits 75 a plurality of columns of stops 641 is required for

each denomination of the fraction stop basket 642.

For example:

$\frac{1}{100}$ of £3,875.19.11. gives the following digits to be set up in the fraction stop basket 642.

	£. units	10/-	Sh. units	d	$\frac{d}{10}$	$\frac{d}{100}$	$\frac{d}{1,000}$	$\frac{d}{10,000}$
$\frac{1}{100}$ of £3,000.....	3		2	6				
$\frac{1}{100}$ of £800.....		1	6	8				
$\frac{1}{100}$ of £70.....			1	5				
$\frac{1}{100}$ of £5.....			1	2	5			
$\frac{1}{100}$ of 10/-.....				1	2	5		
$\frac{1}{100}$ of 9/-.....				1	1	2	5	
$\frac{1}{100}$ of 11d.....					1	1	1	4

From the foregoing it will be seen that in several denominations four digits occur involving four columns of stops in the fractions stop basket 642 for each of these denominations.

For a machine capable of handling multiplicands up to £9,999.19.11.9999d twenty-four columns of stops 641 are required in the fractions stop basket 642 to receive the digits arising out of $\frac{1}{100}$ of any multiplicand. In this connection $\frac{1}{100}$ of any decimal fraction less than $\frac{1}{10}$ penny is neglected.

The table set out below gives the values of $\frac{1}{100}$ of any multiplicand digit from 0.1d to £9,000 and the diagram of Figs. 16a(1), 16a(2), 16b(1), 16b(2), 16c(1), 16c(2), 16d(1), and 16d(2) shows the connections between the wires 635 in the connection box 636 and the wires 640 in the fraction connection box 639 which are necessary to set the stops 641 of the fraction stop basket 642 in accordance with the above table.

	Thousands of pounds	Hun- dreds of pounds	Tens of pounds	Units of pounds	Tens of shill- ings	Units of shill- ings	Pence	Pence 10
	£ s. d.	s. d.	s. d.00	d.00	d.000	d.0000	d.0000	d.0000
1	1-0-10	2-1	2.5	.25	.125	.0125	.001	.0001
2	2-1-8	4-2	5.0	.60	.300	.025	.002	.0002
3	3-2-6	6-3	7.5	.75	.375	.0375	.003	.0003
4	4-3-4	8-4	10.0	1.00	.500	.05	.004	.0004
5	5-4-2	10-5	1-0.5	1.25	.625	.0625	.005	.0005
6	6-5-0	12-6	1-3.0	1.50	.750	.075	.006	.0006
7	7-5-10	14-7	1-5.5	1.75	.875	.0875	.007	.0007
8	8-6-8	16-8	1-8.0	2.00	1.000	.1	.008	.0008
9	9-7-6	18-9	1-10.5	2.25	1.125	.1125	.009	.0009
10							.0104	
11							.0114	

From this table it will be seen that twenty-four columns of stops 641 are required in the fraction stop basket 642, and the arrangement of these stops is shown diagrammatically in Fig. 14.

In the ten thousandths of one penny denomination three columns of stops 641 are required, indicated at A, B and C. Column A receives the

pence
10,000

digits of $\frac{1}{100}$ of the

pence
10

multiplicand digits; column B receives the

pence
10,000

digits of $\frac{1}{100}$ of the pence multiplicand digits, and column C receives the

pence
10,000

digits of $\frac{1}{100}$ of the units of shillings multiplicand digits.

From the table it will be seen that in column

A nine stops are required representing the digits 1 to 9. In column B four stops only are required representing the digits 1 to 4 while in column C only one stop representing the digit 5 is required.

5 In each column of the fraction stop basket 642 a nought stop 673 is provided which is not actuated by a connection box wire. The operation of these nought stops will be explained later.

In the

pence
1000

denomination there are three columns of stops D, E and F in the fraction stop basket 642. The column D receives the

pence
1000

digit of $\frac{1}{100}$ of the pence multiplicand digit, column E receives the

pence
1000

digit of $\frac{1}{100}$ of the units of shillings multiplicand digit, and column F receives the

pence
1000

digit of $\frac{1}{100}$ of the tens of shillings multiplicand digit.

30 From the table it will be seen that in column D nine stops (excluding the nought stop) are provided representing the digits 1 to 9, in column E only three stops representing the digits 2, 5 and 7 are required, while in column F only one stop representing the digit 5 is required.

35

From the table it will be seen that in column D nine stops (excluding the nought stop) are provided representing the digits 1 to 9, in column E only three stops representing the digits 2, 5 and 7 are required, while in column F only one stop representing the digit 5 is required.

In the

pence
100

55 denomination there are four columns of stops G, H, I and J. Column G receives the

pence
100

60 digit of $\frac{1}{100}$ of the pence multiplicand digit, column H receives the

pence
100

65 digits of $\frac{1}{100}$ of the units of shillings multiplicand digit, column I receives the

pence
100

70 digit of $\frac{1}{100}$ of the tens of shillings multiplicand digit, and column J receives the

pence
100

75 digit of $\frac{1}{100}$ of the units of pounds multiplicand digit.

From the table it will be seen that in column G only one stop representing the digit 1 is required, in column H seven stops representing the digits 1, 2, 3, 5, 6, 7 and 8 are required, while in columns I and J only one stop is required in each case, representing the digits 1 and 5 respectively.

In the tenths of pence denomination there are four columns of stops, K, L, M and N which receive the

pence
10

digit of $\frac{1}{660}$ of the units of shillings, tens of shillings, units of pounds and tens of pounds multiplicand digits respectively.

In columns K and L only one stop is provided in each case, each of these stops representing the digit 1. In column M three stops are provided representing the digits 2, 5 and 7, while in column N only one stop representing the digit 5 is provided.

In the pence denomination there are four columns of stops O, P, Q and R, and these columns respectively receive the pence digit of $\frac{1}{660}$ of the units of pounds, tens of pounds, hundreds of pounds and thousands of pounds digits of the multiplicand.

In column O two stops are provided representing the digits 1 and 2, in column P six stops are provided representing the digits 2, 3, 5, 7, 8 and 10; in column Q nine stops representing the digits 1 to 9 are provided, and in column R five stops representing the digits 2, 4, 6, 8 and 10 are provided.

In the units of shillings denomination three columns of stops S, T and U are provided which respectively receive the units of shillings digits of $\frac{1}{660}$ of the tens of pounds, hundreds of pounds, and thousands of pounds multiplicand digits.

In column S only one stop representing the digit 1 is provided, in column T four stops representing the digits 2, 4, 6 and 8 are provided, while in column U seven stops are provided representing the digits 1 to 7.

In the tens of shillings denomination one column of stops V, is provided, which receives the tens of shillings digit of $\frac{1}{660}$ of the hundreds of pounds multiplicand digit. Only one stop is provided in this column representing the digit 1.

In the units of pounds denomination only one column of stops W, is provided, and this column receives the units of pounds digit of $\frac{1}{660}$ of the thousands of pounds multiplicand digits. In this column W, nine stops are provided representing the values 1 to 9.

In the tens of pounds denomination one column X is provided in which there is only one stop representing the digit 1. This column X receives the tens of pounds digit of $\frac{1}{660}$ of the thousands of pounds multiplicand digits.

In Figs. 16a(1), 16a(2), 16b(1), 16b(2), 16c(1), 16c(2), 16d(1), and 16d(2) there are shown diagrammatically the connections between the wires 635 in the connection box 636 and the wires 640 in the fraction connection box 639. In these figures the denominational columns of wires 635 are indicated at MA, MB, MC, . . . MK, and the columns of wires in the fraction connection box are indicated at A, B, C, D, . . . V, W, X. In this connection it may be pointed out that for convenience the columns of wires 640 in the fraction connection box 639 have been given the same reference letters A, B, . . . W, as those allocated to the corresponding columns of stops 641.

The diagram of Figs. 16a(1), 16a(2), 16b(1),

16b(2), 16c(1), 16c(2), 16d(1), and 16d(2) in reality constitutes the table given above set out in diagrammatic form.

In setting up $\frac{1}{660}$ of the multiplicand in the fraction stop basket 642 the value $\frac{1}{660}$ of any digit of the multiplicand of a denomination below the

pence
10

denomination is ignored. Consequently as can be seen in the diagram there are no connections from the columns MA, MB and MC of the connection box 636 to the fraction connection box 639.

As can be seen from the table given above the values of the fraction $\frac{1}{660}$ of the digits 1 to 9 in the

pence
10

denominations are taken as being .0001, .0002, .0003 and so on, up to .0009 respectively. These values are not perfectly accurate but their accuracy is sufficient to give the product to the nearest penny.

Accordingly the wires representing the digits 1 to 9 in the

pence
10

denominational column MD of the connection box 636 are respectively connected by wires A₁, A₂, A₃ . . . A₉ to the wires representing the digits 1 to 9 in column A of the fraction connection box 639.

Referring again to the diagram, the wires 635 of the connection box 636 in the pence column ME are connected as follows:

The wire representing one penny is connected through a wire ME₁ to the No. 1 wire in column D of the fraction connection box. The wire representing twopence in the column ME is connected through a wire ME₂ to the No. 2 wire in column D of the fraction connection box. The wire representing three-pence in the column ME is connected through a wire ME₃ which branches into two wires of which one marked 3D₃ is connected to the No. 3 wire in column D of the fraction connection box, while the other wire marked 3B₁ is connected to the No. 1 wire in column B of the fraction connection box.

The wire representing fourpence in the column ME is connected through a wire ME₄ which branches into two wires of which one 4D₄ is connected to the No. 4 wire in column D of the fraction connection box, while the other wire 4B₁ is connected to the No. 1 wire in column B of the fraction connection box.

The wire representing fivepence in column ME has connected to it a wire ME₅ which branches into two wires 5D₅ connected to the No. 5 wire in column D of the fraction connection box and a wire 5B₂ which is connected to the No. 2 wire in column B of the fraction connection box.

The wire representing sixpence in the column ME has connected to it a wire ME₆ which branches into two wires of which one 6D₆ is connected to the No. 6 wire in column D of the fraction connection box, while the other wire 6B₂ is connected to the No. 2 wire in column B of the fraction connection box.

It is believed that the diagram of Figures 16a(1), 16a(2), 16b(1), 16b(2), 16c(1), 16c(2), 16d(1), and 16d(2) together with the table given above will be found self-explanatory, and that it

is therefore unnecessary to describe each and every connection shown in the diagram.

It is sufficient to point out that in applying reference characters to the diagram any wire which leaves one of the wires 635 is given a reference which comprises the reference MD, ME . . . MK, to the column of wires 635 which it has left followed by a numeral representing the value of the particular wire in that column from which it comes. Thus in the units of shillings column MF the wire which leads transversely from the No. 6 wire in this column is given the reference MF6.

Further, where, as is frequently the case, a wire, such as the wire MF6 branches into two or more wires, the right hand ends of which in the diagram are connected to wires in the fraction stop basket, these branch wires are given reference characters comprising first a number representing the number of the wire in the connection box 636 from which the main wire such as MF6 emanates, secondly a letter denoting the column of wires in the fraction connection box 639 to which the particular branch wire is going, and thirdly a number representing the value of the particular wire in that column of the fraction connection box to which the branch wire in question is connected.

Thus the wire MF6 which comes from the No. 6 wire in the column MF in the connection box 636 branches into two wires 6H7 and 6E5 respectively, the wire 6H7 goes to the No. 7 wire in column H of the fraction connection box 639, and the wire 6E5 goes to the No. 5 wire in column E of the fraction connection box.

It will be noticed that the wire MF9 coming from the No. 9 wire in column MF of the connection box 636 branches into four wires marked 9K1, 9H1, 9E2 and 9C5. From inspection of the diagram it will be seen that the wire 9K1 goes to the No. 1 wire in column K, 9H1 goes to the No. 1 wire in column H, 9E2 goes to the No. 2 wire in column E, and 9C5 goes to the No. 5 wire in column C.

With the foregoing description and the references on the diagram of Figs. 16a(1), 16a(2), 45 16b(1), 16b(2), 16c(1), 16c(2), 16d(1) and 16d(2) the connections for the entire connection box can readily be ascertained.

In the diagram the columns of wires are shown in perspective and as can be seen from Figs. 50 16a(1), 16a(2), 16b(1), 16b(2), 16c(1), 16c(2), 16d(1) and 16d(2) in many of the columns of the fraction connection box 639 there are no wires in certain of the positions. In the diagram the wires which exist are shown in the correct numerical position and the positions of the missing wires are indicated by dots which appear at the top and bottom of each column of wires.

It will be observed that in many cases a particular wire 640 has to be raised when any one of a number of wires 635 is raised, thus for example the No. 5 wire in column J of the fraction connection box may be raised by any one of five wires, 1J5, 3J5, 5J5, 7J5 and 9J5 coming from column MH of the connection box 636. Thus when the No. 1 wire in column MH is raised the No. 5 wire in column J of the fraction connection box is raised by means of the wires MH1 and 1J5. Likewise if the wire No. 3 in column MH is raised the No. 5 wire in column J is again raised, but this time through the medium of the wires MH3 and 3J5. It will be seen that if there is a fixed connection between each of the wires 1J5, 3J5, 5J5, 7J5 and 9J5 and the No. 5 wire in column J, the raising of this

5 No. 5 wire by any of the connected wires would cause lifting of all the other connected wires, and therefore of all the corresponding wires in the column MH of the connection box 636, namely the wires MH1, MH3, MH5, MH7 and MH9. In order to avoid this occurrence where a wire such as the No. 5 wire in column J has to be raised by more than one wire such as the wire 1J5, then the wire J is provided with a projection running over the end of the wire 1J5, so that when the wire 1J5 is raised, it raises the No. 5 wire in column J, but when the latter is raised it does not lift the wire 1J5.

10 This arrangement is illustrated in Fig. 17 which shows a portion of the connection box. In this figure the wire which represents two-pence (wire No. 2 in column ME of the connection box 636) is directly connected by the wire ME2 to the No. 2 wire in column B of the fraction connection box 639. This latter wire represents .0002 pence. Since, in this case, when the No. 2 wire in column ME is raised only one wire has to be raised in the fraction connection box, the connecting wire ME2 is rigidly connected at both ends to the wire with which it is associated, these rigid connections being shown at 650 and 651. These connections may be made by simply sweating the wires together.

15 In the case, however, of the No. 1 wire in the units of shillings column MF, this wire has to raise three wires in the connection box 639, and since these same three wires have also to be raised by the No. 9 wire in column MF, a different form of connection is employed.

20 Considering the No. 1 wire in the column MF (representing one shilling), the wire MF1 is rigidly connected thereto as by sweating at 652. At its right hand end, the wire MF1 branches into three wires 1C5, 1E2 and 1H1 (see the diagram Figs. 16a(1), 16a(2), 16b(1), 16b(2), 16c(1), 25 16c(2), 16d(1), and 16d(2).) The wire 1C5 passes below a projecting pin 653 on the No. 5 wire in column C representing .0005 pence, the wire 1E2 passes below a similar projecting pin 654 on the No. 2 wire in column E representing .002 pence, while the wire 1H1 passes under a projection 655 on the No. 1 wire in column H representing .01 pence.

25 Thus when the wire No. 1 in column MF is raised, the wires Nos. 5 in column C, 2 in column E, and 1 in column H, are simultaneously raised. The raising of any of these three latter wires, however, will not raise the No. 1 wire in column MF.

30 In Fig. 17 the letters representing the columns as indicated in the wiring diagram of Figs. 16a(1), 16a(2), 16b(1), 16b(2), 16c(1), 16c(2), 16d(1), and 16d(2) are placed at the end of the different columns, and at the lower end of each row of holes, is indicated the value of the holes in that row. It may be pointed out that, in the fraction connection box 639 the No. 1 wire is at the front of the column, and No. 9 at the back, whereas, in the main connection box 636, the 0 is at the back, and 9 at the front.

35 From the foregoing it will be seen that when a multiplicand is read from the card the complete multiplicand is set up by means of the connection box 636 in the columns of stops 632 in the multiplicand stop basket 621, and at the same time by means of the connection box 639 the partial quotients of $1/160$ of that multiplicand are set up in the fractions stop basket 642.

40 As already explained, in the fraction stop bas-

ket 642 there are three or more columns of stops in many denominations. For example in the

pence
10,000

denomination there are three columns A, B and C.

Partial quotient accumulator

It is desired to add together the partial quotients set up in the different columns of a denominational group such as A, B and C, and set the corresponding denominational column of stops 631 in the multiplicand stop basket 621 to the value of the resulting digit in that denomination.

To this end there is provided for each of the columns A to X a sliding plate which is set from the associated column of stops by a setting bar.

Figure 18 is a front elevation including the anchoring means for the springs which operate the plates and their associated mechanism. Fig. 19 is a front elevation with these springs removed to show the plates, and Figs. 4C and 4D show these plates and their associated mechanism in plan, while Fig. 20 which is a longitudinal section on the line XX—XX shows in outside elevation the group of plates pertaining to the units of shillings denomination. In this latter figure only the outside plate of the group appears since in showing the remaining plates the drawing would become obscured. Since in most of the denominational groups the sum of the partial quotients set up in the columns, such as A, B and C will exceed the number of digits in the denomination it is necessary to transfer one unit to the next group of plates, and to this end in the majority of the groups a transfer plate is provided at the right-hand end of the group in Figures 19, 4C and 4D.

In the following description each plate will be given the same reference letter as in its associated column of stops in the basket 642 preceded by the letter P; thus, the plate which is set from column A will be referred to as PA, the plate which is set from column B will be referred to as PB, and so on. Since each transfer plate is not set from any stops, but merely receives an amount from the next plate to the right thereof, each transfer plate will be given the reference letter T followed by the number of the group in which it occurs; thus the transfer plate associated with the group of plates PG, PH, PI and PJ, will be given the reference letter T3, since this is the third group of the series (reading from the right of Fig. 4D).

The sliding plates PA to PX are mounted to slide vertically in a frame comprising side plates 661, 662 mounted on cross bars 663 running transversely between the side plates of the main frame of the machine (Figs. 4C, 4D and 47B). Mounted transversely between these plates 661 and 662 are four angle bars 664 having slots which guide the plates PA to PX. In Fig. 20 there is shown in the fraction stop basket 642 the column of stops U which are set to represent the units of shillings partial quotient of $\frac{1}{960}$ of the thousands of pounds digit of the multiplicand.

For each of the plates PA . . . PX there is provided a setting bar SA . . . SX which takes a setting in the manner about to be described from the associated column of stops A . . . X, and sets the associated plate PA . . . PX accordingly.

The setting bar SU for the plate PU appears in Fig. 20 and, like all the other setting bars SA . . . SX is guided in slots in two transverse

bars 665. The setting bar SU is urged to the left by a spring 666 anchored to an angle bar 667 and passing over a pulley 668 mounted in a bracket 669. The other end of the spring is attached to a lug 670 on the bar SU. The spring for the reading bar ST immediately behind the bar SU is shown at 66a and is anchored to a lug 670a projecting downwardly from the bar ST, the other end of the spring being anchored to an angle bar 667a.

A restoring bar 671 which slides in slots 672 in the side plates normally holds the bar SU and the other bars SA . . . SX over to the right (Fig. 20) against the action of their springs such as 15 666.

For each column of stops such as the column U in the fraction stop basket 642 (see Fig. 15) a nought stop 673 is provided which is normally up and clearly if this nought stop 673 is up the 20 setting bars such as SU will be unable to move to the left even though the restoring bar 671 releases them.

When any of the stops in a column such as the column U is raised this movement lowers the corresponding nought stop 673 so that on the movement of the restoring bar 671 to the left, the setting bar SU is free to move to the left under the action of its spring 666 until arrested by a particular stop 641 which has been projected into its 30 path.

In order to cause the descent of the nought stop 673 when one of the value stops 641 is raised each of the latter carries a pin 641a engaging with a cam slot 674 in a slide 675 which is pulled to the 35 right by a spring 676. The nought stop 673 carries a pin 673a engaging a cam slot 677 in the slide 675. When any of the stops 641 is raised its pin 641a by engagement with the cam slot 674 moves the slide 675 to the left and the cam slot 677 by engagement with the pin 673a pulls the nought stop 673 downwards. When the connection wire in the fractions connection box 639 again descends, the spring 676 by pulling the slide 675 back to the right raises the nought stop 673 and lowers the stop 641 which was raised.

After the stops 641 have been set from the card the restoring bar 671 moves to the left and permits all the setting bars SA to SX to move to the left to take a setting from the corresponding 50 columns of stops A to X in the fraction stop basket 642.

The plates PA to PX are normally held in their uppermost position by a restoring bar 680 and after the setting bars SA to SX have been set 55 the restoring bar 680 is lowered thereby permitting the plates PA to PX to descend to varying amounts determined by the settings of the bars SA to SX. The plates are urged downwardly by springs 681 which pass over pulleys 682 mounted in brackets 683 and anchored at the upper end to an angle bar 684.

On each of the plates PA . . . PX is a series of 60 numerical steps 685 formed therein which cooperate with a horizontal lug 686 which is constructed and operates as follows:

The lug 686 projects to the left from a block sliding in a slot 687 in a transverse extensor 688 of the associated setting bar such as SU, the block having a pair of flanges 689 one on either side of the extension 688 to guide its upward and downward movement in the slot 687. Projecting to the right from the block is another lug 690 engaging in a horizontal slot 691 in the next plate to the right.

Considering Figure 21f which shows the group

of plates, PS, PT, PU for the units of shillings denomination with their associated transfer plate T6 which receives the amount to be transferred into the units of shillings denomination from the pence denomination, immediately to the left of the extreme left-hand plate PR in the pence denomination is the transfer slide TS6 which controls the transfer from pence to units of shillings. This slide has a lug 692 projecting to the right and engaging in a stepped slot 694 in the extreme left-hand pence plate PR. This extreme left-hand pence plate receives the sum of the amounts received by all the pence plates O, P, Q and R including the transfer plate T6 which receives the amount transferred from the

pence
10

denomination to the pence denomination. The slot 694 has steps such as 695 and if the movement of the pence plate PR downwardly exceeds 11 units the lowermost step 695 will come below the lug 692 on the transfer slide TS6 and a spring 696 will move the slide TS6 forwardly against the step 695 thus permitting a movement of one unit to the slide TS6.

The slide TS6 has a lug 693 projecting to the left and engaging with steps 697 in the transfer plate T6. When the slide TS6 moves one step forwardly the lug 693 comes below the No. 1 step of the plate T6 thereby permitting the plate T6 to move down one unit.

To the left of the transfer plate T6 is the setting bar SS for the right-hand plate PS in the units of shillings group, and mounted in the slot 687 in the extension 688 of this setting bar SS is the flanged block 689 carrying the projection 690, which, extending to the right, enters a horizontal slot 691 in the plate T6. Accordingly when the plate T6 moves down one step, the lug 690, and the block 689 move down by a like amount. Projecting to the left from the block 689 is the setting lug 686 for the plate PS. Consequently even if the plate PS does not directly receive any amount, the fact that the plate T6 has moved down one step will have brought the lug 686 one step below the lowest step 685 on the plate PS so that the latter will move down one step.

If, however, in addition the setting bar SS is set to the value 1, for example, this will mean that this bar SS will have moved one step to the left in Fig. 21f and will be under the first step 685. Accordingly whatever the downward movement of the lug 686, the plate PS will be enabled to move one step downwardly so that if the lug 686 moves down one step and the bar SS moves forwardly one step, the total movement downwardly of the plate S will be two.

Engaging in the horizontal slot 691 in the plate PS is the lug 690 projecting from the flanged block 689 engaging in the slot 687 in the extension 688 of the setting bar ST for the plate PT, and also projecting from this block 689 is the setting lug 686 for the plate PT. If, therefore, the plate PS has, as in the example already mentioned, moved down two steps, the lug 690 will carry the block 689 associated with bar ST also two steps downwardly, and the corresponding lug 686 will move the plate PT also two steps downwardly. If, for example, the reading bar ST is set to the value 7 the associated lug 686 will move seven steps to the left, bringing it below the seventh step 685 of the plate PT so that the latter

will be able to move downwardly seven further steps, making nine in all.

Engaging in the horizontal slot 691 of the plate PT is the lug 690 projecting from the flanged block 689, engaging with the extension 688 of the setting slide SU for the plate PU. Accordingly the nine steps downward movement of the plate PT will move the block 689 associated with bar SU also nine steps downward. Consequently the lug 686 for the plate PU will have moved nine steps downward, so that the plate PU itself also moves nine steps downwardly.

If now the bar SU is set at 8, then the associated lug 686 will move eight steps to the left, bringing it below the eighth step 685 of the plate PU, so that the latter will be able to move downwardly eight more steps, making seventeen steps in all.

Referring now to Figure 21f it will be seen that plate PU has three steps 695 with which co-operate a lug 692 projecting from the transfer slide TS7 controlling the transfer from units of shillings to tens of shillings.

The length of each of the steps 695 is ten units, so that the plate PU having moved down seventeen steps the second step, that is to say, the middle step 695 will be in register with the lug 692, whereby the slide TS7 will be permitted to move one step to the right under the action of its spring, thereby permitting the transfer plate T7 to move down one unit so that one is transferred to the tens of shillings denomination.

Since the shillings plate PU receives the sum of all the amounts entered into the units of shillings group, this plate is provided with steps 700 for reading off the value in the units of shillings denomination. There are two series of these steps, since the number of shillings may exceed ten, and co-operating with these steps is a lug 701 on a reading bar R6.

There is a reading bar such as R6 for each denominational group of plates PA, PB, PC, and so on, and in the drawings these reading bars are given the reference letter R followed by the number of the corresponding group.

Referring to Fig. 20 all the reading bars, such as R6, are urged to the right by springs 703 which pass over pulleys 704 mounted in an angle bar 705 and are anchored to an angle bar 706. In order normally to hold the reading bars, such as R6, to the left in Fig. 21 a restoring bar 702 is provided which slides in slots 702a in the machine frame plates. After the plates PA . . . PX have been set, the restoring bar 702 moves to the right thereby releasing the reading bars R1 to R9 to the action of their springs 703.

The bars R1 to R9 then move to the right under the action of their springs 703 until arrested by the lug 701 on the bar R6, for example, engaging with one of the series of steps 700 in the associated plate, such as the plate SU, the reading bars, such as R6 being thus set to the amount represented by the position of the plate SU.

At the left-hand end each of the reading bars, such as R6 has a swinging member 721 pivoted thereto at 722, the swinging member being urged downwardly by means of a spring 723. Each swinging member 721 carries an upward projection at its free end 724, which is normally below the nought stop 631 in the associated column of stops in the multiplicand stop basket 621. If, for example, the reading bar R6 moves six steps to the right, the upward projection 724 on the associated swinging member 721 will be under the No. 6 stop in the column of stops 631.

All the swinging members 721 pass through slots 728 in a lifting bar 726, which is carried between arms 727 secured to a shaft 728, and after the reading bars R1 to R9 have been set the arms 727 are raised, whereby the bar 726 lifts all the swinging members 721, whereby the upward projections 724 push upwardly the stops 631 beneath which they have been positioned.

By this means the value of $\frac{1}{660}$ of the multiplicand is set up in the multiplicand stop basket in the columns 631 reserved for the fractional multiplicand.

The mechanism for operating the restoring bars 671, 680, 702 and the shaft 728 will now be described.

The restoring bar 680 slides in vertical slots 729 in the side plates of the frame, and at each end is pivoted to arms 730 secured to a shaft 731. Also secured to this shaft is an arm 732 connected by a link 733 to a lever 734, pivoted to the frame on a spindle 735, and carrying at its other end a roller engaging in a track cam 736 formed in a cam disc 737 secured to the selection shaft 4 (Figs. 1, 10C and 22).

Therefore, as the shaft 4 rotates the restoring bar 680 is first lowered and then raised.

The restoring bar 671 is pivoted at each end to arms 738 secured to a shaft 739, one of these arms being in the form of a bell crank to which is pivoted a link 740 connected at its lower end to a bell crank 741 pivoted to the frame at 742 and connected by a link 743 to a lever 744 pivoted on the spindle 735. At its other end the lever 744 carries a roller engaging in a cam track 744a formed in a cam disc 745 secured to the selection shaft 4.

In order to operate the restoring bar 702, this bar is pivoted at each end to arms 746 secured to a shaft 747 carrying an arm 748 connected by a link 749 to a lever 750 pivoted on the spindle 735. This lever 750 carries a roller engaging in a cam track 751 in the cam disc 745.

The lifting bar 726 for the swinging members 721 is as already explained carried between two arms 727 secured to a shaft 728, and in order to operate this shaft an arm 752 is secured thereto and connected by a link 753 to a lever 754 mounted on a spindle 755. The lever 754 carries a roller which engages with a cam 756 secured to the cam disc 737.

In order to restore the transfer slides TS3 to TS9 a restoring bar 757 is provided carried between two arms 758 secured to a shaft 759 carrying an arm 760 connected by a link 761 to a lever 762 pivoted on the spindle 755. This lever 762 carries a roller which engages with a cam projection 763 on the disc 745.

At the extreme right hand side a plate PY is provided which is fixed and has a slot 691 with which engages the lug 690 projecting from the flanged block 689 associated with the first setting bar SA.

It is unnecessary to provide transfer mechanism between the plates PC and PD since no transfer can occur between the

pence   pence
10,000   1000

denominations, but for manufacturing reasons transfer mechanism is provided although it does not operate as such. This mechanism includes the plate T2 having a slot 691 with which engages the lug 690 associated with the setting bar SD. The plate T2 does not move and can be replaced by a fixed plate such as PY.

Restoration of the transfer slides such as TS3

occurs before restoration of the plates such as PA and if the slide TS6 were made in one piece its movement to the left would be prevented by engagement of the lug 693 with the steps 697 on the plate T6. Accordingly each transfer slide comprises an inner slide Ta, mounted to slide between the turned-over edges Tb of an outer slide Tc, the two slides being connected by a spring Td, while the main actuating spring 696 is connected to the outer slide Tc. The restoring bar 757 acts on a lug Te carried by the outer slide Tc.

With this arrangement, if a transfer slide such as TS6 has operated and its lug 693 is against one of the steps 697 in the associated transfer plate T6, then when the restoring bar 757 moves to the left in Fig. 20 it pushes the outer slide to the left and the spring Td extends, the inner slide Ta being held stationary by the engagement of the steps 697 on plate T6 with the lug 693 which is carried by the inner slide. Then when the plate T6 is restored the lug 693 is released and the spring Td returns the inner slide also.

Mounted adjacent to the multiplicand stop basket 621 is the multiplier stop basket 620 which is similar in construction to the multiplier stop basket 96 described in British specification No. 490,358. Associated with the stops 622 in the multiplier stop basket is a series of multiplier reading bars 110 and associated with the stops in the multiplicand stop basket 621 is a set of reading bars similar to the multiplicand reading bars 111, described in the aforesaid British specification.

Multiplier and multiplicand reading bars

There are eight multiplier reading bars 110a to 110h, while there are thirteen multiplicand reading bars indicated at 111a to 111m (Figs. 4A and 4B). These thirteen multiplicand reading bars correspond respectively to the following denominations:

45   pence   pence   pence
10,000   1000   100   10

pence, units of shillings, tens of shillings, units of pounds, tens of pounds, hundreds of pounds, thousands of pounds, tens of thousands of pounds, and hundreds of thousands of pounds.

It will be noted that the highest denomination in the multiplicand stop basket 621 is thousands of pounds, and the reason for providing the two additional higher denominations as regards the reading bars 111a . . . 111m will become apparent later.

The multiplicand reading bars 111a to 111m are held in their normal position against the action of operating springs 146 by a restoring bar 60 147 (Figs. 3, 4B, 23, 48A and 48B) carried between arms 148, which are secured to a shaft 149. The bar 147 acts on arms 157 pivoted on the shaft 149 and pivoted to the respective bars 111a . . . 111m at 158. Also secured to the shaft 65 149 is a pair of depending arms 150, 150a pivoted at 151, 151a to one arm of a bell crank 152, 152a pivoted respectively to the machine frame at 153, 153a and carrying on their other arms rollers 154, 154a each engaging in a cam track 70 formed in a disc secured to the multiplication shaft 41. These two discs are shown at 156, 156a in Figs. 10A, 10B, 22, 48A and 48B and the cam track in the disc 156 is shown at 155 in Fig. 45A the cam track in the disc 156a being similar.

Each time the multiplication shaft 41 rotates the cams 158, 158a rock the bell cranks 152, 152a first counterclockwise and then clockwise (in Fig. 3) whereby the shaft 149 is rocked first clockwise and then counterclockwise. When the shaft 149 rocks clockwise the restoring bar 147 is moved away from a series of arms 157 (Figs. 4, 23 and 47B) each of which is pivoted at 158 to a corresponding multiplicand reading bar 111, 111a . . . , the arms 157 being freely mounted on the shaft 149. When the restoring bar 147 thus moves away from the arms 157 the springs 148 pull the multiplicand reading bars 111, 111a . . . , to the right in Fig. 4 until they are arrested by stops in the corresponding columns of the multiplicand stop basket 621. The multiplier reading bars 110a to 110h, are likewise pivoted at 158 to corresponding arms 160 freely mounted on the shaft 149. Fixed on the shaft 149 is a pair of arms 161, 161a carrying between them a main restoring bar 162 (Figs. 3 and 23). The operation of this restoring bar is described in British specification No. 490,358.

Cooperating with the bar 162 is an auxiliary restoring bar 163 carried between two arms 164, 164a free on the shaft 149.

Pivoted to each arm 160 at 165 is a latch 166 of which the tail 167 rests against a fixed bar 168 when the arms 160 are fully restored, whereby the latch 166 is held clear of the restoring bar 163 against the action of a spring 169 (Figs. 46B and 24).

As the shaft 149 rotates clockwise the restoring bar 162 is moved away from the arms 164, 164a and actuating springs 170 for the multiplier reading bars 110 pull the latter to the right (Figs. 46B and 24) until they engage with stops 622 in the respective columns of the multiplier stop basket 620. The multiplier reading bars 110 are normally in a position such that in order to engage the nought stop in the respective column the bar has to move through one unit of movement. This one unit of movement brings the corresponding arm 160 sufficiently far away from the fixed bar 168 to permit the latch 166 to engage over the auxiliary restoring bar 163. By this means the restoring bar 163 is positively locked to the arm 160.

As described in the aforesaid British specification the multiplier reading bars are normally held against the action of their operating springs 170 by the main restoring bar 162 and are permitted to move up to the stops of the multiplier stop basket 620 one bar at a time, an escapement device being provided which retains all the bars except one in their normal position, then on the next cycle moves to release the next higher denominational bar while retaining all the remaining bars.

In addition the escapement mechanism is arranged to permit the multiplication shaft 41 to perform as many cycles as there are digits in the multiplier, after which the multiplication shaft is de-clutched and the selection and punch control shaft 4 and 5 are clutched to the main shaft 1 and caused to make one revolution.

The construction of the escapement mechanism in so far as it differs from that described in British specification No. 490,358 will be explained later.

Partial product plates

Disposed below the multiplicand reading bars 111a to 111m is a series of partial product plates which run in planes parallel to those of the multiplicand reading bars. There are ten of these 75

partial product plates indicated at 0P, 1P, 2P and so on, up to 9P, there being thus one partial product plate for each multiplier digit (see Fig. 25).

Each plate has two groups of partial product steps formed thereon (Fig. 26), one group representing the decimal numbers 0 to 9 multiplied by the digital value of the plate, while the other group represents 0 to 11 pence, multiplied by the digital value of the plate. The decimal group thus has ten pairs of steps, while the pence group has twelve pairs of steps. These steps are so arranged that the units step of each pair is to the left of the tens step of the pair, as viewed in Fig. 26.

These partial product plates 0P to 9P are guided in slots formed in horizontal plates 770 and 771, secured at their edges to two side frame plates 772, 773. These plates 772 and 773 are connected by brackets 774, 775 to angle bars 776 and 777 running along the main side plates of the machine frame (Figs. 25, 48A and 48B).

Mounted transversely above the partial product plates 0P to 9P is a series of pairs of horizontal transmission bars 778, (Figs. 4A, 25, 26, 48A and 48B), there being one pair for each pair of steps on the partial product plates, i. e. 22 pairs. At each end each transmission bar has a portion 779 extending upwardly and downwardly so that each element 778, 779, is somewhat in the form of the letter H.

The guide members 779 run in slots formed in the horizontal plate 770 and in slots formed in transverse bars 780.

Associated with each of the multiplicand reading bars 111a to 111f are two transverse bars 139 but the tens of shillings bar 111g has only one transverse bar 139. Of the remaining multiplicand reading bars, the bars 111h to 111l have two bars 139 whilst the highest denominational reading bar 111m has only one bar 139.

Each transverse bar 139 (Fig. 26) projects from a vertical slide 140 of which the lower end passes through a slot in the plate 770, the left hand edge of the slide 140 being guided in a vertical slot in a plate 141 running between the side plates 772 and 773. At its other end the transverse bar 139 is guided in a slot 139c in a plate 781a mounted between the plates 772 and 773.

Each transverse bar 139 carries a rider 139a slidably mounted thereon and from this rider projects a depending finger such as the finger F12 shown in Fig. 26.

The finger F1 which depends from the rider 139a carried by the transverse bar 139 immediately to the left of the lowest denominational multiplicand reading bar 111a (in Fig. 25) passes down through a slot in a saddle 138 carried by the bar 111a. The finger F2 which descends from the rider carried by the second bar 139, passes downwardly through a slot in the same saddle 138, i. e. the saddle carried by the bar 111a, but on the opposite side of the said bar from the finger F1. In like manner the fingers F3 and F4 are suspended from two bars 139, one on either side of the multiplicand reading bar 111b and so on until the units of shillings bar 111f is reached. This bar has a saddle 138 through which pass two depending fingers F11 and F12 carried by the bars 139 to either side of the bar 111f. Then

for the tens of shillings bar 111g there is only one depending finger F13 passing through a saddle 138 carried by the bar 111g, the finger depending from a rider 139a carried by the associated single bar 139. The two bars 139 associated with the units of pounds reading bar 111h each carry a

depending finger F14 and F15 respectively, these two fingers passing through a saddle 138 carried by the bar 111h. Likewise, the higher denominational reading bars, 111i, 111j, 111k and 111l each have two fingers, F16, F17; F18, F19; F20, F21; and F22, F23 respectively. The highest denominational bar 111m has only one finger F24.

For the reason explained in British specification No. 490,358 with reference to the similar fingers 130, 130a, 131, 131a, 132, 132a, 133, 134, 134a, 135, 135a, 136, 136a, and 137 shown in Fig. 10 of British specification No. 490,358 the fingers F1, F3, F5, F7, F9, F11, F13, F16, F18, F22, and F24 are made longer than the remaining fingers.

The two depending fingers F11 and F12 associated with the units of shillings bar 111f are shown in Fig. 26, from which it can be seen that the finger F11 is positioned over the extreme left-hand transmission bar 178 while the finger F12 which is shorter than the finger F11 is over the second transmission bar 178 from the left. This however, is not the position of rest of the machine. In the rest position the multiplicand reading bars 111a . . . 111m are held by their restoring bar 147 one stop pitch behind the zero stops in the respective columns of stops 632 in the basket 621. In this normal position the finger F12 would be disposed to the left of the extreme left-hand bar 178 to the extent of the pitch of the bars 178 and the finger F11 would be disposed to the left of the extreme left-hand bar 178 to the extent of twice the pitch of the bars 178. In Fig. 26 the reading bars 111a . . . 111m are shown in the zero position, i. e. against the zero stops 632 and in this position the fingers F11 and F12 occupy the positions shown in Fig. 26.

When the multiplicand reading bar 111f is set at nought its pair of fingers F11 and F12 are over the two transmission bars 178 which themselves are over the two steps on the plate 3P representing the partial products of 0 multiplied by 3, that is to say, 0 and 0.

If the bar 111f is set at four, the fingers F11 and F12 will be carried along to the right (Fig. 3) until they are over the 9th and 10th transmission bars 178 from the left. These bars in turn are over the 9th and 10th steps from the left of plate 3P. The 9th step represents the units digit 2 of the product $3 \times 4 = 12$, while the 10th step represents the tens digit 1.

Then when the plate 3P is raised in the manner to be described later the 9th step thereon will raise the 9th transmission bar and move the longer depending finger F11 to an extent representing two shillings, plus one additional unit, two shillings being the units of shillings component of the product of $4/- \times 3 = 12/-$. Likewise the tenth step will raise the tenth transmission bar 178 by one unit and through it will raise the shorter finger F12 by one unit representing one unit in the ten shillings denomination, this being the tens of shillings component of the partial product of $4/- \times 3 = 12/-$.

The partial product plates 0P to 9P are selected for operation in the manner described in British specification No. 490,358, each plate having a pawl 210a associated with a latch 211 adapted to be released by the corresponding one of a series of ten cams 214 on a shaft 217 controlled by the multiplier reading bars 110a . . .

In the present machine there is only one group of cams 214 since there is only one group of plates 0P to 9P.

The selected one of the plates 0P to 9P is raised by a lifting bail 213 operated as described in

British specification No. 490,358 by a cam 233 on the shaft 41 (Figs. 22 and 46A).

Partial product accumulator

5 Pivoted at 209 (Fig. 24) to the side of each partial product plate 0P—9P is a pawl of which one part 210a depends along the side of the respective partial product plate, the pawl being normally held in this position by a latch 211 10 pivoted to the machine frame at 211a. Each latch 211 is normally held against a stop bar 212 in position to engage the nose 210b of the pawl by a spring 211b. In order to select a particular plate the latch is released whereupon a spring 210c rocks the pawl and causes its depending portion 210a to project beyond the edge of a slot 213a in the partial product plate into the path of a bail 213 (Figs. 3 and 29) which is mounted to reciprocate vertically. After a selection has been made, the part 210a of the pawl of the selected product plate will be projecting into the path of the bail 213, so that when the latter is raised the plate in question is also raised.

As already mentioned there is a latch 211 associated with each of the partial product plates. 25 In order to release the latches a group of selecting cams is provided there being ten selecting cams 214 in the group. All these cams are secured to a transverse shaft 217 mounted in the 30 side plates 772, 773, between which the multiplying and associated mechanisms are housed (Fig. 23). The operative portion of each of the cams in one of these groups occupies one-eleventh of a complete circle and the cams are staggered round the shaft 217, the angular displacement of one cam relatively to the next being equal to one unit. On each of the latches 211 there is a nose 218 which is disposed to cooperate with the corresponding cam 214, 215 or 216. It will be seen 40 that in the normal position of the cams there is a gap indicated at 219 adjacent to the nose 218.

Going round the shaft 217 in a clockwise direction in Fig. 24 the first cam is that representing the multiplier digit nought and cooperates with the nought partial product plate 0P. The next cam corresponds to the multiplier digit 1 which cooperates with the nose 218 of the latch 211 associated with the 1 partial product plate 1P and so on round the shaft, the last cam corresponding to the multiplier digit 9 and cooperating with the nose 218 of the latch 211 associated with the 9 partial product plate 9P.

55 It has already been explained that the multiplier reading bars 110 taking a setting from the corresponding denominational stops 622 in turn, beginning with the units bar 110. By means of the mechanism about to be described, when the units bar 110 takes a setting from its stops it 60 positions the corresponding cam 214 to operate the latch 211 of the partial product plate which corresponds to the units multiplier digit. On the next revolution of the shaft 41 the tens reading bar 110 will take a setting and will position the 65 cams to release the latch of the partial product plate corresponding to the tens digit of the multiplier.

In order to position the cams 214, 215 and 216 the shaft 217 is provided with a pinion 220 fixed thereto and this pinion engages with a rack 221 having a slot 222 engaging a pin 223 carried on an upward extension 224 formed integral with an arm 225 freely mounted on the shaft 217. The other end of the rack 221 is pivoted at 226 to the lower end of an arm 164b forming a downward

extension of one of the arms 184a between which is carried the restoring bar 163 for the multiplier reading bars 110. The pin 228 also slides in a slot 227 formed in an extension 228 of one of the side plates 772. When a reading bar 110 moves forward and takes a setting from the corresponding denominational column of stops 98 the restoring bar 163 moves with it whereby the arm 184b is moved clockwise (Fig. 24) and pushes the rack 211 to the left thereby rotating the shaft 217 counterclockwise by means of the pinion 220.

Assuming for example that a reading bar 110 is moved forward to the 4 stop the shaft 217 will be turned until the 4 cam overlies the nose 218 of the latch 211 associated with the 4 partial product plate. As the shaft 41 rotates a cam track 229 formed in a disc 230 secured thereto rocks an arm 231 which is secured to a shaft 232 to which is also secured the arm 225 already mentioned together with another arm 225a (Fig. 23) the shaft 217 being freely mounted between these arms. The rocking of the shaft 232 moves the arms 225, 225a counterclockwise (Fig. 24) about the axis of the shaft 232 whereby the shaft 217 with the cams is moved bodily downwards and the particular cam which has been positioned over the nose 218 of its associated latch 211 will, by acting on the nose 218, rock the latch 211 clockwise thereby releasing the corresponding pawl 210b so that the portion 210a of this pawl will project beyond the edge of the slot in the corresponding partial product plate into the path of the bail 213. The bail 213 is then raised by a cam 233 constituted by a track formed in the disc 230 (Figs. 29, 46A and 48A).

With this cam 233 there engages a roll 235 on the arm 236 of a bell crank pivoted to the machine frame at 237 and of which the other arm 238 constitutes a segment having teeth 239 which engage with a pinion 240 secured to a shaft 241 mounted between the side plates 772, 773. Also secured to the shaft 241 is an arm 242 (Fig. 46A) pivoted at 243 to a link 244 which is in turn pivoted to the bail 213. It may be pointed out that there is an arm 242 and a link 244 at each end of the shaft 241 so that the bail 213 is operated from both ends (see Figs. 25, 48A and 48B).

As the cam 233 rotates the bell crank 236, 238 is rocked clockwise whereby the shaft 241 is rocked counterclockwise and the arms 242 and links 244 raise the bail 213, the latter being mounted to slide in slots 245 (Fig. 46B) in the side plates 772, 773. In thus rising the bail 213 will engage the portion 210a of the pawl 210b which has been released by the latch 211 since the portion 210a of this latch will project beyond the edge of the slot in its respective partial product plate into the path of the bail, consequently the bail will lift the corresponding partial product plate, whereby the transmission bars already described will be lifted and also the setting fingers F1, F2 . . . , which have been positioned by the multiplicand reading bars 111, 111a . . . , in accordance with the digits of the multiplicand.

Partial product accumulator

When any depending finger, such as F12 is raised, the associated horizontal bar 139 is also raised. Projecting from the vertical guide member 140 associated with each horizontal bar 139 is a lower arm 143 and an upper shorter arm 144 forming between them a slot in which runs as roller 145 carried by a setting rod SR1 . . . SR24 such as the setting rod 1630 shown in Fig. 11 of British specification No. 490,358. The function

of the rods SR1 . . . SR24 is to transmit into a partial product accumulator indicated at PPA (Figs. 3, 25, 48A and 48B), the partial products read from the steps of the different partial product plates 0P to 9P. The partial product accumulator plates are indicated at RP1, RP2 . . . RP24 in Fig. 25 and are arranged in a similar manner to those described in British specification No. 465,517 or 490,358 and in the present drawings 10 the plate RP1 receives the

10,000 pence

component of a multiple of

10,000 pence

The plate RP2 receives the

1000 pence

component of a multiple of

10,000 pence

The plate RP3 receives the

1000 pence

component of a multiple of

1000 pence

The plate RP4 receives the

100 pence

component of a multiple of

1000 pence

Plate RP5 receives the

100 pence

component of a multiple of

100 pence

component of a multiple of

10 pence

component of a multiple of

100 pence

The plate RP7 receives the

10 pence

component of a multiple of

10 pence

The plate RP8 receives the pence component of a multiple of

10 pence

The plate RP8 receives the pence component of a multiple of pence. The plate RP10 receives the units of shillings component of a multiple of pence. The plate RP11 receives the units of shillings component of a multiple of units of shillings.

The plate RP12 receives the tens of shillings component of a multiple of units of shillings. The plate RP13 receives the tens of shillings component of a multiple of tens of shillings. The plate RP14 receives the units of pounds component of a multiple of units of pounds. The plate RP15 receives the tens of pounds component of a multiple of units of pounds. The plate RP16 receives the tens of pounds component of a multiple of tens of pounds. The plate RP17 receives the hundreds of pounds component of a multiple of tens of pounds. The plate RP18 receives the hundreds of pounds component of a multiple of hundreds of pounds. The plate RP19 receives the thousands component of a multiple of hundreds of pounds. The plate RP20 receives the £1000 component of a multiple of £1000. The plate RP21 receives the £10,000 component of a multiple of £1000. The plate RP22 receives the £10,000 component of a multiple of £10,000. The plate RP23 receives the £100,000 component of a multiple of £10,000, and the plate RP24 receives the £100,000 component of a multiple of £100,000.

There are thus thirteen denominational groups of plates RP1 to RP24 and between each group, except between the first and second group and the second and third group from the left a transfer plate is provided. These transfer plates are indicated at RC3, RC4 and so on up to RC13. The operation of these plates will now be described with reference to Figs. 27 and 27a.

The plate RP9 receives the pence component of a multiple of pence and is set by the upward movement of the setting rod SR9 which is lifted by the associated transmission bar 178, through one of the longer fingers, namely finger F9, and accordingly, if the partial product digit to be transmitted by the rod SR9 is six, the rod SR9 will be moved up six plus one—seven steps. Then when the plate RP9 is released by the action of its spring 190, as will be explained later, the plate RP9 will move to the left (Fig. 27) six plus one—seven steps. To this end the rod SR9 carries a lug 191 co-operating with numerical steps 192 on the plate RP9. In this connection it may be pointed out that for the reason explained in British specification No. 465,517 one plate such as RP9 in each group, must move one step more than the actual value which is received. The plate RP9 may have received from the plate RP8 a further amount which makes the total movement of the plate RP9 exceed eleven steps in which case one shilling will have to be transferred to the next group of plates. To this end the plate RP9 is provided with a slot 193 in which engages a pin 193a on a transverse slide TR6 which is urged upwardly by a spring 193b, the transverse slide TR6 being mounted to slide vertically in the frame within which the plates are mounted.

Projecting from this slide TR6 is a lug 194 which engages with a step 195 on the transfer plate RC6 which receives the amount to be transferred from the pence group to the units of shillings group.

If the pence plate RP9 moves to the left to an extent greater than eleven pence, then the right-hand end of the slot 193 will have passed beyond the lug 193a whereby the spring 193b will be enabled to lift the transverse slide TR6 upwardly to the extent of one step, thereby bringing the lug 194 above the step 195 so that the spring 190 of the plate RC6 can move the latter to the left one step.

In the manner described in British specification No. 465,517 the setting rod SR10 for the plate RP10 is carried on the transfer plate RC6. When the plate RC6 moves one step to the left, therefore, the lug 196 on the setting rod SR10 moves one step to the left also and carries with it the plate RP10 one step to the left. The setting rod SR10 is controlled by one of the shorter fingers, namely the finger F10, and consequently, if the partial product digit to be transmitted by the rod SR10 is seven, the rod SR10 will be moved up seven steps, and the lug 196 carried thereby will move up seven steps and will register with the seventh step 197 on the plate RP10, thereby permitting the latter to move seven steps to the left, making eight steps in all.

The setting rod SR11 for the plate RP11 is likewise carried by the plate RP10, so that the plate RP10 having moved eight steps to the left, the rod SR11 will also have moved eight steps to the left and will have carried with it the lug 198, whereby the plate RP11 will have moved eight steps to the left. The rod SR11 is controlled by one of the longer fingers, namely the finger F11 and consequently if the partial product digit to be transmitted by the rod SR11 is six, the rod SR11 will move up six plus one—seven steps, and the lug 198 will be opposite the seventh step 199 on the plate RP11, so that the latter will be able to move seven steps further to the left, making fifteen steps in all, that is to say, the plate RP11 will have moved an amount representing the total number of shillings entered into the units of shillings group of plates plus the one additional unit already referred to.

Similarly in each denominational group of plates RP1 . . . RP24 one plate moves an amount representing the total number of units arising in that denomination plus one unit. The plates which move in this way are RP1, RP3, RP5, RP7, RP9, RP11, RP13, RP14, RP16, RP18, RP20, RP22, and RP24.

Referring again to the plate RP11, in order to read therefrom the whole amount in shillings entered into the units of shillings group of plates, the plate RP11 is provided with two series of steps 800 and 800a, similar to the steps 684 described in British specification No. 490,358. Associated with these steps is a reading element 801 similar to the reading element 653 described in the aforesaid prior specification and at the appropriate time in the cycle the elements 801 are permitted to descend to take a reading from the plate, such as RP11.

The series of steps 800 and 800a are provided in the plate RP11 because the total amount of units of shillings may exceed nine. The reading element 801 carries a lug 801a to cooperate with the steps 800 and 800a and terminates at its lower end in a rack 270 which, as explained below, serves to transmit the units of shillings digit of the partial product to a units of shillings accumulator wheel. Similarly each of the plates RP1, RP3, RP5 . . . referred to above has a reading element 801 carrying a lug 801a cooperating with steps such as 800, 800a, in the corresponding plate, and terminating in an accumulator wheel actuating rack 270.

As explained in British specification No. 465-517 the member 801—270 (members 649 in British specification No. 465,517) are used to restore the accumulator wheels to zero and accordingly the lugs 801a are normally located at the top of a slot 801b in the respective plate (e. g. RP11) to permit the downward movement of the members

881-278 in restoring the accumulator. The lug 881a is consequently one step behind the zero step of its plate (e. g. RP11) and it is for this reason that each of the plates such as RP11 must move one step or unit of movement in addition to the true amount registered thereby. The tens of shillings plate RP13 is provided with a series of steps 882, these steps being arranged to represent 0 and 1 alternately in the manner of the steps 887 described in British specification No. 490,358. The plate RP13 also has a slot 793x at its right-hand end having steps 793y. Cooperating with these steps is a lug 885 similar to the correspondingly numbered lug in British specification No. 490,358, this lug projecting from the transfer slide TR8 and passing through a slot 1001 in a plate 1000. Projecting from the other side of slide TR8 is a pin 883 engaging in a slot 883a in the units of pounds plate RP14.

If the amount received by the tens of shillings plate RP13 is, for example, seven, that is to say seventy shillings, then three pounds will have to be transferred to the units of pounds denomination and the lug 885 will be on the third step from the left of the steps 793y. Accordingly the slide TR8 will be able to rise to the extent of three units and the pin 883 by acting on the inclined slot 883a will force the plate RP14 to the left to the extent of three units.

The plate 1000 operates in the same manner as the plate 1000 described in British specification No. 490,358.

From the foregoing it will be seen that certain of the setting rods, such as SR11 and SR12, have to move bodily with the plates RP10 and RC7 on which they are carried and it is in order to permit this movement that the lower end of the rods SR11, SR12 are connected by the rollers 145 in the slot formed between the elements 144 and 143 as shown in Figure 26.

The plates RP1 . . . RP24 are under the control of a restoring bar 260 which as described in British specification No. 490,358, is operated by a cam track 261 in the cam disc 156 on the shaft 41.

With the cam track 261 there engages a lever 264 pivoted between its ends to the machine frame at 265 and connected at its upper end by a link 266 to an arm 267 on a transverse shaft 268. The restoring bar 260 is pivotally mounted between the upper ends of the two arms 269, secured to the shaft 268, only one of these arms being shown in Figs. 1 and 2. (See also Figs. 48A and 48B.)

The transfer slides TR3 . . . TR13 are restored by a restoring bar 990 carried between arms 991 (Fig. 28) on a shaft 992 operated through an arm 993 connected by a link 994 to a lever 995, pivoted to the frame at 996 and connected by a link 997 to the arm 102 which as described in British specification No. 490,358, is operated by the cam 185 on shaft 41 (Figs. 1, 22, 48A and 48B).

Result accumulator

After multiplication has been effected by one digit of the multiplier, and the partial products thereof set up in the plates RP1 to RP24, of the partial product accumulator PPA, the sum of these partial products is entered into a result accumulator comprising accumulator wheels 291. This result accumulator is the same as the accumulator illustrated in Figures 15, 24 and 25 of British specification No. 490,358 and operates in the same manner, the reading elements 801 terminating at their lower ends in racks 270 which

set the accumulator wheels 291. If the multiplier is a whole number then at the end of the first multiplying cycle the accumulator wheels 291 contain the product of the multiplicand multiplied by the first multiplier digit.

After the control racks 270 have been set from final product plates, accumulator wheels 291 (Fig. 31) are swung into engagement with the racks 270 and the latter are moved upwardly to zero position whereby the amount to which they had been set is transferred to the accumulator wheels. This upward movement of the racks 270 is effected by the restoring bar 272 under the control of the cam 274. After the amount on the racks has been transferred to the accumulator wheels the latter are swung away out of engagement with the racks.

If the multiplier comprises a whole number and a fraction then at the end of the first multiplying cycle the wheels 291 contain the product of the fractional multiplicand multiplied by the lowest denominational digit of the numerator of the fraction expressed with 960 as the denominator.

As described in British specification No. 490,358 the accumulator wheels 291 (Figs. 3, 4 and 31) are freely mounted on a shaft 292 (Fig. 31) carried between a pair of blocks 293 mounted to slide between pairs of guides 294, 294a fixed to the frame of the machine. Pivoted to the blocks 293 by pins 295 projecting through holes 296 in the side plates of the frame are two arms 297 secured to a transverse shaft 298. In order to rock the accumulator wheels into engagement with the control racks 270 the shaft 298 is rocked clockwise (Fig. 31). To this end the shaft 298 carries an arm 299 (Figs. 1 and 48A) pivoted to a link 300 having a slot 301 engaging with a pin 302 fixed to the side plate of the frame. The lower end of the link 300 carries a roll 303 engaging with a cam 304 (Figs. 1, 22 and 48A) on the multiplication shaft 41. When the multiplication shaft rotates, the cam 304 pushes the link 300 upwardly thereby rocking the shaft 298 counterclockwise in Fig. 1 and clockwise in Fig. 31 and bringing the accumulator wheels into engagement with the control racks 270 after the latter have been set. After the control racks have been zeroised, thereby transmitting their setting to the accumulator wheels, the cam 304 permits the lever 300 to descend under the action of a spring whereby the shaft 298 is rocked counterclockwise and the accumulator wheels are disengaged.

The amount thus transmitted to the accumulator wheels is the product of one multiplier digit multiplied by the multiplicand and during the subsequent cycles of the machine multiplication will be effected by the other multiplier digits and the product resulting from these subsequent multiplications will be added to the product already standing in the accumulator wheels whereby the complete product of the entire multiplicand multiplied by the entire multiplier is stored in the accumulator wheels.

It will therefore be seen that provision must be made for effecting a transfer or carry-over from one denomination to the next within the accumulator. In the construction now being described each accumulator wheel dealing with the decimal amounts has 20 teeth and two transfer pawls located at 10 tooth spaces apart. The pence wheel has 24 teeth with two transfer teeth, that is to say each wheel has twice as many teeth as there are units in the denomination concerned. This arrangement is for constructional reasons only.

In order to explain the transfer mechanism the case of a decimal wheel will be considered in which the transfer occurs when passing from 9-0. The operation of the transfer mechanism in the pence denomination is similar except that transfer occurs when passing from 11-0.

When a decimal wheel passes from 9-0 one or other of the transfer teeth 307a strikes the nose of a transfer pawl 307 (Fig. 31) pivoted on a transverse rod 309 carried between the sliding blocks 293. This pawl rests against a lever 310 pivoted on a transverse rod 311 mounted between the fixed side plates of the accumulator mechanism and resting at its free end against an inclined surface of an arm 312 carrying a stud 313 bearing against a latch 314 which normally rests on top of a fixed abutment 315, being held in position by a spring 316.

A spring 317 secured to a tail 318 of the arm 312 which is pivoted on a fixed rod 319 tends to rock the arm 312 clockwise, this movement being prevented by the lever 310. When the pawl 307 is rocked by the transfer tooth 307a it rocks the lever 310 clockwise whereby the lever 312 is rocked counterclockwise and the stud 313 rocks the latch 314 counterclockwise about a pivot 320 whereby the latch is connected to a transfer segment 321 associated with the wheel 291 of next higher denomination. The segments 321 are freely mounted about a fixed shaft 322 and the accumulator wheels are so arranged that they are normally out of engagement with the control racks 270 and in engagement with the teeth of the associated transfer segments 321. In this connection it will be understood that there is no transfer segment 321 for the lowest denominational wheel. The release of the latches 314 takes place while the wheels 291 are in engagement with the control racks 270 and therefore out of engagement with the transfer segments 321. Accordingly when any latch 314 is released the corresponding segment 321 is free to rock about its pivot 322 and is so rocked in a counterclockwise direction by a spring 323. When the segment 321 is thus rocked the lower end of the latch moves down into engagement with the surface 315a of the abutment 315 and limits the rocking movement of the segment to the extent of one tooth pitch.

It may here be explained that when any decimal wheel passes from 9-0 the segment 321, which is thereby rocked, is the segment associated with the wheel of next higher denomination.

Each segment 321 is provided with an upstanding tail 324 which cooperates with a restoring bar 325 carried between two arms 326 secured to a shaft 327 (Figs. 1 and 31).

Normally the accumulator wheels 291 are in mesh with the transfer segments 321 and the bail 325 is in the position shown in Fig. 31.

After the racks 270 have been set the bail is swung to the right in Fig. 31 until it is almost touching the tails 324 of the transfer segments. Then the accumulator wheels 291 are moved into engagement with the racks 270 and the latter are returned to their normal positions whereby the wheels 291 are rotated. Any decimal wheel 291 which passes from 9 to 0 will activate its transfer pawl 307 whereby the latch 314 associated with the transfer segment 321 in the next higher denomination will be swung to the right clear of the upper edge of the abutment 315. At this time the transfer segment is supported by the bail 325 which is in position to

arrest the tail 324 of the transfer segment after a very slight movement thereof.

The accumulator wheels 291 are then moved into engagement with the transfer segments 321 after which the bail 325 moves back to the position shown in Fig. 31 thereby releasing the transfer segments. Those transfer segments whose latches 314 have been moved clear of the abutments 315 will be pulled down by their springs 323 whereby the associated wheels 291 will be turned one tooth.

The wheels 291 are then moved out of engagement with the transfer segments and the latter are raised again by the bail 325 which moves to the right to its fullest extent. When the segments are thus raised the corresponding latches 314 are moved into engagement with the upper edge of the abutment 315 by their springs 316, whereby the segments are held in the position shown in Fig. 31.

The bail 325 then rocks back to the normal position shown in Fig. 31. In order to operate the bail 325 the shaft 327 is provided with an arm 328 (Fig. 1) to which is connected an operating link 329 having a slot 330 engaging with a pin 331 fixed to the machine frame. At its lower end the link 329 carries a roller 332 engaging with a cam 333 secured to the multiplication shaft 41 (Figs. 1 and 48A). This cam is shown in Fig. 32 in which the roller 332 is illustrated in the position which it normally occupies in relation to the cam when the machine is stationary. At this time the roller 332 is on a low portion of the cam which is concentric with the shaft 41 and indicated at 333a. As the shaft rotates the roller is pushed up by the higher portion 333b of the cam whereby the restoring bar 325 is brought almost into engagement with the tails 324 of the segments 321. Then the roller engages the low portion 333c whereby the bail 325 is moved back to the position shown in Fig. 31 and finally the part 333d of the cam which is higher than parts 333a and 333b moves the bail 325 to the right in Fig. 31 to the fullest extent thereby restoring the segments 321.

The amount thus transmitted to the accumulator wheels is the product of the lowest denominational multiplier digit multiplied by the multiplicand, and during the subsequent cycles 50 of the machine, multiplication will be effected by the other multiplier digits and the product resulting from these subsequent multiplications will be added to the product already standing in the accumulator wheels 291, whereby the complete product of the entire multiplicand multiplied by the entire multiplier is stored in the accumulator wheels 291.

Mechanism for multiplying the multiplicand by ten

In order to effect multiplication by the next higher denominational digit of the multiplier, it is necessary to multiply the multiplicand by ten and in a machine in which the multiplicand is expressed in the decimal system, this multiplication by ten is usually effected by shifting the elements in which the multiplicand is set up one place to the left.

Since, however, in the present machine the multiplicand is a sterling amount it is not possible to multiply by ten by shifting the multiplicand stop basket 621 one place to the left, and accordingly means are provided for erasing the setting of the multiplicand stops made from the card and replacing this setting by a new set-

ting representing the tens multiple of the original setting.

The construction of this mechanism is similar to that described in British Patent specification No. 440,180, the sliding setting changing plates thereof being positioned by control rods actuated through gearing from the corresponding denominational multiplicand reading bars 111a to 111m.

The setting changing plates for the

pence
10

pence, units of shillings, tens of shillings and units of pounds denominations are illustrated diagrammatically in Figures 33 and 33a, in which the first plate TM3 to the right is that for the

pence
10

denomination, and is provided with a setting rod 335c.

In the machine to the right of the plate TM3 are two further plates which are for the

pence
100

and

pence
1000

denominations. These two plates are the same as the plate TM3 and operate in the same manner.

It will be understood that in the tens multiple mechanism no plate such as TM3 is required for the

pence
10,000

denomination, since that is the lowest denomination in the multiplicand stop basket 621 and when multiplied by ten gives a result which has a digit only in the

pence
1000

denomination.

Each of the setting rods, such as 335c is positioned from the corresponding denominational multiplicand reading bar, such as 111c by means of a gear wheel 800 freely mounted on a shaft 801 and secured to another gear wheel 802 which engages with rack teeth on the lower end of the corresponding denominational setting rod, such as 335c.

In Figure 33 the plate TM8 appears together with its setting rod 335f and the gearing connecting that setting rod to the multiplicand reading bar 111f in the units of shillings denomination.

Considering Figures 33 and 33a, when the

pence
100

multiplicand reading bar 111c takes a setting from either the fraction stops 631 or the whole multiplicand stops 632, the corresponding tens multiple setting rod 335c is raised to represent the digit read from the multiplicand stop basket. For example, if this digit is six the rod 335c will be raised to an extent representing six and a lug 903 thereon will be positioned opposite the sixth step of a series of steps 904 on the plate TM3. The plate TM3 is then allowed to move to the left in Figure 33, whereby it is permitted to move to the extent of six steps before it is arrested by engagement of the lug 903 with the sixth step 904. It will be observed that the plate TM3 is positioned to the value of the same digit as that read from the multiplicand stop basket, but since

the plate TM3 is in a denomination which is one higher than the denomination of the column of stops from which the value was read, the setting of the plate TM3 represents the tens multiple of the amount read by the multiplicand reading bar 111c.

In the pence denomination there are two plates TM4 and TM5, the plate TM5 is set by the rod 335e, which is operated by the pence multiplicand reading bar 111e.

It will be understood that the reason for providing two plates in the pence denomination is that in that denomination there can be a component received from the tens multiple of the

pence
10

digit of the multiplicand and also a component received from the tens multiple of the pence digit of the multiplicand.

In order to add these components together a pawl 905 is pivoted on a pin 906 projecting from the plate TM5 and cooperates with steps 907 on the plate TM4, this pawl 905 having a pin 908 engaging in a slot 909 in an extension 910 of the setting rod 335d, which is operated by the

pence
10

bar 111d.

The tens multiples of one penny to elevenpence are as follows:

1d. $\times 10 =$	10d.
2d. $\times 10 =$	1s. 8d.
3d. $\times 10 =$	2s. 6d.
4d. $\times 10 =$	3s. 4d.
5d. $\times 10 =$	4s. 2d.
6d. $\times 10 =$	5s. 0d.
7d. $\times 10 =$	5s. 10d.
8d. $\times 10 =$	6s. 8d.
9d. $\times 10 =$	7s. 6d.
10d. $\times 10 =$	8s. 4d.
11d. $\times 10 =$	9s. 2d.

Accordingly the pence plate TM5 has two sets of steps 911 and 912, the former representing the value 0d. 2d. 4d. 6d. 8d. and 10d. and the latter representing the values 2d. 4d. 6d. 8d. and 10d. These steps co-operate with a lug 913 on the rod 335e, for setting the plate TM5 which receives the pence component of the tens multiple of a pence multiplicand digit, and means are provided as will be explained later, for entering into the units of shillings denomination the units of shillings component of the tens multiple of a pence multiplicand digit.

In order to enter the units of shillings component of a tens multiple of a pence multiplicand digit the setting rod 335e is provided with another lug 914 co-operating with steps 915 on a plate TM6. It will be noticed that the step 915a is twice the height of the remaining steps, the reason for this is that in two consecutive positions of the rod 335e the value to which the plate TM6 is to be set is 5/-(10 times 6d.=5/- and 10 times 7d.=5/10d.).

If the pence multiplicand digit is for example, 9d. the rod 335e will rise to the extent of 9 units and the lug 913 will rise to the 9th step on plate TM5, which is the third step of the series 912, and represents 6d. Therefore, the plate TM5 when permitted to move to the left will be set to six.

If the value in the

pence
10

denomination is 8, i. e. 0.8d. then the rod 335d will rise 8 units and will lift the pin 908 and the pawl 905 to a corresponding extent so that the pawl 905 will come into register with the eighth step of the series 907 in the plate TM4 thereby permitting the plate TM4 to move to the left under spring action eight steps or units relatively to plate TM5. If the pence multiplicand digit is 9d., then the rod 335e will rise nine steps and will come opposite the third step of the series 912 which represents 6d. Accordingly the plate TM5, when permitted to move will move six steps and will carry the pawl 905 with it to the same extent. Plate TM4 will, therefore, be enabled to move a further six steps making fourteen steps in all. Thus the plate TM4 has received the sum of the two pence components derived respectively from the tens multiple of the

pence	
10	

multiplicand digit, and the tens multiple of the pence multiplicand digit.

Since the pence multiplicand digit was 9d. its tens multiple is 7/6d. and the lug 914 will, therefore, be set at 7 accordingly the plate TM6 will be permitted to move seven steps to the left. This plate TM6 carries a projecting pin 916 on which is pivoted an arm 917 carrying a pin 918 engaging a step 919 on the plate TM7. Accordingly when the plate TM6 moves to the left seven steps the plate TM7 also moves to the left seven steps.

It will be remembered that the total movement of the plate TM4 was fourteen pence and since this exceeds 11d. one shilling has to be transferred into the units of shillings denomination. To this end the plate TM4 carries a lug 920 which, when the movement of the plate TM4 exceeds 11d. pushed a pin 920a on an arm 920b secured to a shaft 921 having an arm 922 also secured thereto from which projects a pin 922a lying over a tail 917a of the arm 917.

When the lug 920 pushes the pin 920a the shaft 921 is rocked, the pin 922a depresses the tail 917a thereby raising the pin 918 clear of the step 919 on the plate TM7, whereby the latter plate is permitted to move one further step to the left.

In the tens of shillings denomination the plate TM8 is set by the rod 335f which is positioned by the units of shillings multiplicand reading bar 111f and has a lug 926 cooperating with steps 927 in the plate TM8.

The tens multiples of the units of shillings digits are as follows: 10/-; £1; £1.10/-; £2; £2.10/-; £3; £3.10/-; £4; and £4.10/-.

From the above it will be seen that the tens multiple of a units of shillings digit involves a component (either 1 or zero) in the tens of shillings denomination and may also involve a component in the units of pounds denomination.

Accordingly the tens of shillings plate TM8 has alternate steps representing 0 and 1, the 0 step being shown at 927 and the 1 steps being shown at 927a.

In the units of pounds denomination, the plate TM10 is controlled by a pawl 928 pivoted on a pin 929 projecting from the plate TM9 which receives the units of pounds component of the tens multiple of a tens of shillings digit in the multiplicand.

The plate TM9 is controlled by the rod 335g which is positioned by the tens of shillings multiplicand reading bar 111g, and has a lug 930

co-operating with a single step 931 on the plate TM9.

This step has the value five pounds, since there can only be either the value zero or £5 resulting from the tens multiple of zero or ten shillings.

If the tens of shillings multiplicand digit is one (ten shillings), the rod 335g will rise and the plate TM9 when released will move forward to the extent of five units until the lug 930 engages 10 with the step 931. This movement of the plate TM9 carries the pawl 928 forward also five units and therefore permits the plate TM10 to move forward five units.

The pawl 928 has a pin 932 engaging in a slot 15 933 in an extension 934 of the units of shillings rod 335f.

If the rod 335f rises to the extent of four units its lug 926 will be opposite the second zero step 20 927 in the plate TM8, so that the plate TM8 will not be permitted to move relatively to the lug 926, since ten times four shillings is forty shillings, giving no digit in the tens of shillings 25 denomination. On the other hand the pawl 928 will be swung upwardly until it is opposite the second step 935 in the plate TM10 representing two pounds, so that the plate TM10 will be allowed to move a further two steps to the left so that the plate TM10 moves to an extent representing the sum of all the units of pounds components 30 of the tens multiples of the units of shillings and tens of shillings digits of the multiplicand.

In the tens of pounds denomination there is only one plate TM11 which is under the control 35 of the setting rod 335h, which is positioned by the units of pounds multiplicand reading bar 111h. The rod 335h has a lug 936 co-operating with steps 936a on the plate TM11 and will set this tens of pounds plate TM11 to the same digit as that which occurs in the units of pounds multiplicand denomination.

In the higher denominations there is in each 40 denomination a setting rod such as 335h and a plate such as TM11.

It may here be pointed out that each of the plates has, in addition to the steps already referred to, a zero step indicated at Z which normally abuts against the setting means such as the lug 903 and the pin 918 and the pawl 905.

From the foregoing it will be understood that the plate TM3 is set to the

pence	
10	

55 digit of the tens multiple of the multiplicand, the plate TM4 is set to the pence digit thereof, the plate TM1 to the units of shillings digit thereof, the plate TM8 to the tens of shillings digits thereof, the plate TM10 to the units of pounds digit thereof, and the plate TM11 to the tens of pounds digit thereof.

Tens multiple stop basket

When the multiplier contains a whole number 60 only, during the first multiplying cycle the multiplicand reading bars 111a to 111m are set from the multiplicand stop basket 621, but during subsequent cycles they are set from the tens multiple stop basket 346 (Figure 34), this stop basket being 65 constructed as described in British specification No. 490,358.

The stop basket 346 is itself set from the denominational tens multiple or setting-changing plates such as TM3, TM4, TM7, TM8, TM10 and TM11.

As described in British specification No. 490,-358 the tens multiple stop basket is located below the setting-changing plates TM3 and so on, and each setting-changing plate, such as TM3, TM4, TM7, has a downwardly projecting lug indicated in Figure 33 at L3, L4, L7, L8, L10, L11 which moves with the associated setting-changing plate over the corresponding denominational column of stops 347 in the tens multiple stop basket 346.

In this connection it will be noted that the pence plate TM4 has two lugs L4 and L4a for the following reason. If the movement of the pence plate is less than twelve the lug L4 will be positioned over one of the stops in the pence column of stops 347 in the basket 346. If the movement of the plate TM4 exceeds eleven, however, the stop L4 will have passed beyond the eleventh stop in the pence column, and the stop L4a will then set the appropriate stop in that column.

As described in British specification No. 490,-358 the tens multiple stop basket 346 is set by moving it upwardly until the stops 347 engage the lugs L3, L4 and so on and are displaced downwardly thereby, the basket is then lowered to bring the stops 347 into the path of the multiplicand reading bars 111a to 111m.

The means for moving the tens multiple stop basket is described in specification No. 490,358 and includes a pair of laterally projecting pins 348 engaging in slots in arms 349 secured to a shaft 350 operated through a link 352, actuated by a cam track 355 in the cam disc 156a on the multiplicand shaft 41 (Figures 42 and 48B).

The plates TM3, TM4 and so on and their associated mechanism are held between two side plates 940 and 940a and each plate, such as TM8, carries four guides 941 grooved to engage with a guide rail 942 formed on a bar 943, there being a bar 943 to engage with the two upper guides 941 and the bar 943 to engage with the two lower guides 941. The bars 943 are mounted in the frame on rods 944, spacing sleeves such as 945 being disposed between the bars.

The setting rods such as 335f are guided for vertical movement in comb bars 946 mounted transversely between the plates 940 and 940a.

Each of the plates such as TM8 is urged to the right in Figure 34 by a spring 947 anchored to an anchor bar 948 running transversely of the frame plates 940 and 940a, and the plates are normally held over to the left in Figure 34 by a restoring bar 361 which, as described in specification No. 490,358 is carried between two slides 363 having rack teeth 366 engaging with pinions 367 of which one engages with a toothed quadrant 368 (Figure 3) operated by a cam track 369a formed in a disc 369 secured to the multiplication shaft 41.

The quadrant is connected by a link 1371 to one end of a lever 1372 pivoted to the machine frame at 1373 and having pivoted thereto at 1374 an operating link 1375 of which the lower end is slotted at 1376 to pass over the shaft 41 and carries a roll 1377 engaging in the cam track 369a.

Zero stop control for multiplicand reading bars

In order to hold back the multiplicand reading bars in those denominations in which the digits are zero, a zero stop 370 is provided in each column of the multiplicand stop basket, and means is provided which on every cycle of the selection shaft 4 raises all the zero stops in the multiplicand stop basket, these stops then remain up in those columns in which no other stop is

set until all the multiplicand stops are restored. As described in British specification No. 490,358 in order to set these zero stops 370 in the multiplicand stop basket at each cycle of the selection shaft 4 a shutter 371 (Figs. 37, 47B, 48A and 48B) is secured to a shaft 372 and coacts with projections 373 on the zero connection wires 374 in each column of the multiplicand field in the connection box. The shaft 372 carries an arm 375 connected by a link 376 to an arm 377 pivoted to the machine frame at 378 and carrying a roll 379 engaging with a cam 380 (Figs. 1, 10C and 36) secured to the selection shaft 4.

Moreover, since there is a greater number of denominations required in the tens multiple stop basket 346 than in the multiplicand stop basket 621, additional reading bars are provided which receive a setting from the tens multiple stop basket 346 only, these bars being those in the ten thousand pounds and one hundred thousand pounds denominations, namely, the bars 111l and 111m. In order to hold back these bars when the other bars are being set from the multiplicand stop basket, zero stops 370 are provided in the latter for these bars 111l and 111m, and these stops are likewise lifted in each cycle of the pin box shaft.

Further, in the multiplicand stop basket 621 there is a greater number of columns of whole number stops 632 than of fraction stops 631, and accordingly zero stops are provided for holding back the reading bars above the highest fraction denomination when the stop basket 621 is in the fraction position. These zero stops are shown at 940 and are raised and controlled in the same manner as the zero stops 370.

General arrangement of multiplier and multiplicand stop baskets and reading bars to handle fractional multipliers

The multiplicand reading bars 111a to 111m are spaced apart at the same pitch as the whole number stops 632 and the multiplicand stop basket 621, which as will be explained later, is displaceable laterally, is normally disposed so that the multiplicand reading bars 111a to 111m are opposite to the whole multiplicand stops 632. If the multiplier is a whole number only, then multiplication proceeds in the manner described in British specification No. 490,358, and the fraction stops 631 are not used at all. If, however, the multiplier consists of a whole number and a fraction then the multiplicand stop basket 621 is first displaced to the left to bring the lowest denominational fractional multiplicand column of stops 631 into register with the lowest denominational reading bar 111a and, therefore, to bring also each fractional multiplicand column of stops into register with the corresponding denominational multiplicand reading bar.

The multiplier stop basket is provided with eight columns of stops, of which the three columns 622x (Figure 13) at the right-hand end are reserved for the reception of the numerator of the fraction, which with 960 as the denominator will give the fraction which occurs in the multiplier, e. g. $\frac{1}{3}$ will be set up as 320 since

$$\frac{320}{960} = \frac{1}{3}$$

The remaining five columns of stops 622 are reserved for the whole number digits of the multiplier.

Mechanism for controlling multiplier reading bars when handling fractional multipliers, and escapement mechanism for determining the number of multiplying cycles to be performed

In the manner described in specification No. 490,358 multiplication takes place by each multiplier digit in turn, and escapement mechanism similar to the mechanism including the escapement bar 172, described in the aforesaid prior specification, is provided to control the number of multiplying cycles.

If the multiplier contains a whole number only the first multiplier reading bar to take a setting from the multiplier stop basket 620 must be the fourth bar from the right, i. e., the bar 110d. If on the other hand the multiplier contains a fraction, the the extreme right-hand multiplier reading bar 110a must be the first to take a setting from the stops 622x.

In order to bring about this result the escapement mechanism in the machine according to the invention is constructed in the following manner.

In addition to the escapement slide 172 described in British specification No. 490,358 there is provided a slide 812 (Figs. 4, 8 and 38) mounted behind the slide 172, these two members having slots 172a and 812a by means of which they are slidably supported on a pin 813 secured to the frame of the multiplier stop basket 620. The slides 172 and 812 are also guided in slots formed in lugs 814 of the stop basket frame.

The slides 172 and 812 pass through slots 173 (Fig. 10) formed in the upper edges of the multiplier reading bars 110 so as to be in alignment when the latter are in their normal positions. Referring to Fig. 38 in which the slides 172 and 812 are shown spaced apart in order to enable the various parts of the mechanism to be more clearly seen, there is pivoted at 815 in a recess formed in the escapement bar 172 a lever 816 of which one arm carries a pin 816a projecting through a square hole 817 in the slide 812, while the other arm carries a pin 818 projecting through the vertical arm of an L shaped slot 819 in the slide 812.

Mounted in a further recessed portion in the escapement bar 172 is a lever 821 pivoted to the bar 172 at 822 and carrying a pin 823 extending through a hole in the escapement bar 172. The lever 821 also carries a pin 824 engaging in an inclined slot 825 in the slide 812.

As described in British specification No. 490,358 there is pivoted on a shaft 191a mounted in extensions 171 of the multiplier stop basket 620 a series of latch members or pawls 191, one for each column of multiplier stops except the lowest denominational column.

Associated with each pawl 191 is a latch 192 pivoted on a spindle 192a and carrying a pin 192b which is held against the resetting slide 627 for the corresponding column of stops 622 by means of a spring 193 attached to the pawl 191 which normally rests against the nose 192d of the latch 192. When any stop 622 is raised the slide 627 is pushed to the left against the action of a spring 630. By this means the corresponding latch 192 is rocked clockwise and the corresponding pawl 191 is permitted to rock clockwise also until it is arrested by a shoulder 192c of the latch 192. In the present construction a similar pawl 826 is provided for the lowest denominational column of stops, that is to say, the extreme right-hand column of stops 622x in the multiplier stop basket

628. This pawl 826 carries a lug 827 which lies above the end of the pin 818 (Figure 38).

When the multiplier contains a fraction this fraction will be expressed as three digits in the three columns at the right-hand side of the multiplier field of the card and, therefore, a sensing pin in one or other of the three right-hand columns of the multiplier field will always find a hole if there is a fraction in the multiplier, and the rise of this sensing pin will release either the pawl 826 or one of the pawls 191 for the second and third columns to the left in the manner described for the pawl 191. When there is a fraction in the multiplier it is always required to release the pawl 826 and in order to release this pawl in the event of the lowest denominational digit of the fraction being zero, the pawl 826 and the two pawls 191 to the left thereof are connected by a pin 826a. When the pawl 826 is released it rocks clockwise in Figure 38 under spring action whereby the lug 827 pushes the pin 818 down thereby rocking the lever 816 against the action of a spring 816b. When the pin 818 is thus pushed down it comes into line with the horizontal portion of the L shaped slot 819 thereby permitting a spring 828 to pull the slide 812 to the left relatively to the escapement bar 172.

The escapement bar 172 is provided with two slots 829 and 830 which have a function equivalent to that of the slot 174 in the escapement slide 172 described in specification No. 490,358. When the machine is at rest the slot 829 is located opposite to the fourth reading bar from the right, that is to say, the reading bar 110d in the units denomination of the whole number portion of the multiplier. The other slot 830 is disposed opposite to the reading bar on the extreme right, that is to say, the reading bar 110a in the units denomination of the numerator which, with 960 as a denominator, equals the fraction in the multiplier.

The slide 812 also has two slots 831 and 832. When the machine is at rest the slot 831 is in register with the slot 829 so that the fourth reading bar 110d from the right is free to move to take a setting from the fourth column of stops in the multiplier basket, i. e., the first of the columns 822. The other slot 832, however, is not in register with the slot 830 in the escapement bar 172 and, therefore, the reading bar 110a at the extreme right of the multiplier reading bars is prevented from moving forward by engagement with the material of the slide 812.

When a fractional multiplier is sensed from the card relative movement between the slide 812 and the escapement bar 172 takes place as described above and this relative movement brings the slot 831 out of register with the slot 829 and the slot 832 into register with the slot 830; thus when a fractional multiplier is sensed the machine is automatically set for the extreme right-hand multiplier reading bar 110a to take a setting from the right-hand column of stops 622x.

When the machine is at rest the pins 816a and 818 on the lever 816 occupy the positions shown in Figure 38. In this position the pin 816a stands in the path of the lug 191b on the pawl 191 corresponding to the lowest denominational column but one of stops 622 which receive the whole number portion of the multiplier. If a multiplier comprising a whole number only is set up no movement of the pins 816a and 818 occurs and they remain in the positions shown in Fig. 38.

Assuming now that a whole number containing digits in the units, tens and hundreds de-

nominations has been set up in the whole number columns of stops 622 in the multiplier stop basket by sensing a card, the corresponding pawls 191 will have rocked clockwise on to the shoulders 192c of their corresponding latches 192 and therefore the escapement slides 172 and 812 will be free to move until the pin 816a strikes the pawl 191 in the thousands denomination of the whole number stops 622. Thus the pin 816a acts in the same manner as the pin 194 described in British specification No. 490,358. The pin 816a is so placed that the escapement slide 172 is arrested halfway between two teeth 189, that is to say when the pawl 191 is operated during the third revolution of the multiplication shaft 15 the slide 172 will be prevented from moving to the extent of a complete tooth pitch by engagement of the pin 816a with the pawl 191 in the thousands whole number denomination.

Also projecting from the escapement slide 172 is a series of pins 195 (Figs. 10A, 22, 39 and 48A) one for each column of multiplier stops, both whole number and fraction. These pins cooperate with a lever 196 pivoted to the machine frame at 197. The lever 196 has a cam surface 196a which cooperates with a pin 198 on a link 199 which is pivoted at 200 to an arm 200a, the upper end of the link 199 being guided in a slot formed in a bracket 201 and pulled to the right by a spring 202. Each time the multiplication shaft 41 rotates, a cam 200b attached to the disc 186 (Figs. 23 and 22) engages a roll 200e on the lever 200a and lifts it whereby the link 199 is raised and the pin 198 acting on the cam surface 196a rocks the lever 196 clockwise against the action of a spring 203.

The pitch of the pins 195 on the escapement slide 172 coincides with the pitch of the teeth 189. If the escapement slide is permitted to execute a full movement equal to one tooth pitch, two adjacent pins 195 are disposed one to each side of a nose 196b of the lever 196 so that when the lever 196 is rocked clockwise by the link 199 the nose can pass between the two adjacent pins. When, however, the escapement slide 172 is arrested by engagement of the pin 816a with one of the pawls 191 it is prevented from moving a complete pitch and stops in a position in which one of the pins 195 stands in the path of the nose 196b of the lever 196 so that the latter cannot rock. Then when the link 199 rises the pin 198 rides up the cam surface 196a whereby the link 199 is rocked slightly counterclockwise about its pivot 200 and a pin 204 thereon engages the end of a clutch control lever 206 secured to a shaft 207 carrying at its other end an arm 207a connected by a link 208 to the tail 57a of the clutch control bell crank 57 (Fig. 8).

By this means the bell crank 57 is rocked and the clutch for the shaft 41 is disengaged and the clutch for the shaft 4 is engaged. The escapement bar 172 is returned by a restoring bar 417 as described in specification No. 490,358, which also returns the slide 812.

The bar 417 is operated by the following mechanism.

Pivoted to a bracket 415 (Figs. 1 and 10A) secured to the machine frame is a bell crank 416 carrying a pin 417 which normally lies in line with the end of the escapement bar 172 but in the position shown in Fig. 10A. One arm of the bell crank 416 is connected by a link 418 to a lever 419 pivoted to the machine frame at 420 and connected by a link 421 to a lever 422 pivoted to the frame at 755 and carrying a roll 423 engaging

5 with a cam 424 secured to the selection shaft 4, (Figs. 1, 10C and 36). At the end of a series of revolutions of the multiplication shaft 41 the selection shaft 4 makes one revolution during which the cam 424 rocks the lever 422 clockwise (Fig. 36) and thereby rocks the bell crank 416 clockwise also (Fig. 10A) whereby the pin 417 returns the escapement bar 172 to its normal position.

At the same time the pin 417 engages the inclined face 191d of a block 191a (Figs. 15 and 39) secured to a shaft 191f to which is attached a shutter 191g serving to restore to normal position those pawls 191 which had been displaced therefrom in the manner described with reference to Fig. 11.

When any latch 191 is displaced from its normal position the shutter 191g rocks clockwise in Figs. 11 and 39 and when the pin 417 engages the inclined surface 191d it rocks the shutter 191g counterclockwise whereupon the shutter, by engagement with the tails 191c of the latches 191 returns the latter to normal position in which they are retained by the members 192.

When a fraction occurs in the multiplier the lever 816 is rocked and the pin 816a is raised and the pin 818 is lowered. The latter pin 818 then performs the same function as the pin 816a described above, the pin 816a being idle.

30 *Mechanism for displacing the multiplicand stop basket when the multiplier contains a fraction*

35 As already mentioned the multiplicand stop basket 621 is displaceable and is normally so positioned that the multiplicand reading bars 111a... are in register with the columns of stops 632 which receive the whole multiplicand. If, however, there is a fraction in the multiplier it is necessary that the sensing of this fraction shall 40 displace the multiplicand stop basket 621 to bring the fractional multiplicand stops 631... into register with the multiplicand reading bars 111a...

45 It has already been mentioned that when a fraction is sensed in the multiplier relative movement occurs between the escapement bar 172 and the slide 812.

50 The multiplicand stop basket 621 is mounted to slide on guides which may conveniently be constructed as follows (Figures 4B and 40):

55 Running across the machine parallel to the length of the multiplicand stop basket are two angle bars of which the rear one, 833 (Figure 4B) engages with slots in wings 834 projecting from the end plates 835 of the multiplicand stop basket. The front angle bar 836 carries two brackets 837, 837a and in holes in the vertical portions of these brackets engage pins 838 and 838a projecting from the ends of the multiplicand stop basket.

60 At its right-hand end the multiplicand stop basket is provided with a projecting rod 839, around which is located a spring 840 of which the other end surrounds a rod 841 projecting from a fixed frame plate 842 (Figure 4B). The spring 840 tends to move the stop basket to the left of the machine.

65 The multiplicand stop basket 621 is normally, that is to say, when the machine is at rest, in its position to the right in which it is maintained by a latch 843 (Figure 40) engaging over the left-hand end of the stop basket 621. This latch 843 is pivoted on a shaft 844 and has a tail 843a which co-operates with the pin 823 in the man-

ner about to be described (Figures 4B, 13, 40 and 41).

When the multiplier contains only a whole number the multiplicand stop basket remains in its right-hand position, so that the whole number stops 632 are in register with the multiplicand reading bars 111a to 111m.

If, however, a fraction is sensed in the multiplier then relative movement occurs between the escapement bar 172 and the associated slide 812, whereby the arm 821 is lowered and the pin 823 rocks the latch 843 counter-clockwise, thereby permitting the spring 839 to move the stop basket 621 to the left, so that the fraction stops 631 come into register with the multiplicand reading bars 111a.

Since the friction between the stop basket 621 and the latch 843 may be too great to permit of movement of the latter, means is provided for relieving this latch of the load due to the spring 839 just prior to the movement of the lever 821, and conveniently this load relieving means is operated at each revolution of the selection shaft 4.

The means for relieving the load comprises an arm 845 secured to a shaft 846, and at the proper time in the cycle the shaft 846 is rocked clockwise, whereby a cam nose 845a on the arm engages a block 847 projecting from the stop basket 621 and moves the latter very slightly to the right to an extent just sufficient to relieve the latch 843 of the load due to the spring 839.

The shaft 846 may be operated by the following mechanism:

Secured to the arm 846 is an arm 848 connected at its lower end by a link 849 to a bell crank 850, pivoted to a bracket 851 on the side plate of the frame. Also pivoted to this bell crank is a link 852 running down vertically to an arm 853 to which it is pivoted at 854, the arm 853 being pivoted on the spindle 755. The lever 853 carries a roller 855 co-operating with a cam projection 856 secured to the cam disc 737 (Figure 22).

When a fraction is sensed in the multiplier the multiplicand stop basket 621, after having moved to the left, must remain in that position for three cycles and must then be returned to the right in order that the whole multiplicand may be read from the stops 632.

In order to return the multiplicand stop basket to its normal position after it has been moved to the left by the spring 839, an arm 857 is secured to a shaft 858.

The arm 857 is mounted on a shaft 858 in such a way that while this can rotate with the shaft 858, it can also slide along the shaft.

Loosely mounted on a stud 859 is a plate 860 (Figures 40 and 41) through which the shaft 858 passes, this plate 860 being mounted on the stud 859 and the shaft 858 so that it can rock on the stud 859 in the direction of the length of the shaft 858. At its upper end the plate 860 carries a vertical roller 861 standing in the path of a cam block 862 on the side of the escapement bar 172.

The normal positions of these parts are shown in Figures 40 and 41.

Mounted on the shaft 858 between the plate 860 and the boss 863 of the arm 857, is a sleeve 864 and a spring 865 tends to push the arm 857, the sleeve 863 and the plate 860 over to the left in Figure 41. Normally these parts are in this position to the left, and in this position the arm 857 is out of register with the block 847, so that this arm 857 swings idly.

During the multiplication by the fractional portion of the multiplier, the escapement bar 172 moves step by step to the left and, during its movement from its third to its fourth position, a cam surface 866 on the cam block 862 comes into register with the roller 861, thereby permitting the spring 865 to push the arm 857, the sleeve 864 and the plate 860 over to the left in Figure 41, whereby the arm 857 is brought into register with the block 847 on the stop basket 621. Then, on the next oscillation of the arm 857, the basket 621 is moved over to the right again, in which position it is latched by the latch 843, since by this time, the pin 823 will have passed beyond the tail 843a of the latch. The shaft 858 is rocked at each revolution of the multiplication shaft 41 by means of a cam projection 870 (Figures 22 and 42) secured to the disc 156a described in specification No. 490,358 and serving to operate a bell crank 871 pivoted on a spindle 872 and connected by a link 873, to an arm 874 secured to a shaft 875. (See Figs. 10B, 42 and 48B). Also secured to the shaft 875 is an arm 876 connected by a link 877 to an arm 878 on the shaft 858.

It will be understood that when multiplication by a fractional multiplier is being effected, multiplication is first effected by the right-hand digit or lowest denominational digit of the number which with 960 as a denominator serves as a numerator of the fraction equivalent to the fraction in the multiplier.

Mechanism for resetting the multiplicand and tens multiple stops

When the multiplicand reading bars 111a . . . take a setting from the fraction stops 631 ten times the amount of the fractional multiplicand is at the same time set up in the tens multiple stop basket 346 described in specification No. 490,358 and at each revolution thereof the reading bars 111a . . . take a setting from the stops in the tens multiple stop basket 346.

Accordingly when multiplication by the number representing the fraction in the multiplier has been completed, 1,000 times the original fractional multiplicand which was originally set up in the stops 631 will be contained in the tens multiple stop basket 346.

During the next revolution of the multiplication shaft 41, however, the reading bars 111a . . . have to take a setting from the whole multiplicand stops 632 in the multiplicand stop basket 621 and at the same time the tens multiple of the whole multiplicand has to be set up in the tens multiple stop basket 346.

Accordingly therefore towards the end of the third revolution of the multiplication shaft 41 it is necessary to clear the tens multiple stop basket 346 in readiness for it to receive the tens multiple 60 of the whole multiplicand as read from the whole multiplicand stops 632 during the fourth revolution of the multiplication shaft.

The mechanism for clearing the tens multiple stop basket which is shown at 346 in Figures 10A 65 and 10B is associated with the mechanism for clearing the multiplicand stop basket 621 and to make the operation clear this latter mechanism will first be described.

Mounted in the brackets 837, 837a (Figures 70 4B, 10A and 10B) is a shaft 394 similar to the shaft 394 described in specification No. 490,358 and this shaft carries a shutter indicated at 395a which is similar to the shutter 395 described in specification No. 490,358 and serves to re-set the 75 stops in the multiplicand stop basket 621. Since,

however, it is not desired to re-set the whole multiplicand stops 632 when the fraction multiplicand stops 631 are re-set the shutter 395a is cut away to form a series of projections 395b (Figure 4B) which, when the multiplicand stop basket is in the whole number position, are opposite to the ends of the latching slides 634 for the whole multiplicand stops.

In the present construction the shaft 394 is rocked by means of the cam 870 secured to the disc 156a, which cam operates a lever 879 (Figure 42) pivoted on the spindle 872 connected at its other end by a link 879a to an arm 879b on the shaft 394.

Thus at each cycle of the multiplication shaft 41 the shaft 394 is rocked and the shutter 395a will re-set the whole multiplicand stops 632, when the multiplier is a whole number.

In order to re-set the stops in the tens multiple stop basket 346 re-setting slides 883 are provided as described in the prior specification, but in the present construction each of the slides carries a pin 887 with which co-operates an arm 888 secured to a shaft 881, which is mounted in the side plates 940, 940a of the tens multiple mechanism.

The shaft 881 is rocked counter-clockwise in Figure 42 at each multiplying cycle by a cam 880 (Figs. 10B and 48B) on the shaft 41 which operates a lever 881 pivoted at 872 and connected by a link 892 to an arm 883 on the shaft 881.

As explained in British specification No. 490,358, during the first multiplying cycle the tens multiple mechanism including the setting-changing plates TM3 . . . receives the tens multiple of the original multiplicand and the tens multiple stop basket 346 moves to its uppermost position to receive this tens multiple from the setting-changing plates after which the basket 346 moves down to its mid position, and at the end of the first cycle moves to its lowermost position.

Early in the second multiplying cycle the multiplicand reading bars 111a . . . move forward to take the setting of ten times the original multiplicand from the basket 346, after which the latter is reset, and then moves up to take a new setting from the tens multiple mechanism, which during the early part of the second cycle has received the tens multiple of the multiplicand which it contained during the first cycle, i. e. 100 times the original multiplicand.

Early in the third cycle the multiplicand reading bars take the setting of 100 times the original multiplicand from the basket 346 and the latter is reset, and then moves up to take a new setting of 1000 times the original multiplicand from the tens multiple mechanism.

Accordingly at the beginning of the fourth cycle the tens multiple stop basket 346 contains 1000 times the original multiplicand so that, when, early in the fourth cycle, the multiplicand reading bars move forward they will be set to the thousand multiple of the original multiplicand.

Thus when the multiplier contains a fraction, the tens multiple stop basket contains at the beginning of the fourth cycle 1,000 times the fractional multiplicand so that when the multiplicand reading bars 111a . . . move forward in the fourth cycle they would be set to 1,000 times the fractional multiplicand.

In the fourth cycle, however, it is desired that the multiplicand reading bars 111a . . . shall be

set from the multiplicand stop basket 621 to the value of the whole multiplicand.

Since the normal resetting mechanism for the tens multiple stop basket 346 which is actuated by the shaft 881 does not operate until after the multiplicand reading bars 111a . . . have moved forward, it is necessary, when the multiplier contains a fraction to provide means for resetting the tens multiple stop basket 346 in the fourth multiplying cycle prior to the forward movement of the reading bars 111a . . . and according to the invention this resetting operation is conveniently brought about by the movement of the multiplicand stop basket 621 from the fractions to the whole number position (from right to left in Figure 10).

The construction of this auxiliary resetting mechanism for the basket 346 is as follows:

Pivoted to the bracket 837 (Figure 10) at 883 is a lever 884 carrying a pin 885 which is urged by a spring 886 towards the pin 888 projecting from the right-hand end of the multiplicand stop basket 621.

The upper end of the lever 884 carries a pin 887 which when the machine is in its normal position with the stop basket 621 over to the right, lies to the left of a cam projection 888 on the shaft 881.

When a fraction is sensed in the multiplier 30 the stop basket 621 moves to the left, thereby withdrawing the pin 888 from the pin 885.

At the end of the first multiplication cycle the shaft 881 is rocked, whereby the cam projection 888 is lifted above the pin 887 so that the spring 886 rocks the lever 884 clockwise and brings the pin 887 below the cam projection 888. When at the end of the third cycle the multiplicand stop basket moves to the right, the lever 884 is rocked counterclockwise, and the pin 887, by acting on the cam 888 causes the shaft 881 to rock clockwise, thereby resetting the tens multiple stop basket 346.

Thus when, in the fourth cycle, the reading bars 111a . . . move forward the basket 346 does not affect them since none of its stops are set.

Mechanism for resetting the multiplier stops

Co-axially mounted with the shaft 394 is a shaft 403 upon which is mounted a shutter 404, 50 which is the same as the shutter 404 described in specification No. 490,358, and serves to restore the stops 622 and 622x of the multiplier stop basket by operating the latching slides 627. The shaft 403 is rocked from the selection shaft 4 to restore the multiplier stops at the beginning of the revolution of the shaft 4 in the manner described in British specification No. 490,358, this operation being effected by the cam 409 on the selection shaft 4 (Figure 22).

To this end the shaft 403 carries an arm 405 to which is pivoted a link 406 pivoted at its lower end to a lever 407 secured to a sleeve 407a freely mounted on the fixed rod 755 and having also secured thereto a lever 407b which carries a roll 408 engaging with a cam 409 on the selection shaft 4 (Figs. 1, 10C and 36). The cam 409 rocks the levers 407, 407b clockwise (Fig. 36) thereby pulling the link 406 down and rocking the shaft 403 whereby the multiplier stops 622 and 622x are reset by the shutter 404.

As described in the prior British specification the shutter 404 carries a lug 410 (Figure 10) overlapping the shutter 395a for the multiplicand stops, so that when the shutter 404 is rocked the shutter 395a is rocked also, whereby

the shaft 394 is rocked and by means of the lever 894 on the shaft 403 carrying a pin 895 engaging with a lever 896 on the shaft 881 rocks the latter shaft and resets the tens multiple stop basket also, thus all three stop baskets are reset at the beginning of the revolution of the selection shaft 4.

Mechanism for punching the product in the card

After multiplication by all the multiplier digits has been effected the product is punched in the card by means of the punches 454 which are selected for operation by the set-bars 453 which in turn are set from the accumulator wheels 291 through the racks 270, elements 444, and connection wires 451 in the manner described in British specification No. 490,358.

This operation is controlled from the punch shaft 5 (Figs. 1, 6 and 48C) which rotates with the selection shaft 4 and is therefore set in motion after the revolution of the multiplication shaft 41 corresponding to the highest denominational multiplier digit. The punch shaft 5 rotates synchronously with the selection shaft 4 and therefore makes one revolution when the clutch for the selection shaft is engaged.

Since at this time the multiplication shaft 41 is stationary the mechanism for controlling the accumulator wheels 291 and the restoring bar 272 for the accumulator wheel control racks 270 must be actuated from the punch shaft 5. In order to actuate the restoring bar 272 for the accumulator control racks 270 a cam disc 425 (Figs. 1, 30 and 48C) is secured to the punch shaft 5 and has a cam track 426 formed therein with which engages a roll 427 carried by a lever 428 pivoted to the machine frame at 429 and freely engaging with a pin 430 on the lower end of the link 280 which, when moved downwardly, rocks the shaft 282 and, through the arms 284, 284a, lowers the restoring bar 272 for the accumulator control racks 270. In this connection it may be pointed out that the lever 277 which operates the restoring bar 272 from the multiplication shaft 41 and the lever 428 which actuates this restoring bar from the punch shaft 5 freely engage pins 279 and 430 respectively on the link 280 so that the lever 277 can move the link 280 downwardly independently of the lever 428 and vice versa.

The restoring bar 272 when lowered by the action of the cam 274 on the multiplication shaft 41 operated to release the accumulator control racks 270 to take a setting from the partial product accumulator plates RP, after which the accumulator wheels 291 were brought into engagement with the racks 270 and the latter were zeroised to transmit to the accumulator wheels the final product represented by the positions of these racks. On the other hand when the restoring bar 272 is operated from the punch shaft 5 it is desired that the accumulator wheels 291 shall transfer to the racks 270 the amount which said accumulator wheels held and accordingly the cam 426 on the punch shaft is timed to release the restoring bar 272 after the accumulator wheels 291 have been brought into engagement with the control racks 270.

In order to bring the accumulator wheels 291 into engagement with the racks 270 a cam 431 (Figs. 1 and 48C) is mounted on the punch shaft 5 and engages with a roll 432 on the lower end of a link 433 guided by means of a pin and slot 434 and pivoted at its upper end to a lever 435 secured to the shaft 293 which, when rocked,

swings the accumulator wheels 291 into engagement with the control racks 270.

In order to operate the transfer ball 325 (Fig. 31) from the punch shaft 5 an arm 530 is secured to the shaft 321 (Figs. 1 and 31) and this arm is pivoted to a link 531 guided by a pin and slot connection 532 to the frame and carrying at its lower end a roll 534 engaging a cam 535 on the punch shaft 5 (see also Figs. 48A and 48C).

Each of the accumulator control racks 270 is formed with rack teeth 441 (Fig. 31) which permanently engage with a corresponding pinion 442, the pinions 442 all being mounted freely on a common shaft 443. Each pinion 442 engages with a corresponding rack 444 formed with slots 445 engaging with rods 446 fixed to the machine frame whereby the racks 444 can slide. Pivoted to each rack 444 at 447 is a punch setting element in the form of a lever 448 having an upstanding arm 449 carrying a block 450. When the control racks 270 take a setting from the accumulator wheels 291 the corresponding racks 444 are moved to the left in Fig. 31 (right in Fig. 3) and take up positions representing the final product stored in the accumulator wheels. This movement of the racks 444 moves the corresponding blocks 450 over the upper ends of corresponding columns of set connection wires 451 (Figs. 3 and 6) carried in a connection box 452, the lower ends of these wires 451 lying over corresponding columns of set bars 453 (Figs. 1 and 6) of which the lower ends lie above corresponding punches 454. Thus, after the control racks 270 have been set from the accumulator wheels 291 the punch setting racks 444 are moved to positions in which the respective blocks 450 lie over those connection wires 451 in each column which represent the denominational digits of the final product.

Mounted above the upward extensions 448 of the setting arms 448 is an operating plate 455 (Figs. 3 and 31). This plate carries two pairs of lugs 457 and these lugs carry pins 456 engaging with inclined slots 458 in the side plates of the machine frame the plate 455 being normally pulled to the right (Fig. 31) by a spring 459 whereby the rods 456 are held at the upper ends of the slots 458. Secured to a transverse shaft 460 is an arm 461 which abuts against the plate 455 and when the shaft 460 is rocked clockwise pushes the plate 455 to the left (Fig. 31) whereby the inclined slots 458 cause the plate 455 to move downwardly thereby rocking the arms 448 counterclockwise about their pivots 447. This movement of the arms 448 causes the blocks 450 to depress the connection wires 451 over which the blocks 450 have been positioned by the racks 270 and the depression of the connection wires 451 depresses also the corresponding set bars 453 so that now in each column of set bars 453 one set bar is depressed representing the corresponding denominational digit of the final product.

In order to rock the shaft 460 the said shaft carries an arm 462 (Fig. 1) pivoted to a link 463 which, at its lower end, is pivoted to an arm 464 pivoted to the machine frame at 465. This arm 464 carries a roll 466 engaging with a cam 467 secured to the punch shaft 5, the timing of this cam being such that after the racks 444 have been set from the accumulator wheels 291 through the control racks 270 the cam 467 rocks the shaft 460 counterclockwise in Fig. 1 (clockwise in Fig. 31) and thereby depresses the plate 455 whereby the set bars 453 are set to represent the final product.

The punches 454 are freely mounted in an upper die plate 469 (Fig. 6) below which is a lower die plate 470 having holes therein arranged in accordance with the arrangement of the punches. The card, after being sensed, passes from the pin box into the punch unit 15 between the die plates 469 and 470 where it is held by a card stop 471. This card stop is normally in position to arrest the card and is lowered to release the card, after the latter has been punched, by a cam 472 on the punch shaft 8 the cam engaging with a roller 473 on the end of an arm 474 secured to a shaft 475 carrying an arm 476 connected to the card stop 471 by a link 477 (see Figs. 1, 47A and 48C). After the card has been delivered into the die plates 469 and 470, where it is held by the card stop 471, and after the set bars 453 have been set from the accumulator wheels the die plates 469 and 470 are raised. The punches 454 are provided with heads 454a which normally rest on a fixed plate 478, the lower ends of the punches being then above the space between the die plates 469 and 470. When the die plates are raised the punches 454 are also raised by the card which is between the die plates but where a set bar 453 has been depressed the punch 454 cannot rise to the fullest extent and accordingly is caused to perforate the card. All those punches in respect of which a set bar has not been depressed are freely lifted by the card and do not perforate it.

After the card has thus been perforated with the final product the die plates 469 and 470 are lowered again and the card stop 471 is lowered by the cam 472 whereupon the card is fed out of the die plates by skid rolls 8c and is delivered to the card receiver 16 (Fig. 1) by the feed rolls 8b.

In order to raise and lower the die plates 469, 470 the latter are carried in a frame having a depending portion 479 with which engages one arm 480 of a bell crank pivoted to the machine frame at 481 and of which the other arm 482 carries a roll 483 engaging in a cam track 484 formed in a disc 485 secured to the punch shaft 5.

The set bars 453 are of the well known type in which the set bars in each column are mounted between upper and lower plates 486 and each set bar carries a pin 487 normally disposed above a corresponding cam projection 488 on a slide 489 which is pressed to the left by a spring 490 (Fig. 6). When any set bar 453 is depressed the corresponding pin 487 acting on the cam projection 488 pushes the slide 489 to the right and after the pin 487 has moved below the nose 488 the slide 489 is pushed to the left again by the spring 490 whereby the set bar 453 is locked in the depressed position. In order to release the set bars after the punching operation has been completed a resetting ball 491 is provided which is mounted to slide in the machine frame and carries at each end a pin 492 engaging with a slot in a lever 493 pivoted to the machine frame at 494, the lower end of each lever carrying a roller 495 engaging with a cam 496 on the punch shaft 8.

The whole number portion of the multiplier is set up in the stops 622 directly from the multiplier field of the card through wires in the connection box 636 acting through wires 638a in an intermediate connection box 637a.

The fractional portion of the multiplier may be punched in the card in the form of the numerator of the fraction which with 960 as denominator equals the fraction in the multiplier, e. g. $\frac{1}{3}$ may be punched as 320 in the card. In

such a case the number 320 would be entered directly into the stops 622x through wires in the box 636.

Alternatively the fraction may be punched directly in the card, e. g. $\frac{1}{3}$ may be represented by but a single hole. In that case the corresponding single wire in the multiplier side of the box 636 would be branched to set the appropriate stops 622x, e. g. the single wire representing $\frac{1}{3}$ would be branched to set stops representing 320.

Further by making the connection box 636 removable it can be exchanged for another wired for a different series of fractions in the multiplier.

15 Thus one connection box might be wired for halves, quarters, eighths and sixteenths and another connection box might be wired for thirds, sixths and twelfths.

20 In the machine particularly described with reference to the accompanying drawings the predetermined fraction $\frac{1}{960}$ of the multiplicand was employed because this fraction renders it possible to effect multiplication by a large range of fractions, for example, thirds, fifths, quarters, 25 eighths, tenths, twelfths, sixteenths, and thirty-seconds. If it is desired to multiply by fractions which cannot be exactly expressed with 960 as a denominator then some predetermined fraction of the multiplicand other than $\frac{1}{960}$ may be employed. For example by setting up $\frac{1}{336}$ of the multiplicand, fractional multipliers involving thirds, sevenths, quarters, eighths, twelfths and sixteenths may be handled.

30 In order to set up $\frac{1}{336}$ of the multiplicand the fractions connection box 639 and fractions stop basket 642 would have to be modified accordingly.

35 In order to render the machine capable of handling any fraction in the multiplier the fractions connection box 639 and fractions stop basket 642 may be made removable so that they can be replaced by a connection box and stop basket appropriate to the desired range of fractions. In such a case the setting bars SA . . . SX and the accumulator plates PA . . . PX would have to be capable of handling the maximum number of digits arising out of any predetermined fraction of the multiplicand which might occur.

Operation

50 In order that the operation of the various parts of the machine may be quite clear, the performing by the machine of a specific calculation will now be described by way of example.

55 In this example the multiplicand is £9937;16:8.9456 and the multiplier is $46^{\frac{53}{64}}$.

The greatest multiplicand which can be handled by the machine is £9999;19:11.9999d. and the greatest whole number multiplier is 99999. There are therefore eleven columns in the multiplicand field of the card and eight columns in the multiplier field, i. e. five for the whole number multiplier digits and three columns to the right of these five columns to receive the digits of the number which represents the fractional portion of the multiplier.

60 In the present example the number which represents the fractional portion of the multiplier will be 795 since

$$70 \qquad \qquad \qquad \frac{795}{960} = \frac{53}{64}$$

i.e. the fraction in the multiplier.

65 Accordingly the digits 46 795 will be punched in the first five multiplier columns, of which the first three digits from the right, i. e. the digits

5, 9 and 7 respectively are the units, tens and hundreds digits of the number which represents the fraction, while the last two digits, i. e. the digits 6 and 4, are the units and tens digits of the whole number portion of the multiplier.

In the multiplicand field the amount £9937:16:8.9456d. will be punched.

The cards are placed in the magazine 6 and it will be assumed that the card punched with the factors above referred to is the lowermost card in the stack and will thus be the first card to be fed.

To start the machine the starting button 46 is pushed to the right in Fig. 8 whereupon the lower end of lever 51 engages the pin 92 on link 90 and moves the latter to the left to close the motor switch. The movement of the button 46 also causes the lower clutch 36, 44 (Figs. 9 and 10D) to engage and set the selection shaft 4 in rotation. After performing one revolution the lower clutch 36, 44 disengages in the manner already described and the selection shaft 4 stops.

As already explained, when the sensing pin box 21 performed its last operation on the preceding pack of cards, there was no card in the pin box and accordingly the "no card" mechanism was set to stop the machine on the next revolution of the selection shaft 4. Accordingly at the end of the one revolution of the selection shaft 4 consequent upon the pressing of the starting button, the motor is switched off and it is necessary to press the starting button again in order to cause the machine to continue to operate.

Referring to the timing diagram of Fig. 51A, during the one revolution of the selection shaft 4 which occurs consequent upon the first depression of button 46, the picker 7 (Fig. 47A) reaches the first card at 115° and at 220° the card reaches the feed rolls 8 which convey it into the sensing pin box 21. At 201° the card stop 600 commences to open, is open at 230° and remains open until 290° returning to its normal uppermost position at 312°. At 300° the card reaches the card stop 600 and is arrested thereby.

At 50° in this one revolution of the shaft 4 the sensing pin box 21 begins to rise and is fully up at 85°, remaining in this position until 320° when it starts to descend to sense the first card which was arrested by the card stop at 300°. At 355° the pin box is completely down and at 360° the selection shaft 4 stops, with the sensing pins through the holes in the card.

The starting button 46 is then pressed again and the selection shaft 4 makes another revolution. At 50° in this second revolution the pin box 21 commences to rise, and is fully up at 85°. At 115° the picker 7 begins to feed the second card, the first card remaining in the pin box 21 until 230° when it is released by the card stop 600 and conveyed by the feed rolls 8a towards the punch unit indicated generally at 15 in Fig. 47A.

While the selection shaft 4 is making one revolution the punch shaft 5 is also making one revolution, being driven from the selection shaft by a chain and sprocket drive (Figs. 4A and 4B). Referring to Fig. 52 showing the timing of the punch shaft, the punch card stop 471 (Figs. 47A) is closed at the beginning of the cycle, and remains closed until 240° when it commences to open, becoming fully open at 285°. The punch card stop remains open until 340° and is fully closed again at 350°.

In the revolution of the selection shaft 4 consequent upon the second depression of button 46, the first card is released from the pin box 21 by

the card stop 600 at 230° and the feed rolls 8b convey the card towards the punch unit, in which it is arrested by the punch card stop 471 just after the latter has closed at 350°. At 360° the selection shaft stops with the first card in the punch unit and the second card in the sensing pin box 21.

During the revolution of the selection shaft 4 consequent upon the first depression of the button 46 the first card was sensed in the pin box 21 and accordingly the "no card" mechanism did not prevent engagement of the upper clutch 36a, 44a (Fig. 10B) so that the multiplication shaft 41 commences to rotate, the selection and punch shafts 4 and 5 remaining stationary due to disengagement of the lower clutch 36, 44.

During the next following revolution of the selection shaft 4, brought about by the second depression of button 46, the pin box 21 rises from 50° to 85° and thereby sets up the factors read from the first card, during the first cycle of the selection shaft, in the multiplier stop basket 620 and the multiplicand stop basket 621, and also during this second revolution of shaft 4, $\frac{1}{60}$ of the multiplicand is computed and then set up in the multiplicand stop basket 621.

When the sensing pin box 21 rises from 50° to 85° in the second revolution of the selection shaft 4 the sensing pins which found holes in the first card during the first cycle are rendered effective by the action of the shutter as described in British specification No. 401,012, and raise corresponding wires 635 in the connection box 636.

In the multiplier field the wires 635 raise, through intermediate pins 638 (Fig. 15), stops 622 corresponding to the digits punched in the multiplier field of the first card.

Referring to Figs. 4B and 13, in the present numerical example stops will be set in the multiplier stop basket 620 as follows. Reading from the top of Fig. 13, in the three columns of stops 622x there will be set the No. 5, the No. 9 and the No. 7 stops respectively, these being the values of the units, tens and hundreds digits of the number 795 which represents the fraction $\frac{5}{64}$ in the multiplier.

In the next two columns of stops 622 there will be set the No. 6 and the No. 4 stops, respectively, these being the values of the units and tens digits of the integral or whole number portion 46 of the multiplier. In the remaining three columns of stops 622 the zero stop in each column remains set since no other stop in the same column has been set.

The multiplicand stop basket 621 is normally so positioned that the multiplicand reading bars 111a . . . are in register with the columns of stops 632 (Fig. 4B) which receive the whole multiplicand.

Accordingly when the pin box 21 rises from 50° to 85° in the second cycle of the selection shaft 4 the pins which sense the multiplicand field of the card lift connection box wires 635 which set the whole multiplicand stops 632 representing the whole multiplicand (Figs. 10A, 10B and 37), while at the same time stops 641 in the fractions stop basket 642 (Figs. 14, 15, 20 and 47B) are set to represent the digits of the partial quotients of $\frac{1}{60}$ of the multiplicand, by means of the branch wires illustrated diagrammatically in Figs. 16a to 16d.

The multiplicand in the present example is £9937:16:8.9456d. and referring to Fig. 4B, this amount will be set up in the columns of whole multiplicand stops 632 of the multiplicand stop basket 621, which columns, as already explained,

are interdigitated with the columns of stops 831 for receiving $\frac{1}{600}$ of the multiplicand.

In this connection it is pointed out that at 50° in the revolution of shaft 4, cam 380 (Figs. 1, 7 and 10C) rocks shaft 372 clockwise (Figs. 1, 37 and 47B), whereby shutter 371 raises all the zero stops 632. The value stops representing the whole multiplicand are subsequently set by the rise of the pin box at 85° and the setting of any value stop resets the zero stop in the same column.

In the present example $\frac{1}{600}$ of the multiplicand £9937:16:8.9456d. gives the following partial quotient digits to be set up in the columns A to W respectively of the fractions stop basket 642 (Fig. 14).

$\frac{1}{600}$ of 0.0006d.
 $\frac{1}{600}$ of 0.005d.
 $\frac{1}{600}$ of 0.04d.

These three values are not set up because they are so small that they may be neglected if the product is required to the nearest penny.

16d) controlling column B of the fractions stop basket (Fig. 14), so that the No. 3 stop (.0003d.) is set in this column. The other wire 8D8 is connected to the No. 8 wire in column D (Figs. 16b and 16d) whereby the No. 8 stop (.008d.) is set in column D of the fractions stop basket.

The

pence
100

10 partial quotient of $\frac{1}{600}$ of 8d. is zero, so that in column G the zero stop 673 remains up, the fractions stop basket being of the type in which the zero stops are normally up and are lowered by the setting of a value stop in the same column.

15 In the units of shilling multiplicand denomination sensing of the digit 6/- results in the raising of the No. 6 wire in column MF (Figs. 16a and 16c) which through its offset wire MF6, having branches 6E5 and 6H7 (Figs. 16c and 16d), sets the No. 5 (.005d.) stop in column E and the No. 7 stop (.07d.) in column H of the fractions stop

	Pounds units	Shgs. tens	Shgs. units			Pence			Pence 10			Pence 100			Pence 1,000			Pence 10,000							
			W	V	U	T	S	R	Q	P	O	N	M	L	K	J	I	H	G	F	E	D	C	B	A
$\frac{1}{600}$ of 0.9d.																									9
$\frac{1}{600}$ of 8d.																									
$\frac{1}{600}$ of 6/-																									
$\frac{1}{600}$ of 10/-																									
$\frac{1}{600}$ of £7.																									
$\frac{1}{600}$ of £30.																									
$\frac{1}{600}$ of £900.																									
$\frac{1}{600}$ of £9,000.	9	1	7	8	0	6	9	7	1	5	7	5	2	5	7	0	7	0	5	6	8	0	3		

These partial quotients, when accumulated, as will presently be explained, yield £10:7:0.4592d. which is $\frac{1}{600}$ of the multiplicand £9937:16:8.9456d.

The setting up of the partial quotients of $\frac{1}{600}$ of the multiplicand will now be explained.

Referring to Figs. 16a and 16c it will be observed that the connection box wires in the columns MA, MB and MC for the ten thousandths of one penny, the thousandths of one penny and the hundredths of one penny respectively, have no branches connecting them to the wires 640 which set stops 641 in the fractions stop basket 642, the reason being that $\frac{1}{600}$ of any amount in these three lowest denominations is so small that it can be neglected. Accordingly the sensing of the amount of 0.0456d. in the multiplicand does not result in the setting of any stops in the fractions stop basket 642.

In the tenths of one penny denomination however the sensing of the digit 9 raises the No. 9 wire 635, in the corresponding column of the connection box 636 which column is represented at MD in the diagram Figs. 16a and 16c. This No. 9 wire in column MD has a branch MD9 (Figs. 16c and 16d) which is connected to the No. 9 wire 640 in the column of the fractions connection box 640 which controls the column A in the fractions stop basket (see Fig. 14). The stops in this column A receive the

pence
10000

component of $\frac{1}{600}$ of tenths of one penny. Accordingly in column A of the fractions stop basket the No. 9 stop (.0009d.) is set.

In the pence column of the pin box the sensing of the digit 8d. causes the No. 8 connection box wire in column ME (Figs. 16a and 16c) to be raised. This wire has connected to it a wire ME8 (Fig. 16c) which branches into two wires 8B3 and 8D8 of which wire 8B3 is connected to the No. 3 connection box wire in column B (Figs. 16b and 16d) and

35 basket. In columns C and K the zero stops remain up.

In the tens of shillings multiplicand denomination sensing of the digit one (10/-) results in the raising of the No. 1 wire in column MG (Figs. 16a and 16b) which through its offset wire MG1, having branches 1F5, 1I2 and 1L5 (Figs. 16c and 16d) sets the No. 5 stop (.005d.) in column F, the No. 2 stop (.02d.) in column I and the No. 5 stop (.1d.) in column L.

45 In the units of pounds multiplicand denomination sensing of the digit £7 causes raising of the No. 1 wire in column MH (Figs. 16a and 16b) which through its offset wire MH1 having branches 7J5, 7M1 and 1O1 (Figs. 16c and 16d) sets the No. 5 (.05d.) stop in column J, the No. 7 stop (.7d.) in column M and the No. 1 stop (1d.) in column O.

55 In the tens of pounds multiplicand denomination sensing of the digit 3 (£30) causes raising of the No. 3 wire in column MI (Fig. 16a) which through its offset wire MI3 having branches 3N5, and 3P7 (Figs. 16a and 16b) sets the No. 5 stop in column N (.5d.) and the No. 7 stop (7d.) in column P. In column S the zero stop remains up.

60 In the hundreds of pounds multiplicand denomination sensing of the digit 9 (£900) causes raising of the No. 9 wire in column MJ which through its offset wire MJ9 having branches 9Q9, 9T8 and 9V1 (Figs. 16a and 16b) sets the No. 9 stop (9d.) in column Q, the No. 8 stop (8/-) in column T and the No. 1 stop (10/-) in column V.

65 Lastly in the thousands of pounds multiplicand denomination the sensing of the digit 9 (£9000) causes raising of the No. 9 wire in column MK which through its offset wire MK9 having branches 9R6, 9U7 and 9W9 (Figs. 16a and 16b) sets the No. 6 stop (6d.) in column R, the No. 7 stop (7/-) in column U and the No. 9 stop (9) in column W.

The setting of the stops in the fractions stop basket 642 occurs simultaneously with the set-

ting of the multiplier stops 622 and the whole multiplicand stops 632 during the rise of the sensing pin box 21 from 50° to 85° in the second revolution of the selection shaft 4.

Referring to the timing diagram Fig. 51B, at 89° in the revolution of the selection shaft 4, the restoring bar 671 for the setting bars SA . . . SX (Figs. 3, 4C, 4D, 19, 20, 21a to 21h and 43D) begins to move to the left in Figs. 3, 45B and 46B, under the control of its cam track 744a (Fig. 10C) in cam disc 745 (Fig. 45A) thereby releasing the setting bars SA . . . SX to the action of their springs 686, 686a (Fig. 46B). This movement of the restoring bar 671 is completed at 114° and accordingly at this point all the setting bars SA . . . SX will have moved up to the stops 641 which have been set in the respective columns. In those columns in which no value stop is set the setting bar will remain held at zero by the corresponding zero stop 673 (Fig. 20).

At 118° the restoring bar 680 for the partial quotient accumulator plates PA . . . PX begins to descend under the control of its cam track 736 (Figs. 1 and 10C) thereby releasing the plates PA . . . PX to the action of their springs 681 (Fig. 3).

This movement of the restoring bar 680 is completed at 148° in the cycle (Fig. 51B) and accordingly at this point the plates PA . . . PX have completed their downward movement by which they add up the partial quotient digits set up in the fractions stop basket 642.

Referring to Figs. 21a to 21h the movements of these plates PA to PX are as follows:

The setting bar SA (Fig. 21a) has moved to the left to the No. 9 stop in column A and accordingly the left hand lug 686 will be below the tenth step 685 of the plate PA representing 9, the lug 690 merely sliding along the slot 691 in the fixed plate PY. Plate PA therefore moves down nine steps taking with it, by means of lug 690 engaging in slot 691 on plate PA, the flanged block 689 on the extension 688 of the reading bar SB. Lug 686 carried by this block 689 and serving to control plate PB will therefore be moved nine steps down.

The setting bar SB has moved to the left to the No. 3 stop in column B and accordingly has moved the lug 686 serving to control plate PB below the fourth step 685 of the plate PB, representing 3, the associated lug 690 sliding in the slot 691 in plate PA. But this lug 686 has already moved down nine steps so that plate PB will move down 12 steps in all, taking with it by means of lug 690 engaging in slot 691 in plate PB, the flanged block 689 on the extension 688 of setting bar SC. The lug 686 carried by this block 689 and serving to control plate PC will therefore be moved 12 steps down.

In column C no value stop was set, accordingly the setting bar SC will remain held at zero by the zero stop 673 in column C. The lug 686 serving to control plate PC has, however, been moved down 12 steps by the accumulated movements of plates PA and PB. Accordingly plate PC will be able to move down 12 steps, representing the sum of the

pence
10,000

amounts received by all the

pence
10,000

plates PA, PB and PC, (i. e. .0012d.).

The 12 steps downward movement of plate PC 75 one step.

will bring its second long step 695 into register with the lug 692 on the transfer slide TS2 which therefore moves to the right (Fig. 21a) one step bringing its lug 693 under the second transfer step 597 in transfer plate T2.

Transfer plate T2 therefore moves down one step taking with it the block 689 on setting bar SD whereby one unit is transferred to the

10 pence
1000

denomination.

Setting bar SD has moved to the left to the No. 8 stop in column D thereby bringing the lug 686 controlling plate PD below the ninth step 685 (representing 8) in that plate. Since this lug had already been moved down one step by transfer plate T2, the plate PD will move down nine steps taking with it the lug 686 (Fig. 21b) controlling the plate PE. This lug 686 is carried by the flanged block 689 in setting bar SE which is not shown in Figs. 21a and 21b but appears in Figs. 4D and 19.

Setting bar SE has moved up to the No. 5 stop in column E thereby bringing the lug 686 controlling plate PE (Fig. 21b) below the sixth step 685 (representing five) on that plate. Since this lug had already been moved down ten steps by the movement of plate PD, the plate PE will move down fourteen steps, taking with it the flanged block 689 on setting bar SF. The lug 686 controlling plate PF will therefore move down fourteen steps.

Setting bar SF has moved up to the No. 5 stop in column F thereby bringing the lug 686 controlling plate PF below the sixth step 685 (representing five) on plate PF. Since this lug had already been moved down fourteen steps by the accumulated movements of plates PD and PE, the plate PF will move down nineteen steps, representing the sum of the

45 pence
1000

amounts (.019d.) received by all the

45 pence
1000

plates PD, PE and PF including the transfer of one unit from

50 pence
10,000

received by plate T2.

This 19 step movement of plate PF will bring its second long step 695 in register with lug 692 on transfer slide TS3 which therefore moves to the right (Fig. 21b) one step, bringing its lug 693 under the second transfer step 697 in transfer plate T3.

Transfer plate T3 therefore moves down one step taking with it the block 689 on setting bar SG carrying the lug 686 controlling plate PG whereby one unit is transferred to the

65 pence
100

denomination.

In column G no value stop was set so that setting bar SG remains held at zero by the zero stop 673 in column G. The lug 686 serving to control plate PG has however been moved down one step by the transfer plate T3. Accordingly plate PG moves down one step taking with it the flanged block 689 on setting bar PH. The lug 686 controlling plate PH will therefore move down 75 one step.

Setting bar SH has moved up to the No. 7 stop in column H thereby bringing the lug 686 controlling plate PH below the eighth step 685 (representing 7) in that plate. Since this lug had already been moved down one step by plate PG, the plate PH will move down eight steps in all, taking with it the flanged block 689 on setting bar SI. The lug 686 controlling plate SI will therefore move down eight steps.

Setting bar SI has moved up to the No. 2 stop in column I, thereby bringing the lug 686 controlling plate SI below the third step 685 (representing 2) on that plate. Since this lug had already been moved down eight steps the plate PI will move down ten steps in all, taking with it the flanged block 689 on setting bar SJ. The lug 686 controlling plate PJ will therefore move down ten steps.

Setting bar SJ has moved up to the No. 5 stop in column J thereby bringing the lug 686 controlling plate PJ below the sixth step 685 (representing 5) on that plate. Since this lug had already been moved down ten steps, plate PJ will move down fifteen steps in all, representing the sum of the

pence
100

amounts (.15d.) received by all the

pence
100

plates PG, PH, PI and PJ including the transfer of one unit from

pence
1000

received by the transfer plate T3.

This fifteen step movement of plate PJ will bring its second long step 695 into register with the lug 692 on transfer slide TS4 (Fig. 22c) which therefore moves to the right one step, bringing its lug 693 under the second transfer step 697 in transfer plate T5 (Fig. 21e). Transfer plate T5 therefore moves down one step taking with it the block 689 on setting bar SO carrying the lug 686 controlling the plate PO, whereby one unit is transferred to the pence denomination.

Transfer plate T4 therefore moves down one step taking with it the block 689, on setting bar SK carrying the lug 686 controlling the plate PK, whereby one unit is transferred to the

pence
10

denomination.

In column K no value stop was set, and accordingly setting bar SK remains held at zero by the zero stop 673 in column K. The lug 686 serving to control plate PK (Fig. 21d) has however been moved down one step by the transfer plate T4. Accordingly plate PK moves down one step, taking with it the flanged block 689 on setting bar SL. The lug 686 controlling plate PL will therefore move down one step.

Setting bar SL has moved up to the No. 1 stop in column L thereby bringing the lug 686 controlling plate PL below the second step 685 (representing 1) in plate PL. Since this lug had already been moved down one step by plate PK, the plate PL will move down two steps, taking with it the flanged block 689 on setting bar SM. The lug 686 controlling plate PM will therefore move down two steps.

Setting bar SM has moved up to the No. 1 stop in column M thereby bringing the lug 686 controlling the plate PM below the eighth step 685 (representing 7) in plate PM. Since this lug had already been moved down two steps, plate PM will move down nine steps taking with it the flanged block 689 on setting bar SN. The lug

686 controlling plate PN will therefore move down nine steps.

Setting bar SN has moved up to the No. 5 stop in column N thereby bringing the lug 686 controlling plate PN below the sixth step 685 (representing 5) in plate PN. Since this lug had already been moved down nine steps by plate PM, the plate PN will move down fourteen steps, representing the sum of the

pence
10

amounts (1.4d.) received by all the

pence
10

plates PK, PL, PM and PN, including the transfer of one unit from

pence
100

received by the transfer plate T4.

This fourteen step movement of plate PN will bring its second long step 695 into register with the lug 692 on transfer slide TS5 (Fig. 21d) which therefore moves to the right one step bringing its lug 693 under the second transfer step 697 in transfer plate T5 (Fig. 21e). Transfer plate T5 therefore moves down one step taking with it the block 689 on setting bar SO carrying the lug 686 controlling the plate PO, whereby one unit is transferred to the pence denomination.

In columns O, P, Q and R the stops 1, 1, 9 and 6 were respectively set. Accordingly setting bars SO, SP, SQ and SR will respectively move one, seven, nine and six steps to the left in Fig. 21e. The lug 686 on setting bar SO had already been moved down one step by plate T5, so that plate PO moves down two steps, taking with it the lug 686 on bar SP, whereby plate PP is allowed to move down $2+7=9$ steps. Lug 686 on bar SQ is thereby moved down 9 steps so that plate PQ moves down $9+9=18$ steps, taking with it the lug 686 on bar SR, whereby plate PR (Fig. 21f) is allowed to move down $18+6=24$ steps, representing the sum of the pence amounts (24d.) received by all the pence plates PO, PP, PQ and PR, including the transfer of 1d. from

pence
10

received by the transfer plate T5.

This twenty-four step movement of the plate PR represents two shillings and therefore the third long step 695 of plate PR will be in register with the lug 692 on transfer slide TS6 (Fig. 21f), which therefore moves to the right two steps, bringing its lug 693 under the third transfer step 697 (representing 2/-) on transfer plate T6. Transfer plate T6 therefore moves down two steps taking with it the block 689 on the setting bar SS carrying the lug 686 controlling plate PS, whereby two units are transferred to the units of shillings denomination.

In columns S, T and U, the stops 0, 8 and 7 were set respectively. Accordingly setting bar SS will remain at zero while setting bars ST and SU will respectively move eight and seven steps to the left in Fig. 21f. The lug 686 on setting bar SS had already been moved down two steps by plate T6, so that plate PS moves down two steps, taking with it the lug 686 on bar ST whereby plate PT moves down $2+8=10$ steps. Lug 686 on bar SU is thereby moved down 10 steps so that plate PU moves down $10+7=17$ steps, representing the sum

of the units of shillings amounts (17/-) received by the units of shillings plates PS, PT and PU including the transfer of 2/- from the pence denomination received by the transfer plate T6.

This seventeen step movement of plate PU brings the second long step 695 thereof into register with the lug 692 on transfer slide TS7 (Fig. 21g), which moves to the right one step, bringing its lug 693 under the second transfer step 697 (representing 10/-) on transfer plate T7. Transfer plate T7 therefore moves down one step taking with it the block 689 on the setting bar SV carrying the lug 686 controlling plate PV whereby one unit is transferred to the tens of shillings denomination.

In column V the No. 1 stop was set. Accordingly setting bar SV moves to the left one step. The lug 686 on setting bar SV had already been moved down one step by plate T7 so that plate PV moves down two steps, representing the sum (20/-) of the tens of shillings amount received by plate PV and the transfer of 10/- from the units of shillings denomination received by the transfer plate T7.

This two step movement of plate PV brings its second step 695 into register with the lug 692 on transfer slide TS8, which moves to the right one step, bringing its lug 693 under the second transfer step 697 (representing £1) on transfer plate T8. Transfer plate T8 therefore moves down one step taking with it the block 689 on the setting bar SW (Fig. 21h) carrying the lug 686 controlling plate PW whereby one unit is transferred to the units of pounds denomination.

In column W the No. 3 stop was set. Accordingly setting bar SW moves to the left nine steps. The lug 686 on setting bar SW had already been moved down one step by plate T8 so that plate PW moves down ten steps, representing the sum (£10) of the units of pounds amount received by plate PW and the transfer of £1 from the units of shillings denomination received by the transfer plate T8.

This ten step movement of plate PW brings its second step 695 into register with the lug 692 on transfer slide TS9, which moves to the right one step by bringing its lug 693 under the second transfer step 697 (representing £10) on transfer plate T9. Transfer plate T9 therefore moves down one step, taking with it the block 689 on the setting bar SX, carrying the lug 686 controlling plate PX whereby one unit is transferred to the tens of pounds denomination.

Setting bar SX does not move to the left as no amount was set up in a corresponding column of the fractions stop basket 642. Accordingly plate PX moves down only one step representing the amount (£10) transferred from the units of pounds denomination.

Although the foregoing movements of the plates PA . . . PX, lugs 686, transfer plates T2 to T9 and transfer slides TS2 to TS9 have been described separately, they all occur contemporaneously so that the plates PA . . . PX reach their set positions before 171° in the revolution of the selection shaft 4 (Fig. 51B) at which time the restoring bar 702 (Figs. 20 and 45B) for the reading bars R1 to R9 commences to move to the right (Fig. 20) under control of its cam track 751 in cam disc 745 (Figs. 10C and 45A).

Restoring bar 702 has completed its travel to the right at 196° (Fig. 51B) in the revolution of the selection shaft permitting springs 703 (Fig. 47B) to pull the reading bars R1 to R9 to the right (Figs. 20, 47B and 21a to 21h).

Referring to Figs. 21a to 21h, the

pence
10,000

5 plate PC has, as described above, moved down 12 steps, whereby the lug 701 on reading bar R1 is in register with the second step in the upper series of steps 700 in plate PC. Reading bar R1 therefore moves to the right two steps, thereby registering .0002d.

The

pence
1000

15 plate PF has moved down 19 steps, whereby the lug 701 on reading bar R2 is in register with the ninth step in the upper series of steps 700 in plate PF. Reading bar R2 therefore moves to the right nine steps, thereby registering .009d.

The

pence
100

20 plate PJ has moved down 15 steps whereby the lug 701 on reading bar R3 is in register with the fifth step in the upper series of steps 700 in plate PJ. Reading bar R3 therefore moves to the right five steps, thereby registering .05d.

The

pence
10

25 plate PN has moved down 14 steps whereby the lug 701 on reading bar R4 is in register with the fourth step in the upper series of steps 700 in plate PN. Reading bar R4 therefore moves to the right four steps, thereby registering .4d.

30 The pence plate PR has moved down 24 steps and as there are 12 steps in each of the two lower series of steps 700 in the plate PR the lug 701 on the reading bar R5 will be in register with the zero step in the third (uppermost) series of steps 700 in plate PR. Reading bar R4 therefore does not move at all, registering zero pence.

The units of shillings plate PU has moved down

35 17 steps whereby the lug 701 on the reading bar R6 is in register with the seventh step in the upper series of steps 700 in plate PU. Reading bar R6 therefore moves to the right seven steps, registering 7/-.

40 The tens of shillings plate PV has moved down two steps whereby the lug 701 on reading bar R7 is in register with the top step 700 in plate PV, which step represents zero. Reading bar R7 will therefore not move at all, registering zero in the tens of shillings denomination.

45 The units of pounds plate PW has moved down 10 steps and as there are ten steps in each of the two series of steps 700 in plate PW, the lug 701 on reading bar R8 will be in register with the zero step in the second (upper) series. Consequently reading bar R8 also does not move, registering zero in the units of pounds denomination.

50 The tens of pounds plate PX has moved down one step and consequently the lug 701 on reading bar R9 will be in register with the first step in the lower series of steps 700 in plate PX. Accordingly reading bar R9 will move to the right one step, registering £10.

55 These movements of the reading bars R1 to R9 position the upward projection 724 at the free ends of the swinging members 721 (Figs. 4B and 20), pivoted to the reading bars at 722, beneath the stops 631 in the multiplicand stop basket corresponding to the values to which the respective 60 reading bars have been set.

At 208° in the revolution of the selection shaft 4 the cam 756 (Figs. 1 and 10C) rocks lever 754 clockwise (Fig. 1) thereby pulling down link 753 and rocking shaft 728 clockwise (Figs. 1 and 20) whereby arms 727 lift the bar 726 which in turn lifts all the swinging members 721 to set the stops 631 under which their ends 724 have been positioned.

Referring to Fig. 4B in which the multiplicand stop basket appears in plan it will be remembered that the columns of fractional multiplicand stops 631 are interdigitated with the columns of whole multiplicand stops 632. In the

pence	
10,000	

column of stops 631 (topmost column in Fig. 4B) the No. 2 stop is set; in the

pence	
1000	

column the No. 3 stop; in the

pence	
100	

column the No. 5 stop, and in the

pence	
10	

column the No. 4 stop. In the pence column the zero stop is set. (In this stop basket all stops including the zero stop are normally down.) In the units of shillings column the No. 1 stop is set; in the tens of shillings and units of pounds columns the zero stops are set, and in the tens of pounds column the No. 1 stop is set.

The result, therefore, is that in the columns of stops 631 of the multiplicand stop basket 621, the amount £10:7:0.4592d. is set up, this being $\frac{1}{990}$ of the multiplicand £9937:16:8.9456d., which is set up in the stops 632.

It may here be pointed out that at 50° in the revolution of shaft 4, cam 380 (Figs. 1 and 10C) rocks shaft 372 clockwise (Figs. 1, 37 and 47B) to raise all the zero stops in the multiplicand stop basket, these stops being normally down. The subsequent setting of value stops due to the rise of the pin box 21 at 85° , however, lowers the zero stops in all columns in which a value stop is set, so that in the present example no zero stops remain up in the columns of stops 632.

At 216° in the revolution of the selection shaft 4 the cam 756 permits the swinging members 721 to drop under their own weight assisted by their springs 723 (Fig. 20).

From 226° to 251° the cam 751 positively returns the restoring bar 702 to normal position and the reading bars R1 to R9 follow it under the action of their springs 103.

From 240° to 250° the cam 763 (Fig. 45A) rocks lever 762 clockwise, which through link 761 rocks shaft 759 counterclockwise, whereby restoring bar 757 (Figs. 20, 45A and 47A) is moved to the left to restore the transfer slides T2 to T9, the bar 757 returning from 295° to 305° .

From 255° to 290° the cam 744a positively raises the restoring bar 688 which in turn lifts the plates PA to PX up to their normal positions.

Then from 290° to 320° cam 744a in disc 745 (Figs. 45A and 10C) acting through lever 744 and links 743 and 746 rocks shaft 739 clockwise to move restoring bar 671 to the right (Fig. 47B) to restore the reading bars SA to SX.

Finally at 345° in the revolution of the selection shaft 4 the cam 856 (Figs. 1 and 10C) lifts

link 852 (Figs. 1, 10C and 10A) whereby bell crank 858 is rocked clockwise (Fig. 10A), whereby, through link 848 and arm 848, shaft 846 (Figs. 10A and 40) is rocked counterclockwise.

As shaft 846 rocks, arm 845 thereon, acting on abutment 847 (Figs. 13 and 40), pushes the multiplicand stop basket 621 slightly to the right in Fig. 40, thereby relieving the load on latch 843.

When the stops in the multiplier stop basket 10 were set, the raising of a stop in the extreme right hand column 622x (Fig. 13) rocked the corresponding latch 826 clockwise (Fig. 38), whereby the lug 827 moved pin 818 down into the lower part of the slot 817 in the slide 812 associated with the escapement bar 172.

Accordingly when the load on latch 843 is released by cam 856, spring 828 (Fig. 38) pulls slide 812 to the left relatively to the escapement bar 172 and cam slot 825 in said slide, acting on pin 824, rocks lever 821 counterclockwise whereby pin 823 is moved down and rocks latch 843 counterclockwise in Fig. 41, clear of the multiplicand stop basket 621. The spring 840 (Fig. 4B) thereupon moves the multiplicand stop basket 621 to the left of the machine (left in Fig. 10B, down in Fig. 4B) to bring the fractional multiplicand stops 631 into register with the multiplicand reading bars 111a to 111m.

At the same time the movement of the slide 30 812 relatively to the escapement bar 172 has brought the slots 829 and 831 out of alignment and the slots 830 and 832 into alignment (Figs. 10A, 12 and 38) whereby the extreme right hand multiplier reading bar 110a is free to take a 35 reading from the extreme right hand column of stops 622x, all the other multiplier reading bars being held back by the bars 172 and 812.

At 360° the selection shaft 4 stops, and the multiplication shaft 41 commences to rotate. In 40 the present example there are five digits in the multiplier and accordingly the multiplication shaft 41 will make five revolutions, each herein-after referred to as a multiplying cycle.

At the beginning of any revolution of the multiplication shaft 41 the tens multiple stop basket 346 is in its lowermost position (see Fig. 50B) but as at the beginning of the first multiplying cycle there are no stops set in the tens multiple stop basket the multiplicand reading bars 111a . . . 111m are free to move up to the stops of the multiplicand stop basket 621.

At 4° (Fig. 50B) in the first multiplying cycle the cam tracks 155, 155a (Fig. 22) in discs 156, 156a (Figs. 4, 10A, 10B, 48A and 48B) commence 55 to rock the restoring bars 147 and 162 (Fig. 24) to the right, to release the multiplier and multiplicand reading bars to the action of their springs.

The multiplicand reading bars 111a . . . 111m 60 move up to the stops in the columns 631 in the multiplicand stop basket 621, but all save the extreme right hand multiplier reading bar 110a are prevented from moving more than one step by the escapement bar 172. The bar 110a, however, passes through the slots 830 and 832 in the slide 812 and bar 172 and engages the No. 5 stop in the extreme right hand column 622x of the multiplicand stop basket.

Referring to Figs. 24 and 46B, as the bar 70 110a moves to the right it rocks lever 160 whereby latch 165 is brought clear of bar 168 and rocks clockwise into engagement with the auxiliary restoring bar 163. Lever 160 also pushes bar 163 to the right thereby rocking arms 164 and 164b. Arm 164b pushes rack 221 to the

left whereby shaft 217 is rotated counterclockwise until the No. 5 cam 214 (Figs. 23, 24, 48A and 48B) overlies the nose 218 of the latch 211 associated with the No. 5 partial product plate 5P (Figs. 25 and 48B). By this means the partial product plate for the digit 5 in the lowest denomination of the number 795 representing the fraction $\frac{53}{64}$ in the multiplier is selected for operation.

Then at 34° the cam track 229 in disc 230 (Figs. 24, 46A and 48A) rocks shaft 232 counterclockwise whereby the No. 5 cam 214 rocks latch 211, thereby releasing latch 210a, 210b, so that the portion 210a moves over the ball 213.

At 43° track 233 in disc 230 (Figs. 29, 46A and 48A) rocks bell crank 236 counterclockwise whereby shaft 241 is turned and lifts bail 213 whereby the selected No. 5 partial product plate 5P is lifted.

At 34° the multiplicand reading bars had moved up to the stops 631 in the multiplicand stop basket, and were accordingly positioned in accordance with the digits of $\frac{1}{64}$ of the multiplicand, i. e. £10:7:0.4592d. That is to say the bars 111a, 111b, 111c and 111d will have moved to the right in Fig. 4, by 3, 10, 6 and 5 units of movement respectively, i. e. one unit more than the value of the corresponding digit because in the rest position the multiplicand reading bars are one unit behind the zero position. The pence bar 111e will move one unit, and the units of shillings bar 111f will have moved 8 units. The tens of shillings and units of pounds bars 111g and 111h move one unit, and the tens of pounds bar 111i moves two units. Bars 111j, 111k, 111l and 111m move one unit.

Considering bar 111f which appears in Fig. 26, the eight units of movement of this bar will bring the depending fingers F11 and F12 over the fifteenth and sixteenth transmission bars 778 which themselves are over the pair of steps in the partial product plate 5P representing

7/- $\times$ 5 = 35/-

Thus the raising of the plate 5P will lift the fifteenth bar 778 and through it the finger F11 (which is one of the longer fingers) six units, representing five shillings plus the one extra unit required for the reason already explained, while the sixteenth bar 778 and the shorter finger F12 will be raised three units representing 3 ten shilling units.

Referring to Fig. 25 the following table gives the number of units by which the different fingers F1 to F24 will be raised to represent the partial products of the amount £10:7:0.4592d. multiplied by 5.

Multipli-cand reading bar	Multipli-cand digit	Partial product		
		Units	Tens	
111a.....	2	1	0	Finger F1 raised 1. Finger F2 raised 1.
111b.....	9	4	5	Finger F3 raised 6. Finger F4 raised 4.
111c.....	5	2	5	Finger F5 raised 6. Finger F6 raised 2.
111d.....	4	2	0	Finger F7 raised 1. Finger F8 raised 2.
111e.....	0	0	0	Finger F9 raised 1. Finger F10 not raised.
111f.....	7	3	5	Finger F11 raised 6. Finger F12 raised 3.
111g.....	0	0	0	Finger F13 raised 1.
111h.....	0	0	0	Finger F14 raised 1. Finger F15 not raised.
111i.....	1	0	5	Finger F16 raised 6. Finger F17 not raised.

There are no partial products to be transmitted by fingers F18 to F24 and accordingly fingers F18, F20, F22 and F24 are raised by one unit representing zero plus the one extra unit already referred to, while fingers F19, F21 and F23 are not raised.

The movements of fingers F1 to F17 are transmitted to corresponding setting rods SR1 to SR17 (Fig. 25) and at 77° the cam track 261 in disc 158 (Fig. 46A) rocks the restoring bar 260 for the partial product accumulator plates RP1 to RP4 (Fig. 25) to the left in Fig. 45B, whereupon the plates move to the left to take up a setting from the corresponding setting rods. (See also Figs. 27 and 27A.)

In the first multiplying cycle wherein

£10s7:0.4592d.

is multiplied by 5 the plate RP1 receives the

20 pence
10,000

component of .0002d. $\times$ 5 which is zero. The 25 pence
10,000

component of the product of £10:7:0.4592d. has to be read off from plate RP1, which therefore is formed with steps such as the steps 800, 800a shown in the plate RP11 in Fig. 27, with which 30 steps cooperates a reading element 801. Consequently for the reason already explained plate RP1 actually moves 1 step although the amount to be registered thereby is zero. Plate RP3 receives the sum of the 35 pence
1000

component of .0002d. $\times$ 5, which is 1, and the 40 pence
1000

component of .009d. $\times$ 5, which is 5. Plate RP3 moves, however not $1+5=6$, but seven steps i. e. one step more than the amount actually registered thereon.

Plate RP5 receives the sum of the

pence
100

50 component of .009d. $\times$ 5 which is 4, and the 55 pence
100

component of .05d. $\times$ 5 which is 5. Plate RP5 therefore registers $4+5=9$ but actually moves ten steps including the one additional step already referred to.

Plate RP7 receives the sum of the

pence
10

60 component of .05d. $\times$ 5 which is 2, and the 65 pence
10

component of .4d. $\times$ 5 which is zero. Therefore plate RP7 registers $2+0=2$ but actually moves 3 steps, including the one additional step already referred to.

Plate RP8 receives the sum of the pence component of .4d. $\times$ 5 which is 2d., and also the pence component of 0d. $\times$ 5 which is zero. Plate RP8 therefore registers $2+0=2$, but actually moves 3 steps including the one additional step already referred to.

75 Plate RP11 receives the sum of the units of

shillings component of $0d \times 5$ which is zero and the units of shillings component of $7/ \times 5$ which is 5. Plate RP11 therefore registers $0+5=5$ but actually moves 6 steps including the one additional step already referred to.

Plate RP13 receives the tens of shillings component of $7/ \times 5$ which equals 3, but moves 4 steps including the one additional step already referred to.

There is no ten shillings digit in the fractional multiplicand, so that the plate RP13 only receives the 3 units above mentioned, although it moves 4 steps as above stated.

In the units of pounds denomination the fractional multiplicand digit is also zero so that plate RP14 only receives the one unit transferred to it from the tens of shillings denomination. Accordingly plate RP14 therefore registers 1, but actually moves two steps including the one additional step already referred to.

Plate RP18 receives the sum of the £10 component of $£0 \times 5$ which is zero and the £10 component of $£10 \times 5$ which is 5. Plate RP18 therefore registers 5 although it moves six steps including the one additional step already referred to.

The plate RP17 registers zero because the £100 component of $£10 \times 5$ is zero. Likewise all plates RP18 to RP24 register zero, although plates RP18, RP20, RP22 and RP24 move the one additional step.

Accordingly when all the plates are set, the amount entered into the partial product accumulator is $£51:15:2.2960d.$ which is

$$£10:7:0.4592d. \times 5 = 5/960$$

of the whole multiplicand.

At 132° (Fig. 50A) the cam track 274 on disc 188 (Figs. 1, 30 and 48A) rocks arm 277 counterclockwise thereby rocking shaft 282 and lowering the restoring bar 272 for the control racks 270, this operation being completed at 162° .

At 164° (Fig. 50B) the accumulator wheels 291 (Fig. 31) are moved out of engagement with the transfer segments 321 under control of cam 304 acting through link 300, arm 289 and shaft 298 (Figs. 1 and 48A) and at 179° are fully in engagement with the racks 270.

From 178° to 211° the restoring bar 272 rises, restoring the racks 270 whereby the amount $£51:15:2.2960d.$ is entered into the accumulator wheels 291.

While the wheels 291 are still in engagement with the racks 270 the portion 333b of cam 333 (Figs. 1 and 32) rocks bail 325 almost into engagement with the tails 324 of transfer segments 321. At 220° the wheels are moved into engagement with the transfer segments again and bail 325 is permitted to rock clockwise in Fig. 31 by the low part 333c of cam 333, thereby releasing any transfer segments 321 of which the latches 314 were released by the passage of an accumulator wheel 291 beyond 9 (beyond 11 in the case of the pence wheel). In the first multiplying cycle this operation is idle because the accumulator wheels 291 were standing at zero before the product was entered into them, and therefore no transfers occur.

At 285° the wheels 291 are moved out of engagement with the segments 321 and then the highest part 333d of cam 333 rocks the bail 325 fully counterclockwise to reset any transfer segments 321 that have operated.

Finally at 330° the wheels 291 are moved into engagement again with the segments, being fully in engagement therewith at 345° .

From 211° to 241° (Fig. 50A) the partial product accumulator plates RP1 to RP24 are restored by their restoring bar 260 and from 212° to 220° the restoring bar 890 (Figs. 28, 43B and 47B) is actuated to restore the transfer slides TR1 to TR18 (Figs. 43B, 48A and 48B), under control of cam 185 on disc 186 operating through lever 182, link 897, lever 895, link 894 and shaft 892 (see also Fig. 43F).

From 80° to 110° (Fig. 50A) the cam track 228 on disc 230 (Fig. 24) rocks shaft 232 clockwise, thereby raising the partial product plate selector cams 214 to normal position, whereupon spring 211b rocks latch 211 counterclockwise under tail 210b of bell crank 210a, 210b.

From 241° to 266° cam track 233 on disc 230 (Fig. 29) rocks the toothed segment 238 counterclockwise thereby lowering the bail 213, whereby the No. 5 partial product plate 5P descends under the action of its spring (Fig. 25). As plate 5P descends the tail 210b of bell crank 210a, 210b pivoted to the plate engages the top of latch 211 whereby the portion 210a is rocked clear of bail 213.

While the product of $1/600$ of the multiplicand, ($£10:7:0.4592d.$) multiplied by the units digit 5 of the number 795 representing the fraction in the multiplier was thus being computed and entered into the partial product accumulator wheels 291, the tens multiple of $£10:7:0.4592d.$ was being computed and entered into the tens multiple stop basket 346.

As the multiplicand reading bars 111a . . . move up to the multiplicand stops 631 they raise 35 through gearing 800, 902 (Fig. 34) corresponding setting rods 335a . . . 335m (Figs. 3 and 43C).

The manner in which the digits 2 and 9 are set up on the

40

pence	
1000	

plate TM1 and the

45

pence	
100	

plate TM2 is the same as that in which the digit 5 is set up on the

45

pence	
10	

50 plate TM3. Referring to the

50

pence	
10	

plate TM3 (Fig. 33) the setting rod 335c is raised 55 to the 5 position by the

60

pence	
100	

multiplicand reading bar 111c, whereby the lug 60 903 is brought into register with the No. 5 step 904 on plate TM3.

The setting rod 335d for the pence plate TM4 is raised to the 4 position by the

65

pence	
10	

multiplicand reading bar 111d, whereby the pawl 905 is raised into register with the No. 4 step 907 on plate TM4.

70 The setting rod 335e for plates TM5 and TM6 does not rise since the pence digit is zero.

The units of shillings digit is 7 and accordingly the setting rod 335f rises 7 steps, bringing its lug 926 into register with one of the "1" steps 75 927 on the tens of shillings plate TM8. At the

same time the pin 832 lifts pawl 828 into register with the No. 3 step on the units of pounds plate units of pounds plate TM10.

The tens of shillings digit and the units of pounds digits are both zero. Accordingly the rods 335g and 335h do not rise.

The tens of pounds digit is 1 and accordingly rod 335i will rise one step causing plate TM12 to be set to 1, in like manner to the setting of plate TM3.

From 60° to 109° (Fig. 50A) the cam track 369a on disc 369 (Figs. 35 and 48B) rocks the toothed segment 1368 clockwise (Fig. 35), counterclockwise in Fig. 3, whereby the restoring bar 361 for the tens multiple accumulator plates is moved to the right in Fig. 34 releasing the plates to the action of their springs whereby they take a setting from the setting rods 335a . . . 335m.

This setting of the tens multiple plates brings their lugs such as L8 (Fig. 34) over that stop 347 in the corresponding column of the tens multiple stop basket 346 which represents the corresponding digit of the tens multiple.

From 109° to 144° the tens multiple stop basket rises to its uppermost position under the control of cam track 365 on disc 156a (Figs. 42 and 48B) which rocks shaft 350 (Fig. 45B) and lifts the basket by means of arms 349.

At 144° the stops 347 are set to the tens multiple of the previous multiplicand, i. e. to

$$10 \times £10:7:0.4592d. = £103:10:4.5920d.$$

which is $\frac{1}{990}$ of the whole multiplicand.

After the stops 347 are set the tens multiple stop basket 346 descends to its mid position which it reaches at 179° remaining there until 325° when it descends to its lowermost position.

From 184° to 264° the restoring bar 361 returns the tens multiple plates to normal position.

Then at 330° the stops 631 in the multiplicand stop basket 621 are reset by the shutter 395a on shaft 394, rocked by cam 870 (Figs. 10A, 10B, 42 and 48B) acting through lever 879 and link 879a. This action does not affect the whole multiplicand stops 632, which are at this time in register with the cut away portions of shutter 395a (Fig. 4B), and therefore remain set to the value of the whole multiplicand.

When, at 4° (Fig. 50A) the multiplier reading bar 110a moved forward, its slot 173 (Fig. 11) passed out of register with the escapement bar 172 and slide 812 and accordingly the escapement bar 172 is prevented from moving to the left (Figs. 10A, 12 and 38) under the action of spring 828.

From 212° to 220°, the cam 185 on disc 186 (Figs. 1, 10A, 39 and 48A) rocks lever 182 clockwise whereby through link 187 the housing 178 for the escapement pawl 176 is rocked clockwise about its pivot 178a, thereby bringing the pawl 176 to the right in Fig. 39 and clear of the teeth on the escapement bar 172. When the pawl 176 is thus rocked to the right it rocks clockwise about its pivot in Fig. 10A under the action of a spring plunger (not shown) mounted within the housing 178 as described in British specification No. 490,358. When the pawl has rocked clockwise it is located beside the next tooth of the escapement slide 172 to the right (Fig. 10A) of the tooth with which it was originally in engagement.

From 220° to 231° the cam 185 releases lever 182 to the action of spring 187 (Fig. 39) whereby housing 178 is rocked counterclockwise about its pivot 178a, bringing pawl 176 into register with

the tooth to the right of that with which it was originally in engagement.

From 280° to 320° the restoring bars 162 and 147 restore the multiplier bar 110a and all the multiplicand reading bars, and at 317° (Fig. 50A) the slot 173 (Fig. 11) in the multiplier bar 110a comes into register with the escapement slide 172 and bar 812. At that moment the spring 828 (Fig. 38) which is stronger than the spring within the housing 178 pulls the slide 812 and escapement bar 172 to the left (Fig. 10A), the pawl 176 rocking counterclockwise in Fig. 10A against the action of the spring within the housing 178.

By this means the slots 830 and 832 are brought into alignment with the second multiplier reading bar 110b in readiness for that bar to take a setting from the stops 622x in the second multiplying cycle.

At 335° to 345° the cam 870 (Figs. 10B, 48B and 42) rocks bell crank 871 counterclockwise thereby rocking shaft 875 counterclockwise (Fig. 10B) and pulling link 877 to the right so that shaft 858 is rocked counterclockwise in Figs. 10A and 40. This operation is for the purpose of restoring the multiplicand stop basket 621 to its normal position to the right (Figs. 10A, 10B and 40) but is idle in the first multiplying cycle because the escapement bar 172 has not yet moved sufficiently to bring cam surface 886 on block 882 (Figs. 12, 13, 40 and 41) into register with the roller 861 so that arm 857 on shaft 858 remains out of register with block 847 on the multiplicand stop basket 621. Hence the rocking of shaft 858 and arm 857 is idle.

When the multiplier stops were set in the cycle of the selection shaft 4, the pawls 191 for the second and third columns 622x of the stops for receiving the number representing the fraction in the multiplier were released and moved out of the path of the pin 818 which was moved into operative relation with the pawls 191 by the relative movement of escapement bar 172 and slide 812 due to the release of pawl 826.

Since the pawl 191 for the second column of stops 622x was withdrawn the pin 818 did not engage this pawl and the escapement slide was able to move a full tooth pitch, whereby a space between two adjacent pins 195 on the escapement bar 172 was brought opposite the nose 196b of the clutch control feeler or lever 196 (Fig. 39).

At 349° (Fig. 50B) the cam 200b (Figs. 1, 10A and 39) rocks lever 200a clockwise, thereby lifting link 199 and rocking lever 196 clockwise. As a space between two adjacent pins 195 is opposite the nose 196b of lever 196, the latter is able to rock to the fullest extent, whereby link 199 rises without rocking counterclockwise about its pivot 200 and the pin 204 thereon does not rock the clutch control lever 206. Accordingly the clutch 60 is not operated at the end of the first multiplying cycle and the multiplication shaft 41 continues to rotate.

From the foregoing it will be seen that in the first multiplying cycle, $\frac{1}{990}$ of the whole multiplicand £9937:16:8.9456d. (i. e. £10:7:0.4592d.) was multiplied by the units digit 5 of the number 795 representing the fraction $\frac{53}{64}$ in the multiplier and the resulting product £51:15:2.2960d. was entered into the partial product accumulator 70 wheels 291.

Also the tens multiple of the amount

$$£10:7:0.4592d.$$

(i. e. £103:10:4.5920d.) was computed in the tens 75 multiple mechanism and set up in the tens mul-

iple stop basket 346. Further the multiplicand stops 631 in basket 621 in which the amount £10:7:0.4592d. was set up have been reset, but the multiplicand stops 632 still remain set to the amount of the whole multiplicand

£9937:16:8.9456d.

During the second multiplying cycle the tens multiple of $\frac{1}{990}$ of the multiplicand, i. e.

£103:10:4.5920d.

will be multiplied by the tens digit of the number 795 representing the fraction in the multiplier.

The one tooth movement of the escapement bar 172 has brought the slots 830, 832 into register with the second multiplier reading bar 110b so that in this cycle the bar 110b moves up to the No. 8 stops in the second column of stops 622x and selects the partial product plate 9P for operation. At the same time the multiplicand reading bars 111a . . . move forward and take a setting from the stops 347 in the tens multiple stop basket, which remains in its lowermost position until 109° in the cycle (Fig. 50B). The stops 631 of the multiplicand stop basket 621 do not interfere with this movement of the reading bars 111a . . . because these stops were reset at 330° in the first multiplying cycle.

Accordingly the partial products of

£103:10:4.5920d. 9

are computed and accumulated in the partial product accumulator plates RP1 to RP24, whence their sum (£931:13:5.3280d.) is transferred to the partial product accumulator wheels 291. These wheels already contain the amount

£51:15:2.2960d.

being the product obtained in the first multiplying cycle so that at the end of the second multiplying cycle the wheels 291 contain the amount

£983:8:7.6240d.

The movement of the multiplicand reading bars up to the tens multiple stops 347 set the rods 335a . . . for the tens multiple accumulator plates TM1 . . . so that these plates receive the tens multiple of the contemporaneous multiplicand £103:10:5920d., which tens multiple is £1035:3:9.9200d.

At 126° in the second multiplying cycle the cam 880 (Figs. 10B, 42 and 48B) rocks lever 881 counterclockwise whereby, through link 892, shaft 881 is rocked counterclockwise, thereby resetting the tens multiple stops 347 in the manner already described. Then at 109° the tens multiple stop basket 346 rises to take a setting from the plates TM1 . . . of the tens multiple mechanism, the stops 347 being set at 144° to the value of ten times the contemporaneous multiplicand, which value is 100 times the amount £10:7:0.4592d. and is equal to $\frac{100}{990}$ of the whole multiplicand.

After the tens multiple stops 347 have been reset the multiplicand reading bars are held in the set position by the aligner bar (not shown) described in British specification No. 490,358.

At 317° the escapement bar 172 and slide 812 move one further step and bring their slots 830, 832 into register with the third multiplier reading bar 110c and because the latch 191 corresponding to the third column of multiplier stops 622x has been withdrawn the pin 818 is not obstructed and the bar 172 and slide 812 make a full step movement. Consequently lever 196 is free to rock and the clutch is not operated so that the multiplication shaft continues to rotate.

During the third multiplying cycle the hundreds multiple £1035:3:9.9200d. of $\frac{1}{990}$ of the multiplicand is to be multiplied by the hundreds digit 7 of the number 795 representing the fraction in the multiplier.

Multiplier reading bar 110c moves forward to the No. 1 stop in the third column of stops 622x and selects the partial product plate 7P for operation. At the same time the multiplicand reading bars 111a . . . move up to the stops 347 in the tens multiple stop basket and become set to the amount £1035:3:9.9200d.

Accordingly the partial product of the amount £1035:3:9.9200d. $\times$ 7 are computed and accumulated in the partial product accumulator plates RP1 to RP24 and their sum £7246:6:9.4400d. is transferred to the accumulator wheels 291. These wheels already contain the amount

£983:8:7.6240d.

so that at the end of the third multiplying cycle the wheels 291 contain the amount

£8229:15:5.0640d.

25 The movement of the multiplicand reading bars up to the tens multiple stops 347 set the rods 335a . . . for the tens multiple accumulator plates TM1 . . . so that these plates receive the tens multiple of the contemporaneous multiplicand £1035:3:9.9200d. which tens multiple is

£10351:18:3.2000d.

Then at 109° in the third cycle the tens multiple stop basket 346 rises to take a setting from the plates TM1 . . . , the stops 347 being set at 144° to the above amount £10351:18:3.2000d.

At 317° the return movement of multiplier bar 110c releases the escapement bar 172 and this bar moves to the left one tooth space (Figs. 12 and 40) since the pawl 191 for the first column of whole number multiplier stops 622 corresponding to multiplier reading bar 110d is withdrawn. In so moving the escapement bar 172 brings the cam portion 866 of block 862 (Figs. 40 and 41) into register with the roll 861 whereupon spring 865 pushes arm 857, boss 863 and sleeve 864 to the left along shaft 858 (Fig. 41) rocking arm 860 counterclockwise. Arm 857 is thus brought into register with the block 847 on the multiplicand stop basket 621. Accordingly when, at 335° in the third cycle, cam 870 (Figs. 10B and 42) rocks shaft 858 counterclockwise in Fig. 40, arm 857 pushes the multiplicand stop basket to the right thereby restoring it to its normal position in which it is retained by the latch 843 in readiness for multiplication by the units digit of the whole number portion of the multiplier to be carried out in the fourth cycle.

60 At this time (end of the third cycle) the tens multiple stop basket 346 is down and its stops 347 are set to 1000 times the amount £10:7:0.4592d. (i. e. £10351:3:9.9200d.). In the fourth cycle, however, the multiplicand reading bars 111a . . . have to take a setting from the stops 632 in the multiplicand stop basket 621 which stops have been brought into register with these bars by the restoring movement of the multiplicand stop basket above described.

In order that the unwanted setting of the tens multiple stops 347 shall not interfere with the setting of the multiplicand reading bars from the stops 632, the restoration of the multiplicand stop basket 621 is caused to reset the tens multiple stops in the manner already described.

75 Accordingly in the fourth cycle the multipli-

cand reading bars are free to take a setting from the whole multiplicand stops 632 and become set to the value of the whole multiplicand £9937:16:8.9456d. Also multiplier reading bar 110d moves forward to the No. 6 stop in the first column of whole number multiplier stops 622, this stop representing the units digit 6 of the whole number portion of the multiplier. Accordingly partial product plate 6P is selected for operation and the partial products of the whole multiplicand £9937:16:8.9456d. multiplied by the units digit 6 of the whole number portion 46 of the multiplier are accumulated in the partial product accumulator plates RP1 to RP24 and their sum £59627:0:5.6736d. is transferred to the accumulator wheels 291. These wheels already contain the amount £8229:15:5.0640d., so that at the end of the fourth multiplying cycle the wheels 291 contain the amount

£67856:15:10.7376d.

The movement of the multiplicand reading bars up to the whole multiplicand stops 347 set the rods 335a . . . for the tens multiple accumulator plates TM1 . . . to the tens multiple of the whole multiplicand, i. e.

£99378:7:5.4560d.

and at 144° the tens multiple stops 347 are set to this amount.

At 317° the escapement bar 172 moves another full step, freeing the fifth multiplier reading bar 110e to take a setting from the multiplier stops in the fifth cycle.

Towards the end of the cycle, at 330°, the whole multiplicand stops 632 are reset by the bail 395a since the restoring movement of the multiplicand stop basket 621 has brought the resetting slides for these stops into register with the teeth 395b on this bail (Fig. 4B).

In the fifth cycle the multiplicand reading bars are set to the tens multiple £99,378:7:5.4560d. of the whole multiplicand and the multiplier reading bar 110e moves up to the No. 4 stop in the second column of whole number multiplier stops 622, so that partial product plate 4P is selected and the product of £99,378:7:5.4560d. multiplied by the tens digit 4 of the whole number portion 46 of the multiplier is computed and entered into the accumulator wheels 291. This product is £397,513:9:9.8240d., and since the wheels already contain the amount

£67,856:15:10.7376d.

they will, at the end of the fifth cycle, contain the amount £465,370:5:8.5616d. This amount is the final product, and is equal to the multiplicand £9937:16:8.9456d. read from the card multiplied by the multiplier 46 $\frac{5}{6}$, read from the card.

At 317° in the fifth cycle the escapement bar 172 attempts to move another step, but as the pawl 191 for the sixth column (corresponding to multiplier reading bar 110f) has not been withdrawn the pin 818 engages this pawl 191 and arrests the bar 172 midway between two teeth so that one of the pins 195 (Figs. 13 and 39) stands in the path of the lever 196.

Accordingly when, at 349° in the fifth cycle, the cam 200b lifts the link 199, the lever 196 is unable to rock and the pin 198 on link 199 rides up the surface 196a of the lever 196 thereby rocking link 199 slightly counterclockwise about its pivot 200 so that as link 199 rises its pin 204 engages under arm 206 and rocks shaft 207 counterclockwise (Fig. 39). At its other end

(Fig. 48B) shaft 207 carries an arm 207a connected by link 208 to the clutch mechanism so that rocking of shaft 207 disengages the clutch for the multiplication shaft 41 and engages the clutch for the selection shaft 4.

The multiplication shaft 41 therefore stops and the selection shaft 4 and punch shaft 5 start.

As already explained, during the previous revolution of the selection shaft 4 the first card (from which the factors multiplied during the five multiplying cycles described above were read) was conveyed to the punch unit 15 (Fig. 47A), and the product computed in the operations just described has now to be punched in this card.

Referring to Fig. 52 which shows the timing of the punch shaft, at 60° in the revolution of the punch shaft the accumulator wheels 291 are moved into engagement with the control racks 270, by cam 431 (Figs. 1 and 48C) acting through link 433 and shaft 298.

The restoring bar 272 for the control racks 270 is then (from 100° to 130°) moved down by cam 426 which rocks lever 428 and through link 280 rocks shaft 282 counterclockwise (Fig. 1). The racks 270 descend, turning the wheels 270 backwardly until the latter reach zero, whereby the final product is transferred to the racks 270.

Referring now to Figs. 3 and 31 as the racks 270 descend they move the punch setting racks 444 to the left through gears 442, whereby the setting blocks 450 are positioned over the connection box wires 451 corresponding to the punches

35 which are to be set.

From 140° to 160° the cam 467 rocks shaft 460 clockwise in Fig. 31 thereby lowering setting plate 445 and depressing the levers 448 carrying the setting blocks 450 whereby the latter depress the

40 wires 451 which in turn set the punch set bars 453 (Fig. 6).

At the same time cam 535 operates the accumulator transfer bail 325 (Fig. 31) through link 531.

45 Then from 170° to 230° the punch cam 484 (Figs. 6 and 48C) lifts the die plates 469, 470 to effect punching of the final product in the card from which the factors were read, after which from 240° to 285° the punch card stop 471 is 50 opened by cam 472 to permit the punched card to be ejected by the feed rolls 85.

Finally from 290° to 310° the cam 496 operates to restore the set bars 453.

During this revolution of the punch shaft 5 55 the selection shaft 4 is also rotating.

At 5° in the revolution of the selection shaft 4 the cam 409 on disc 22a (Figs. 1, 7 and 10C) rocks levers 407b and 407 (see also Fig. 45A) clockwise whereby link 406 is pulled down and rocks shaft 403 (Figs. 1, 10A, 15 and 45B) also clockwise, whereby shutter 404 (Figs. 4B and 15) resets the multiplier stops 622 and 622x. At the same time the lug 410 on shutter 404, which overlaps the shutter 395a, rocks the latter, thereby resetting 65 the multiplicand stops 632. Also pin 895 on lever 894 on shaft 403 rocks lever 896 and shaft 881 to reset the tens multiple stops 347, this operation of resetting all three stop baskets occurring at 30° (Fig. 51A).

70 From 6° to 65° the cam 424 (Figs. 1, 7 and 10C) rocks lever 422 clockwise, lifting link 421 and whereby link 418 (Fig. 10A) is raised and rocks the lever 416 clockwise, so that bar 417 on the end of said lever restores the escapement bar 75 172 and slide 812 to their normal positions.

In this operation, bar 411 also moves slide 812 to the right relatively to the escapement bar 812 whereby lever 821 (Fig. 38) is raised to its normal position and pin 818 re-engages the upper part of the slot 819 to retain the slide 812 and bar 172 in their normal relative positions.

As the bar 172 is returned to the right the cam surface 866 on block 862 (Fig. 40) engages roller 861 and rocks lever 860 clockwise about the stud 859 thereby pushing arm 857 along shaft 858 into the normal position shown in Fig. 41.

At 115° in this revolution of the shaft 4 the picker 7 reaches the third card, and at 220° the third card reaches the feed rolls 8. At 230° the pin box card stop 600 releases the second card which is conveyed to the punch unit and arrested by the punch card stop 471 which closes at 350°. At the end of the revolution the third card is in the pin box, the second card is in the punch unit and the first card has been punched and ejected.

The multiplication shaft 41 then starts to rotate and the product of the factors read from the second card is computed and entered into the accumulator wheels 291 after which the shaft 41 stops and the selection shaft 4 and punch shaft 5 make another revolution, during which the second card is punched and ejected and the third card is fed up to the punch card stop.

What I claim is:

1. A machine for multiplying an amount by a whole number and/or a fraction, comprising four set-up devices, means for entering a multiplicand into one of said set-up devices, a dividing mechanism operative under the control of said multiplicand entering means to divide the multiplicand by a predetermined divisor and enter the resulting quotient into another of said set-up devices, means for entering into the third set-up device the integral portion of the multiplier and also a different multiplier which represents the fractional portion of the multiplier, means for multiplying a multiplicand by a single digit multiplier, means for causing the multiplying means to perform a number of successive multiplying operations equal to the number of digits in the integral portion of the multiplier and in the different multiplier which represents the fractional portion of the multiplier, means operative at each multiplying operation to set up in the fourth set-up device a predetermined multiple of the contemporaneous multiplicand, means whereby during the first of a series of successive multiplying operations the multiplying means is placed under the control of the set-up device which contains the quotient obtained from the dividing mechanism, while during subsequent multiplying operations said multiplying means is placed under the control of the set-up device in which the predetermined multiples are set up, until multiplication of the said quotient by all the digits of the number representing the fractional portion of the multiplier has been completed, means for then erasing the predetermined multiple set-up, means for then placing the multiplying means under the control of the set-up device containing the whole multiplicand during one multiplying operation only, and means for thereafter placing said multiplying means again under the control of the predetermined multiple set-up device until multiplication of the whole multiplicand by the integral portion of the multiplier has been completed.

2. A machine for multiplying an amount by a

whole number and/or a fraction, comprising a multiplicand stop basket having two sets of denominational columns of stops, means for entering the multiplicand directly into one of said sets of stops, a plurality of groups of accumulator elements, one group for each denomination of a predetermined fraction of the multiplicand, and each group containing a number of elements sufficient to receive all the partial quotient digits arising in the associated denomination from the division of the multiplicand by the denominator of the predetermined fraction, a dividing mechanism operative under the control of the multiplicand entering means to divide the multiplicand by said denominator and to enter the resulting partial quotient digits into said accumulator elements, means for reading from each group of accumulator elements the digit, in the associated denomination, of the sum of the partial quotient digits received by the group, means for entering the digits thus read into the other set of stops in the multiplicand stop basket, a multiplier receiving device, means for entering into said multiplier receiving device the integral portion of the multiplier and also a different multiplier which represents the fractional portion of the multiplier, multiplying means, means for causing said multiplying means to effect multiplication of the multiplicand set up in said first mentioned stops by the integral portion of the multiplier, means for causing said multiplying means to effect multiplication of the amount set up in said second mentioned stops by the different multiplier which represents the fraction in the multiplier, and means for adding the two products thereby obtained.

3. A multiplying machine according to claim 2, wherein the whole multiplicand is entered directly by connection wires actuated by sensing elements which read the multiplicand field of a perforated record, and certain of said direct connection wires are operatively connected to one or more other connection wires corresponding to the digits of the partial quotients obtained by dividing the value, assigned to the direct connection wire, by the denominator of the predetermined fraction, said other connection wires serving to set stops in a fractions stop basket containing denominational groups of columns of stops, one column to each partial quotient accumulator element, there being also provided means for setting said accumulator elements from said stops.

4. A multiplying machine according to claim 2, including a multiplier stop basket settable by the multiplier entering means and containing one group of columns of stops to receive the integral portion of the multiplier and a second group of stops to receive the number which represents the fractional portion of the multiplier, a multiplier reading bar for each column of stops, an escapement device permitting said reading bars to operate consecutively, and means operative under the control of the multiplier stops to cause the reading bar corresponding to the lowest denomination of the integral portion of the multiplier to operate first when the multiplier contains a whole number only, or the reading bar corresponding to the lowest denomination of the number representing the fraction to operate first when the multiplier contains a fraction.

5. A multiplying machine according to claim 2, including a multiplier stop basket, containing one group of columns of stops to receive the integral

portion of the multiplier and a second group of columns of stops to receive the number representing the fractional portion of the multiplier, means for setting said multiplier stop basket from the multiplier entering means, a multiplier reading bar for each column of stops, said bars having recesses which are in alignment when the bars are in their normal positions, an escapement slide passing through said recesses and having two recesses the first of which is normally in register with the multiplier reading bar for the units digit of the integral portion of the multiplier, while the second recess in the escapement slide is normally in register with the multiplier reading bar for the units digit of the number representing the fractional portion of the multiplier, an auxiliary slide disposed adjacent the escapement slide and having two recesses, the first of which is normally in register with the first recess in the escapement slide, while the second is normally out of register with the second recess in the escapement slide whereby normally movement of the reading bar for the units digit of the integral portion of the multiplier is permitted and movement of the reading bar for the units digit of the number representing the fractional portion of the multiplier is prevented, means operative under the control of the multiplier entering means when the multiplier contains a fraction to cause relative movement of the two slides so as to bring their second recesses into register and their first recesses out of register, whereby movement of the reading bar for the units digit of the number representing the fractional portion of the multiplier is permitted and movement of the reading bar for the units digit of the integral portion of the multiplier is prevented.

6. In a machine for multiplying an amount by a whole number and/or a fraction, having a multiplier receiving device and means for entering into said multiplier receiving device the integral portion of the multiplier and also a number which represents the fractional portion of the multiplier, the combination of a plurality of obstructors, one for each denomination in the integral portion of the multiplier and in the number representing the fractional portion of the multiplier, except the lowest denomination of said last mentioned number, means for withdrawing the corresponding obstructor when a digit is entered in any denomination, an escapement member, means for moving said escapement member one step at each single-digit multiplying operation, a first abutment carried by said escapement member, and normally positioned to the extent of one-half of one step movement thereof behind the obstructor for the tens column of the integral portion of the multiplier, a second abutment carried by said escapement member and normally positioned clear of all the obstructors, and means operative, under the control of the multiplier entering means when a fractional multiplier is entered, to withdraw said first abutment clear of all the obstructors and to position said second abutment half of one step movement of the escapement member behind the obstructor for the tens column of the number representing the fractional portion of the multiplier, whereby when the multiplier contains a whole number, the escapement member will be arrested by engagement of the first abutment with the first obstructor standing in its path, while when the multiplier contains a fraction, the escapement member will be arrested

by engagement of the second abutment with the first obstructor standing in its path.

7. A machine for multiplying an amount by a whole number and/or a fraction comprising in combination a plurality of denominational multiplicand reading bars, a multiplicand stop basket slidable transversely of said reading bars and having one set of denominational columns of stops to receive one multiplicand, and a second set of denominational columns of stops to receive a different multiplicand, said basket being normally positioned with one of said sets of stops in register with the multiplicand reading bars, a multiplier stop basket containing one group of columns of stops to receive the integral portion of the multiplier and a second group of columns of stops to receive a number representing the fractional portion of the multiplier, a multiplier reading bar for each column of multiplier stops, an escapement device permitting said multiplier reading bars to operate consecutively, means operative under the control of said escapement device after the column of multiplier stops containing the highest denominational digit of the number representing the fractional portion of the multiplier has been read to shift the multiplicand stop basket into a position in which the other set of multiplicand stops is in register with the multiplicand reading bars.

8. A multiplying machine according to claim 7, wherein each multiplier reading bar has a recess, said recesses being in alignment when the bars are in their normal positions, and including in combination an escapement slide passing through said recesses, and itself having two recesses the first of which is normally in register with the multiplier reading bar for the units digit of the integral portion of the multiplier, while the second recess in the escapement slide is normally in register with the multiplier reading bar for the units digit of the number representing the fractional portion of the multiplier, an auxiliary slide disposed adjacent the escapement slide and having two recesses, the first of which is normally in register with the first recess in the escapement slide, while the second is normally out of register with the second recess in the escapement slide whereby normally movement of the reading bar for the units digit of the integral portion of the multiplier is permitted and movement of the reading bar for the units digit of the number representing the fractional portion of the multiplier is prevented, means operative under the control of the multiplier entering means when the multiplier contains a fraction to cause relative movement of the two slides so as to bring their second recesses into register and their first recesses out of register, whereby movement of the reading bar for the units digit of the number representing the fractional portion of the multiplier is permitted and movement of the reading bar for the units digit of the integral portion of the multiplier is prevented, means operative under the control of the two slides to displace the multiplicand stop basket into its other position when said relative movement between the slides occurs, and means operative under the control of the escapement slide to return the multiplicand stop basket to its normal position after the column of multiplier stops containing the highest denominational digit of the number representing the fractional portion of the multiplier has been read.

9. In a record controlled calculating machine,

means for performing division by a predetermined fixed number of an amount read from a record, comprising in combination record sensing means, a partial quotient stop basket including denominational groups of stops, each group containing a number of columns equal to the number of partial quotient digits which may occur in the associated denomination, a connection box for setting the stops under control of the sensing means, said connection box containing a column of connection wires for each de-

nomination of the dividend, certain of said connection wires having branches, each of which terminates in cooperative relation with a stop in a different one of said groups of stops, means for reading the settings of the stops in the partial quotient stop basket, means for accumulating the amounts so read, a quotient stop basket, and means for setting said quotient stop basket from said accumulating means.

10

ERNEST CHARLES McCLURE.
